UNITED STATES PATENT OFFICE.

WILLIAM NICHOLAS AND WILLIAM ACKERMAN, OF NEW YORK, N. Y., ASSIGNEES TO
UNITED STATES GRAPHTYPE COMPANY, A CORPORATION OF NEW YORK.

TYPE CASTING AND COMPOSING MACHINE.

964,677.

Specification of Letters Patent. Patented July 19, 1910.

Application filed February 26, 1908. Serial No. 417,898.

To all whom it may concern:

Be it known that we, WILLIAM NICHOLAS, a subject of the King of Great Britain, and WILLIAM ACKERMAN, a citizen of the United States, both residents of the city, county, and State of New York, have invented certain new and useful Improvements in Type Casting and Composing Machines, of which the following is a specification.

10 Our invention relates to monotype casting and composing machines.

More particularly our invention relates to a monotype machine in which the control is electrical, and fundamentally like that of 15 the so-called Goodson monotype machine, illustrated for example in U. S. Letters Patent, No. 530,481. Our invention in a sense, may be considered a development of the Goodson machine. The present machine, 20 however, presents many features novel to the art, whereby its capacity for work and its mechanical structure is such as to adapt it to the actual requirements of the trade.

The slugs or type bodies cast in machines 25 of the class above referred to were of but six sizes to a set. These sizes differed each from the next size by a unit of measurement which was one-sixth of a full "set" measurement. Type of a face properly not accommodated to any of the full sizes of slugs 30 offered by the machine had either to be contracted or expanded to the nearest of these six sizes. For certain grades of work, this distortion of the type was possibly not of 35 vital consequence; but for other work the machine was thereby rendered unavailable. Again machines of the class above referred to have heretofore had a capacity of but a hundred matrices in the matrix plate. This 40 number of matrices is inadequate for the greater part of the work for which a machine of this character should be available. The matrix capacity of the Goodson machine presented therefore a second limitation to its usefulness. Again with the few 45 sizes of slugs heretofore cast in such machines, satisfactory justification was not possible. The space quads in any line whenever of two sizes, had necessarily to differ, 50 the one from the other, by an amount equal to one-sixth of the full set measurement.

Such a variation gives an uneven appearance to the composition, and is, therefore, undesirable. Other monotype machines

while capable of casting of a sufficiently 55 small unit of set variation have not been able to cast type of over thirteen point, because of the nature of the matrix layout used therein. Our machine is capable of casting type of practically any point desired with a unit of set variations so small that the type so cast compare favorably for all practical purposes with founder's type. In a monotype machine, deficiencies such as 60 those noted in connection with the prior art are readily overcome. The various elements of a monotype machine have necessarily a peculiarly intimate and complex 65 relation to one another. A change in the number or disposition of matrices, or in the 70 number of available sizes of slugs, for instance, involves changes in the connections and elements throughout the machine, and practically involves its entire reconstruction.

With these and other considerations, a 75 first object of the present invention is an electrically controlled monotype machine capable of casting slugs of sixteen sizes, differing each from the next by a unit of measurement which is one-sixteenth of the full 80 set measurement, instead of one-sixth as in the Goodson machine; wherefore, the machine of this invention is capable of producing, for every type, a set size suitable for any size or style of face. In the evolution 85 and final attainment of this feature of the invention, we have devised various important novelties of structure, such for instance, as a movable mold stop carriage, and other 90 peculiarities in the style and adjustment of the mold parts.

A second object of invention is a monotype machine, wherein type may be cast from as many as two hundred and twenty-five matrices, without change of matrix 95 plate. This feature of the invention is necessarily interlinked to a large extent throughout the machine with the means whereby the first named object of the invention is accomplished.

A third object of the invention relates to a switch or circuit changer by means of which the circuits controlling the mold stops may be readily altered to accord to any one of a number of matrix plates or lay-outs, so 105 that no disconnection or interchange of wires is necessary when the lay-out is changed. As the lay-outs have frequently to be

changed with the varying character of composition required, this feature of the invention is of great importance.

A fourth object of the invention is to make 5 all justification additive in amounts of from one to sixty four units and distributable in full units to the spaces of the line in such a manner that no space quad in any line may vary from any other quad in that line by 10 more than one of the small units heretofore mentioned, so that a line, or in case of multiple justification, a section of a line as much as sixty-four units short may be brought to length. The means whereby we have in this 15 machine effected the justification, differs considerably in structure from anything heretofore known to the art. Since the justifier of a monotype machine controls the mold setting for space quads, this feature of our invention likewise has an intimate relation 20 to the novel mold control and structure heretofore mentioned.

A fifth object of the invention is the adaptation of the machine to multiple justification. This involves in the present machine means whereby the justification mechanism may operate, at intermediate points of the line, independently of the galley mechanism for delivering a completed line to the 25 galley, and at the end of the line in conjunction with such galley mechanism.

Other features of the invention are; an improved record tape feeding device; a type separator in the line for temporarily holding 30 the last delivered or uncooled type from previously set-up type, whereby the machine may cast slugs of large size at great speed, without possibility of adhesion of type in the line; an improved cut-out automatically 35 operable in event of over or under feed of line; an improved safety device in the galley whereby the shift of an over-fed line to the galley may not injure the galley mechanism; and various other objects which will herein- 40 after more particularly appear in connection with the accompanying drawings in which—

Figure 1 is a perspective view of the assembled machine from the left hand rear corner of the same. Fig. 2 is a top plan 45 view of the assembled machine. Fig. 3 is a view in side elevation of the assembled machine from the right hand side thereof. Fig. 4 is a view in side elevation of the assembled machine from the left hand side thereof. Fig. 5 is a view in front elevation of the machine, the door of the cam casing being removed to show the cam shaft. Fig. 6 is an enlarged top plan assembly view of a 50 section of the machine, the top of the cam casing and upper platform being removed to show the cams. Fig. 64 is a view in horizontal cross section through the end-of-line and justification cam member showing the clutch and gearing by which the same is connected to the cam shaft. Fig. 65 is a view in side elevation of the parts shown in Fig. 64. Fig. 66 is a perspective view of the trip for the clutch shown in Fig. 65. Fig. 67 is a view in elevation showing the switch for changing from working to setting circuits and vice versa. Fig. 68 is a detail view on the line 68—68 of Fig. 6 taken in cross section through the fulcrum shifting slide and lever to show the distance piece. Fig. 69 is a perspective view showing the distance piece mounted in the fulcrum shifting slide. Fig. 70 is a top plan view of the justifier, the justification setting slide, and the end-of-line slide. Fig. 71 is a view similar to that of Fig. 70, except that it is taken through the justifier on the line 71—71 of Fig. 85. Fig. 72 is a perspective view of the end-of-line slide. Fig. 73 is a broken detail perspective view of a part of the justification slide showing the pocket by which the same is locked to the end-of-line slide. Fig. 74 is a view in cross sectional elevation through the end-of-line and justification slides, showing means for locking the slides together. Fig. 75 is a view on the line 75—75 of Fig. 74. Fig. 76 is a perspective view of the block 484 of Fig. 74 with the locking pins therein. Fig. 77 is a detail view of the locking pin 483 of Fig. 74. Fig. 78 is a view showing the automatic cut-out and the various mechanisms for actuating the same. Fig. 79 is a detail perspective view showing the mechanism for controlling the cut-out from the line feed. Fig. 80 is a detail view of the circuit closer operated from the end-of-line slide in the case of an underfed line to effect the cut-out. Fig. 81 is a view in cross sectional elevation through the head of the galley showing the line shifting block and rule and the mechanism for operating the same the block and rule being shown in the position maintained by them during the setting up of a line. Fig. 82 is a view similar to Fig. 81, except that the parts are shown in position assumed in shifting the line to the galley. Fig. 83 is a view in cross sectional elevation showing the rule and a mechanism by which the same is operated from the end-of-line slide. Fig. 84 is a view in end elevation of the part shown in Fig. 83. Fig. 85 is a view in cross sectional elevation through the justifier. Fig. 86 is a perspective view of the justifier circuit changer contacts 625 and the mechanism for releasing the same step by step as the space quads are cast. Fig. 87 is a perspective view showing the justifier lever stops and the lever controlled thereby to set the justifier circuit changer. Fig. 88 is a view of the second circuit changer of the justifier 130

for reversing the connections from the first circuit changer to the selected mold stop magnets. Fig. 89 is a view in cross sectional elevation longitudinally through the circuit changer, shown in Fig. 88, showing the means for setting the same. Fig. 90 is a diagrammatic view showing the justifier stops and the circuits controlling the same. Fig. 91 is a table deduced from Fig. 90 showing the particular circuits employed for selecting any two desired stops where the space quads are to be of two sizes. Fig. 92 is a diagrammatic view of the justifier lever stops, the several circuits controlling the stops being indicated. Fig. 93 is a table showing the circuits of the justifier stops and of the justifier lever stops employed for controlling the mold setting when the space quads of a line are to be all of a size. Fig. 94 is a table indicating the justifier lever stop in each instance employed where the space quads are to be of two sizes. Figs. 95, 96, 97 and 98 together represent a chart showing the distribution of any amount of justification from one to sixty-four units among from one to twenty spaces in a line. Figs. 99, 100, 101 and 102 together comprise a chart showing the justifier, the justifier levers and the row 13 magnet circuits used for each of the justifications shown in the chart of Figs. 95 to 98 inclusive. Fig. 103 is a diagrammatic view of the line-cancel and matrix stop-action magnet circuits. Fig. 104 shows the matrix cam lever 94 locked against movement by means of a latch controlled from the matrix stop-action magnet, also shown. Fig. 105 is a plan view in cross section through the mechanism controlling the line-cancel switch. Fig. 106 is a view in cross sectional elevation on the line 106—106 of Fig. 105, showing also the line-cancel magnet and switch. Fig. 107 is a view of the line-cancel switch in one of the three positions assumed by the same. Fig. 108 is a view of the line-cancel switch in another of its positions. Fig. 109 is a diagrammatic view showing the end-of-line slide lock magnet circuit and the fulcrum shifting slide trip magnet circuit employed in the event of multiple justification. Fig. 110 is a view in elevation of the matrix changing lay-out switch and the row magnet circuit thereto. Fig. 111 is a top plan view of the lay-out changing switch in part shown in Fig. 110. Fig. 112 is a diagrammatic view of the justifier circuits and the space circuit. Fig. 113 is a view in end elevation of the circuit changing switch and switchboard. Fig. 114 is a plan view showing the connections of the justifier setting lever to the justifier slide 626.

The movements of the several mechanisms of the machine are, in the main, effected by cams affixed to a shaft 1 (see Figs. 1 to

6 inclusive), or by such cams in conjunction with springs placed under tension and released by the same. This shaft will herein-after be designated the cam shaft. The cam shaft is driven by an electric motor 2, (see Fig. 4) located on a shaft 3 beneath the platforms of the machine, and connected through a counter-shaft 3' with the cam shaft 1 by means of a pulley 4 on the shaft 3', a belt 5 and a pulley 6 on the shaft 1. The motor 2 is in turn operated from any suitable source of electricity, the ordinary lighting circuits being convenient for this purpose; and, in order that the current from whatever source may be fed to the motor at the proper strength and voltage there may be interposed between the motor and the supply mains, a rheostat (see Fig. 5). The shaft 1 also carries a hand wheel 8, in order that it may be actuated manually, when necessary or desirable.

Although many of the mechanisms receive their power of movement in each instance from the cam shaft, yet with certain of the mechanisms, the recurring movements so effected will not be uniform. The mold setting mechanism for example must have a movement variable in each instance according to the unit width of the particular type next to be cast, and similarly the extent and direction of movement of the matrix block must in each instance be such as to present to the mold the proper matrix for the next casting. In addition to those parts which have an ever changing movement, there are other parts which operate only on occasions, such for example as at the end of a line of composition; and again, there are parts which operate only under abnormal conditions, as when a line of composition is to be canceled. All movements positively effected by the cam shaft must naturally be constant, and there must, therefore, be a second class of mechanisms, the movements of which are not uniform, and which receive their power of movement from sources other than the cam shaft. In this second class of elements are the means for controlling or determining the movements of the mold setting mechanisms, and of the matrix block, and of the justifying mechanisms, etc. In it are also a number of clutches for applying the power of the cam shaft to various mechanisms to be operated only at the end of a line. The intermittently operating elements of this second class determines the composition to be produced by the machine, and are themselves controlled from a register, which in the present machine is the record strip or tape produced in the composing machine forming the subject matter of our co-pending application, No. 417,899 filed of even date herewith.

The tape effects its control of the various mechanisms through the medium of electro-

magnets, the circuits of which are made or broken by the tape. Whether such circuits are made or broken depends upon the position of the perforations in the tape, a circuit being made by the passage of a contact pin through the tape whenever the latter registers with a perforation, being or remaining broken when there is no such registering perforation. In describing the machine, therefore, we have to consider the operation of the mechanisms, first, as actuated by the movement of the cam shaft, and secondly, as controlled or determined in their movements by other mechanisms electrically operated from the tape. It will be convenient in the first place to describe the mechanism by which the tape is fed through the machine and the means for establishing the controlling circuits from the tape.

20 The feed of the record strip and the index head.—A section of a record strip is shown in Fig. 8. As described in connection with the composing machine, the tape as fast as it is perforated in that machine is taken up 25 and wound upon a spool. The spool of tape thus prepared for the casting machine is then removed from the composing machine, and as shown at 10 (see Fig. 5) is placed with its spindle 11 in the yoke 12 of 30 a standard 13 on the head 14 of the frame of the casting machine. The end of the tape (see Figs. 5 and 9) is then led under a friction guide 15 on a standard 16, in turn mounted on the standard 17 of the index head. Thence the tape is led up and through 35 a guide-way 18 in the index standard below the head of the latter, over a feed roll 19, down over an idler 20, and thence on to be fastened to a take-up roll or spool 21. It 40 will be noted that the tape is turned off the roll 10 and fed into the casting machine in a direction reverse to that in which it is fed onto the roll in the composing machine. The last perforation effected in the tape by 45 the composing machine will, therefore, be the first perforation to effect the operation of the casting machine.

The index head, indicated at 22 in Fig. 5 is shown in detail in Figs. 9, 10, 11, 12, 13 50 and 14. Along one edge of the tape (see Fig. 8), there extends a line of perforations 23 by means of which the tape is engaged and fed. These perforations are engaged by a series of teeth 24 on the roll 19 (see 55 Figs. 9 and 13). The roll 19 is rotated from the cam shaft 1, and in rotating moves the tape in the direction indicated by the arrow on Fig. 9.

The mechanism by which the roll 19 is 60 actuated from the cam shaft is as follows: Referring to Figs. 5 and 14, there is shown about the center of the cam shaft a cam 25 engaging a roller 26 on the end of a bell crank cam lever 27, pivoted at 28, on the 65 underside of the upper platform 14 of the

frame. A spring 28' attached to a post on the frame and to the lever 27 causes the roller 26 to follow the cam 25. The arm 29 of the lever 27 (see Fig. 14) is connected at its outer end to a link 30, which passes up 70 through an opening in the plate 14. The link 30 (see Fig. 12) is connected at its upper end to the lower end of a slide 31, mounted on the inside of the index standard 17. The slide 31 carries at its upper end the 75 index head 32, and near its upper end carries also a lug or arm 33 projecting laterally through a slot or opening 34 in the standard 17. This arm 33 (see Figs. 10 and 13) turns laterally across the face of the standard 80 and terminates in a yoke 35.

The feed roll 19 is mounted on a shaft 36 in the index standard 17. On the shaft 36 with the roll 19 is a ratchet wheel 37 by means of which the shaft 36 and the roll 19 85 are turned. Also mounted loosely on the shaft 36 is an arm 38, carrying at one end the pawl 39 adapted to engage the ratchet 37, and at the other end a lug 40, which protrudes into the yoke 35 on the arm 33 of the 90 slide 31. A stop 41 limits the feed movement of the pawl 39, and a spring 42 returns the pawl to its normal position after each forward movement. A spring controlled 95 lock pawl 43 also engages the ratchet wheel 37 to hold the same in its forward position while the pawl 39 returns for the next feed.

The slide 31 in response to the rotation of the cam 35 and the movement of the levers 27 and 30, reciprocates up and down once 100 on each turn of the cam shaft. This reciprocation of the slide 31 causes the yoke 35 to engage the lug 40 on the pawl-carrying arm 38, and to rock the latter. Each time the arm 38 is rocked, the pawl 39 moves the 105 ratchet wheel 37, and consequently the roll 19 one step forward. The forward feed of the roll feeds the tape or record strip a distance equal to the space between the feed holes 23 along the edge thereof.

It will be noted that the space between the prongs of the yoke 35 is appreciably greater than the width of the lug 40 on the pawl-carrying arm 38, so that the lug is not engaged by the yoke 35 and rocked until 115 after a certain amount of movement of the slide 31. The reason for this lost motion will be presently explained. A pair of adjustable stops 44 project through the prongs of the yoke 35 to permit the amount of lost 120 motion between the yoke and the lug 40 to be properly adjusted.

Yieldingly mounted in two rows of holes 45 in the cross arms 32 at the head of the slide 31 (see Figs. 9 and 12) are two rows of 125 contact pins 46. Light coil springs 47 attached to and embracing the pins 46 provide for the yielding movement of the latter in the holes 45. The pins 46 are arranged to register with the perforations in the tape, 130

and are of a size to pass through such perforations when the slide 31 carries the cross arms 32 downward. Where there are no perforations in the tape corresponding in position to the pins, the pins on striking the unperforated portion of the tape are stopped by the latter by virtue of the yielding connection of the pins to the index head. Where such registering perforations in the tape exist, however, the pins passing through the same on the downward movement of the slide 31 enter corresponding mercury wells 48 in a stationary bar 49 carried by the standard 17.

15 The mercury wells 48 are each connected by a wire 50 with one of a series of mercury wells 51 in a second bar 52 to electrical insulating material supported on the platform 14 at the base of the index standard 17. Each 20 of the mercury wells 51 is in turn connected as hereinafter to be described, to one of the contacts of an electric switch, and thence to some one of the various mechanisms for controlling the operation of the machine. Each 25 of the pins 46 is likewise in one of these circuits, and, whenever, upon the downward movement of the slide 31, any of the pins 46 may enter any mercury wells 48, the particular circuit of such pin is made. One, two 30 or three pins 46 (according to circumstances hereinafter fully set forth) may pass through the tape on the downward movement of the slide 31, and each of said pins will establish its own circuit. The upward 35 movement of the slide 31 carrying with it the pins 46 breaks all such circuits again. The bars 49 and 52 are of insulating material, and pieces of insulation 53 insulate the index standard 17 and the arm 29 of the lever 27 from the frame of the machine, in order that the pin circuits may not be grounded through the machine.

40 It is desirable that after each feed of the tape by the roll 19, the tape is positively held in such position, so that when the index head descends, the pins will truly register with the perforations in the tape. To insure such true registration, there is mounted upon the top of the slide 31, a pin 54 (see Figs. 9, 10 and 13) arranged to register with the feed holes in the tape. The pin is removably attached to a lug 55 on one of the bars 32 of the index head, as by means of a bayonet joint, whereby the pin may be locked down in position or may be held up away from the paper by a spring 56. The pin 54 projects somewhat below the pins 46, so that upon the downward movement of the slide 31, the pin 54 will enter one of the feed 50 holes in the tape, and secure the latter against possible displacement before the pins 46 reach the tape. At the time the pins 46 reach the tape, the latter is held securely in its proper position by virtue of the pin 54, 60 on the one hand and the teeth 24 of the roll

19, on the other hand. Of course, the pin 54 and the pins 46 must not engage the tape until after the latter has been fed to its proper position by the roll 19, and similarly they must leave the tape in time for the next 70 feed of the roll. To give the pins time to withdraw from the tape before the latter is fed, the lost motion between the yoke 35 of the slide 31 and the lug 40 of the pawl actuating arm heretofore mentioned is provided. 75

Operation of tape feed and index head.—In Fig. 10, the index head is shown as having been raised by the upward movement of the slide 31 in response to the action of the spring 28', following the movement of the 80 cam 25 on the cam shaft. Both the contact pins 46 and the tape holding pin 54 are here indicated as above and out of contact with the paper. The lower prong of the yoke 35 has engaged the lug 40 of the roller actuating pawl 39, and by rotating the ratchet 37 and roll 19, has advanced the tape preparatory to the descent of the pins. The cam 25 continuing to rotate now starts the parts toward the position shown in Fig. 11. 90 The slide 31 moving in response to the cam 25 first brings the pin 54 into engagement with the tape to secure the latter against displacement. Further downward movement of the slide 31 brings the pins 46 to the tape, 95 and such of these as find perforations in the latter pass through the same and into the mercury wells 48 to establish the desired circuits in the machine. Still further downward movement of the slide 31 causes the 100 upward prong of the yoke 35 to engage the lug 40 on the pawl actuating arm 38 and to return the pawl 39 to its initial position for the next feed. This brings the parts into the position shown in Fig. 11. The slide 31 105 now being at the lowest end of its stroke, and the proper electric circuits having been established, a further revolution of the cam 25 permits the spring 28' to commence raising the slide 31 again. The first result of 110 the upward movement is to withdraw the contact pins 46 from the tape. The holding pin 54 is then withdrawn from the feed hole with which it is engaged. All the pins being thus withdrawn from the tape, the tape is 115 ready for a forward movement. The lower prong of the yoke 35 has not yet engaged the lug 40 on ratchet arm 38, but now the further upward movement of the slide 31 brings the yoke 35 into engagement with the lug 120 40, and the tape is fed forward, after which the parts are again in the position shown in Fig. 10. This cycle of movements is repeated on each revolution of the cam 25.

Tape winder and slack preventer.—The 125 take-up spool 21 (see Fig. 5) is mounted on a standard 60 at the right-hand end of the platform 14. On the same standard 60 below the spool 21 and bearing against the latter is a roller 61 for turning the spool 130

21 and for taking up the slack in the tape as the latter is fed to the spool from the index head. The spindle of the take-up roll 21 (see Fig. 5) is supported on bearing plates 63 in yokes 62 at the top of the standard 60. The bearing plates 63 are pivoted as at 64 on the standard 60. Springs 66 (see Fig. 16) serve to hold the bearings 63 in correct position with respect to the yokes 62, and pins 65 serve to maintain the bearing plates properly against the side of the standard.

The spool 21 receives its rotary motion from the roll 61 when in contact with the latter. The roll 61 is in turn driven from the cam shaft through the following connections: The cam 67 on the cam shaft (see Fig. 5) engages the roll 68 on a cam lever 69, pivotally mounted in a bearing 70 on the underside of the plate 14 of the frame, (see Figs. 5 and 14). The other end of the lever 69 is attached to the link 71 passing up through the plate 14, which link is in turn attached at its upper end (see Figs. 15 and 25) to an arm 73 pivotally mounted on the standard 60 of the take-up roll. The arm 73 carries a pawl 74, engaging with a ratchet 75 fast to the shaft 76 on which the roll 61 is mounted. A pawl 77 on the standard 60 holds the ratchet 75 in its advanced position after each forward feed of the latter by the pawl 74.

Referring now more particularly to Figs. 16 and 17, it will be noted that the roll 61 is not rigidly attached to its spindle 76, but is secured thereto by means of a coil spring 78, one end of which is fast to the spindle 76 and the other end to the roll 61. To permit of the proper positioning of this spring connection, the roll, as shown in Fig. 17, is formed in two parts which are united by bolts 79. In the interior of the roll 61, between the two parts of the same, the spring is located. At each rotation of the cam shaft, the spindle 76 of the roll 61 is turned an amount corresponding to one tooth of the ratchet wheel 75. Because of the yielding connection between the spindle 76 and the roll 61, the latter is not, however, moved with every movement of the spindle 76.

Whether or not the roll moves with the spindle depends upon whether the force stored in the spring by the movement of the spindle is great enough to move the roll against the frictional resistance offered by the take-up spool 21, resting thereon and upon which the tape is drawing. If the tape is taut, it will hold the take-up spool against rotation, and the take-up spool bearing upon the roll 61 will offer such frictional resistance to the movement of roll as to hold the latter from rotating under the action of its driving spring 78. When the tape is taut, therefore, the rotation of the spindle 76 merely serves to more tightly coil

up the spring and to store energy therein. The tape can never be torn, because as soon as the energy stored in the spring is sufficient to overcome the frictional engagement of the roller and the spool, and before such energy is sufficient to tear the paper, the roll 61 will slip on the spool. When now the tape becomes slack, the spool 21, and, consequently the roll 61 are free to rotate in response to the action of the spring 78, and any energy that may have been stored up in the spring is, therefore, immediately applicable to turn the roll 61 and spool 21 to take up the slack. As soon as the slack is taken up and the tape becomes taut, the rolls again become stationary. In this manner the take-up device is automatic in its movement, acting only when an undesirable amount of slack in the tape occurs.

Having now described the manner of feeding the tape through the machine and of effecting therethrough the electrical control of the various mechanisms, actuated from the cam shaft 1, we are prepared to describe the structure and operation of these parts in connection with means for controlling the same.

The matrix block and its actuating mechanisms.—It will be remembered that in this class of machines, the type are cast in a single mold, the walls of which are adjustable to make the mold cavity accord to the unit of set of body of any type to be cast, and the character matrices are all carried by a plate movable across the top of the other mold sections to present to the mold cavity the matrix of the particular character called for. In the present machine, a single unitary plate or matrix block has in its lower face all the matrices necessary for any particular set-up. The matrices, therefore, have no movement independent of each other. As in other machines of this class, the matrix block is for convenience movable in two directions across the face of the mold to present the matrices to the latter. As heretofore stated, when the registrations in the record tape, corresponding to any particular type character, present themselves at the index head, certain stops or other means for determining the width of the mold cavity, and for determining the traverse of the matrix block in its movement across the face of the mold, are actuated through the electrical connections there established.

The matrix block carriage and most of the actuating mechanisms therefor are mounted upon a section 80 of the frame, (see Figs. 1, 2, 6, 18 and 19) pivotally supported at 81 by a standard 81' on the right hand side of the machine frame, and resting at its free end on a standard 81" (see Fig. 1). The section 80 is pivotally mounted so that it can be lifted up to permit of access to the mold and other underlying

parts of the machine. The section 80 of the frame is well shown in Figs. 18 and 19. The matrix block 82, (see Figs. 18, 19 and 21) is mounted to have a reciprocating sliding movement in ways 83 on the carriage 84. The carriage 84 is in turn mounted to have a reciprocating sliding movement in ways 85 on the frame member 80. The matrix block 82 is actuated by a slide 87, which 5 moves in ways 114 on the frame member 80. Since the matrix block moves with the carriage 84 in a direction perpendicular to the ways 114, there must be a sliding connection between the arm 87 and the matrix 10 block 82. This is provided by a recess or groove 115, (see Figs. 19 and 21) on the edge of the block 82, which serves as a way for a finger 116 on the slide 87, by means of which the slide 87 is attached to the block 82. 15 During the normal operation of the machine, each rotation of the cam shaft through a series of connections presently to be described, causes the carriage 84 to be moved in the direction of the arrow (see 20 Figs. 18 and 19) into an initial position on the frame member 80, and simultaneously the matrix block 82 to be moved in the direction of the arrow (Figs. 18 and 19) into an initial position on the carriage. At 25 other times during such rotations of the cam shaft, the carriage 84 and the matrix block 82 are moved in directions reverse to the arrows to set any particular matrix on the block over the mold. These setting positions are determined by stops adapted to 30 be projected into the paths of movement of the carriage and matrix block. The stops are arranged in banks at right angles to each other, one bank for the carriage, and one bank for the matrix block. Each individual stop in each bank is controlled by an 35 electromagnet in the circuit of some one of the index pins 46, except, of course the last stop, which may be stationary. The characters on the matrix block are, for convenience, preferably arranged in rows according to the unit width of the characters. No particular arrangement is, however, essential, and as will hereinafter appear, the 40 "set up" may be altered regardless of the unit widths of the characters. In bringing a matrix to a position over the mold, the carriage 84 is moved until the particular row in which the matrix appears is brought 45 over the mold cavity, and simultaneously the matrix block is moved in a direction at right angles to the carriage until the particular matrix in that row stops over the mold cavity. In each instance, the carriage and 50 block are finally stopped by the stop pins referred to. There are, therefore, as many stop pins in the bank of stops controlling the movement of the carriage as there are rows on the matrix block, and as many stop 55 pins in the bank controlling the movement 60 of

of the block on the carriage as there are individual matrices in the row on the matrix block.

Referring now to Figs. 19 and 20, the carriage 84 is shown as having attached to the bottom thereof a stop arm 86. The slide 87 serves as a similar stop arm for the matrix block 82. The bank 88 of stops 89, which co-act with the stop arm 86 is shown in Fig. 20. In this view the carriage is seen to be stopped by the next to the last stop pin in the bank. The stop pins 89 are adapted to be elevated into the path of the arm 86 by the armatures of electric magnets, not shown, but which, as stated, are energized from the record tape. The stop pin so actuated is retained elevated by the stop arm 86 during the casting operation by reason of a beveled recess 90 on the top of the stop, engaging a corresponding bevel on the shoulder of the stop arm. The stop pins, when released by the arm 86, are returned to their normal positions by springs 91 (see Fig. 20). The stops for the matrix block arm 87 is indicated at 91 in Fig. 6. In arrangement and operation, the stops 91 are like the stops 89.

The matrix block 82 and the carriage 84 are, after each casting operation, returned to their initial positions by the following connections from the shaft 1. The cam shaft carries a cam 92 (see Figs. 5, 6 and 14), engaging a roller 93 on a cam lever 93, pivoted at 94 to the underside of the platform 14 (see Fig. 14).

In the path of the cam lever 93 (see Figs. 2 and 6) is the arm 95 of a three armed lever 94 pivoted to a lug on the frame section 80, (see Figs. 18 and 19). Through another of its arms 96, this latter lever moves the carriage 84, and through a third arm 97, it moves the matrix block through the connections 108, 105 and 87. Pivotedly attached to the carriage at 98 (see Figs. 19 and 20) is a link 99, in turn connected at 100 to the lever 101, (see Figs. 18 and 20). The lever 101 is pivoted at 102 to the frame section 80 and carries a lug or roller 103, which lies in the path of the arm 96 of the lever 94, and which when engaged by the lever arm 96 causes the arm 101 to be rocked on its pivot, carrying with it the link 99, and the carriage 84, to which the latter link is fastened at 98. Similarly, the matrix block stop arm 87 has attached to its upper face at 104, one end of a lever 105. The lever 105 is pivoted to the frame member 80 at 106, and carries the lug or roller 107 with which an arm or slide 108 is connected to the lever arm 97.

When the lever arm 95 is rocked by the cam lever 93, in the direction of the arrow *a* in Fig. 18, the carriage 84 through the connections just traced is moved in the direction of the arrow *b* to an initial position at one end of the frame member 80, and simultane-

ously, the matrix block 82, through the connections traced, is moved in the direction of the arrow *c* to an initial position at one side of the carriage. When the carriage and matrix block have been forced into their initial positions, in the manner just described, the electric connections, established at the tape, set the proper stops in the paths of each, and, the cam 92 continuing to rotate, 10 provides for the movement of the carriage and matrix block to the stops.

To effect movement of the carriage 84 and of the slide 87 to the stops after the latter are set, there is mounted upon the pivot post 15 102 of the arm 101, (see Fig. 18) a coil spring 109, attached at one end 110 to the arm 101 and at the other end to an arm 111 on the post 102. The spring 109 is always under tension, and this tension may be adjusted by adjusting the angular position of the arm 111 on the post 102. The spring 109 turns the arm 101, and moves the carriage to the stop 89, as soon as such movement is provided for by the cam 92. Similarly on the pivot post 106 of the matrix block lever 105 is a coil spring 112, attached at one end to the lever 105, and at the other end to an arm 113, carried by the post 106. The position of the arm 113 may be adjusted 25 to vary the tension of the spring 112. The spring 112 tends to urge the pin stop slide 87 of the matrix block toward the stops, and accomplishes this as soon as the cam 92 provides for such movement.

35 It has been pointed out that the section 80 of the frame is movable on an axis 81 to permit of access to the underlying mechanism. When the member 80 is raised, the carriage and matrix block should be locked in 40 their initial or zero positions against the action of the coil springs 109 and 112. To effect this automatically, there is a spring latch 117 (see Figs. 18 and 23), attached at 118 to the frame section 80, and adapted 45 when the section 80 is raised to engage a lug 119 on the arm 96 of the lever 95, after the latter has been moved to the limit of its stroke in the direction of the arrow *a*, Fig. 18. The arm 96, when thus engaged, 50 is prevented from moving in response to the action of the coil springs 109 and 112, and the carriage and matrix block are consequently held locked. This latch 117, however, can engage the lug 119 only when the 55 frame section 80 is lifted. At other times, the latch 117 is out of the path of movement of the arm 96, so that the latter may have the function for which it is designed. To prevent the latch 117 from engaging the arm 60 96 when the frame section 80 is down, and to keep it out of the path of the arm 96 at the time the machine is operating normally, there is mounted upon the stationary portion of the machine frame below the 65 section 80, a pin 120, (see Fig. 23). This

pin when the frame 80 is down, projects through and above the same, and engages and holds the latch 117 up out of the way of the arm 96. When, however, section 80 of the frame is lifted, the latch 117 thereon 70 is moved away from the pin 120, and is then free to drop over the lug 119 in response to its own spring action. To prevent the latch 117 from falling behind the arm 96, there is a second pin stop 121 for the 75 same (see Fig. 23), this last stop being carried by the movable section 80 of the frame.

The mold.—See assembly views 1, 2, 4, 5, 6 and 7 and detail views 24, 25, 26, 27, 28, 29, 30, 31, 32, 33, 34, 35, 36 and 37. The assembled mold is shown in Fig. 24. The casting position of the mold cavity is at the point 122 of the mold block. Two blocks 123 and 124 form the side walls of the mold cavity, and have a constant position relative to each other, determined by the thickness of the mold blade or plunger 125. A plate 126 forms the front wall of the cavity, and the rear or adjustable wall of the cavity is 85 formed by the blade or plunger 125. The unit set of the mold cavity, which varies for the particular type to be cast, is determined by the position of the mold blade with respect to the plate 126. The setting of 90 the mold blade for each casting is controlled from the index head by the operation of one of a number of stops in the pin circuits.

95 After each casting operation, it is necessary that the type be ejected from the mold cavity into the galley. For this purpose there is a slot or opening 127 through the wall 126 to the galley. After the casting of a type or quad, in order to eject the same from the mold to the galley, the mold sections 123 and 124, together with the mold blade are slid from the casting position 122 to a position in which the mold blade registers with the opening 127, whereupon a forward movement of the blade 125 forces the 100 type out of the mold and through the opening 127. After this last operation, the mold blade is released to the action of a spring 128, attached thereto, and by the latter is drawn back and away from the wall 126, 105 a distance determined by the stops referred to, in order to form a cavity of the right unit width for the next type. The mold blade thus positioned is then together with the blocks 123 and 124 moved back to the 110 casting position 122.

115 In addition to the movements just described, the mold in its entirety is, after each casting operation and before any movement of the parts 123, 124 and 125 to the 125 type ejecting position 127, given a downward movement away from the matrix block. In the present machine, the matrix block, as has been seen, has movement only in a horizontal plane. It is not elevated 130

after the type is cast, and, therefore, in order that the type may be removed from the matrix, it is necessary that the mold have the downward movement referred to. 5 Otherwise, of course, the movement of the parts 123, 124 and 125 toward the galley entrance 127 would cause the character to be sheared from the top of the type body. After the return to the casting position 122, 10 and after the matrix block has been set for the next type, the mold is again elevated against the matrix block to form with the latter the compartment for the casting of another type.

15 In detail the mold structure and operating mechanism is as follows: Referring to Figs. 24, 25 and 26, the plate 126, forming the rear wall of the mold cavity, is shown as integral with the base plate 129 of the mold. 20 On the base plate 129 of the mold, (see Figs. 24 to 27 inclusive) there is mounted a slide 130, the movement of which across the base plate is limited by suitable stops to be later referred to. Attached to the slide 130, as 25 by means of screws 131, (see Figs. 25 and 28) is the block 123 of the mold. Attached by screws 132 to the upper face of the block 123 (see Fig. 24) is a plate 133. This plate extends not only across the top of the block 30 123, but over the mold blade and over the block 124. Strips 134' fastened to the thrust plate 221 of the mold extend slightly over the blocks 123 and 124, and hold the latter down in position. As shown in Fig. 30, the 35 blocks 123, 124, and the mold blade 125 are locked to move laterally together by means of a stop 160.

The mold blade 125, although held between the blocks 123 and 124, and, therefore, 40 compelled to move laterally with the same, is free to have a movement at right-angles to the movement of the slide 130. This movement of the mold blade is effected in one direction by the spring 128, already mentioned, and in the other direction by a lever 45 135 (see Figs. 36 and 44), actuated from the cam shaft and engaging the mold blade in an aperture 136 in the latter. The extent of the forward movement of the mold blade 50 125 to eject the type is determined by the movement allowed the cam lever 135, and by the adjustable stop 137, carried on the standard 138, to which the mold blade and spring 128 are attached. Engagement of 55 the end of the pin 137 with the block 123 prevents further forward movement of the plunger.

Since the backward movement of the plunger to determine the unit of set of the 60 mold cavity must vary according to the unit of set of type or space quad to be cast, the stop for limiting the backward movement of the mold plunger must be a variable one. This variable stop which may be termed the 65 unit gage, is shown in Fig. 25. It consists

of a plate 138' having a stepped edge 139, and attached to a slide 140 adapted to have movement on and across the base plate 129 of the mold at right-angles to the mold blade. The mold blade is recessed on its 70 underside to bridge this unit gage, whereby free movement across and over the same is allowed. On movement of the mold blade to a setting position, however, a shoulder on the bottom of the mold blade brings up 75 against the stepped edge 139 of the unit gage, and the mold blade is thereby stopped. According to the position of the unit gage 138', or in other words, according to the particular step of the same in the path of 80 the stop shoulder or the bottom of the mold blade, the movement of the latter will be greater or less, and, consequently, the unit width of the mold cavity, determined. In the present machine the mold cavity is 85 adapted to have a set varying from four to sixteen units for casting slugs of corresponding sizes. There are, therefore, thirteen steps on the edge 139 of the unit gage, each being cut back the distance of one unit from 90 the next adjacent step.

The guideway for the unit gage slide 140 is formed, on the one hand, by the adjacent slide 130, and on the other hand, by a bar or plate 141, (see Figs. 24 and 25) bearing 95 against a plate 143 attached to the bottom plate 129 of the mold. In order that the position of the unit gage slide may be accurately adjusted, and to take up any wear on the same, the bar 141 is adjustable to and 100 from the wall 126 of the mold. The rear face 142 of the plate 141 (see Fig. 25) is beveled to engage a similar bevel on a second bar 143, fixedly secured to the base plate 129 of the mold. Pins 144 carried by the bar 105 143, pass horizontally through the plate 141 and connect the two plates. The pin passages in the plate 141 are elongated, however, to permit of a longitudinal movement of the plate 141 along the beveled edge of the 110 plate 143. By reason of the bevel, a wedge-like action takes place, when the plate 141 is moved longitudinally, whereby the plate 141, is moved laterally as well, and the unit gage slide provided a movement toward the mold 115 plate 126. The longitudinal adjustment of the plate 141 is attained by means of an adjustment screw 146, attached to the mold base plate 129, and having a flange fitting into a groove 147 near the end of the plate 120 or bar 141. By turning this screw 146, the wedge is moved in and out, and the adjustment of the gage slide effected.

Referring now to Fig. 5, there is shown 125 on the cam shaft 1, a cam member 149, having on its inner face a cam groove (not shown in Fig. 5), engaging a cam roller 150. The cam roller 150 is mounted on the end of a cam lever 151 (see Figs. 5 and 30). The cam lever 151 is pivoted to the frame at 152, 130

to have an oscillating movement in response to the cam, and at its free end engages in a socket 153 in the slide 154 (see Fig. 30). The slide 154 moves in ways 155 on the frame 5 of the machine (see Fig. 30 and Fig. 31, Sheets 19 and 20). One face 156 of the slide 154 is beveled to engage a corresponding bevel on a gib 155', whereby the slide is held in place in the way 155. Attached at the 10 inner end of the slide 154 is a goose-neck 157. To the top of the goose-neck is attached a block 158, having at one end a lug 159. An adjustable set screw 160 in the lug 159, bears against the face of the mold 15 section 124, and is also in line with and 15 adapted to engage a set screw 161 in a lug 162 on the slide 130 (see Fig. 24). The slide 130, it will be remembered is attached to one of the mold body sections 123, (see Figs. 20 27 and 28). The movement of the goose-neck from the cam shaft, therefore, effects the movement of the mold body sections from the type-casting to the type ejecting position by reason of the engagement of the 25 set screw 160 with the set screw 161; and effects the movement of the same parts from the type-ejecting to the type-casting position, by reason of the engagement of the set screw 160 with the mold section 124. In 30 order that the slide 130 may not carry the plunger 125 and the type to be discharged beyond the edge of the entrance 127 to the galley, a stop 163 (see Fig. 28) is attached to the underface of the slide 130. Contact 35 of the stop 163 with the face of the plate 129 of the mold prevents further movement of the slide 130. The extent of movement of the mold sections, in passing from the type-ejecting to the type-casting position, is 40 determined by the set screw 160. In adjusting the parts, the screw 160 is first set to give the mold parts the proper throw to the casting position, to bring the mold cavity into proper position with respect to the 45 matrix block and pump nipple. The set screw 161 is then turned into contact with the screw 160, so that there may be no lost motion between the slide 130 and the goose-neck.

50 The goose-neck slide, in moving the mold parts to the type ejecting position, carries with it the unit gage in order that the position of the plunger may not be disturbed. After the plunger has then been moved forward with type toward the galley and out of the path of the stepped edge of the gage, the movement of the unit gage slide 140 is continued to its zero or initial position by certain connections from a cam 164 on the cam shaft 55 1 (see Figs. 5 and 6). The cam 164 engages a cam roller 165 (shown in Fig. 6, but more clearly shown in Fig. 32). The cam roller 165 is mounted on the end of a slide 166, moving in ways on the frame of the machine, and adapted to bear at one end against

a distance piece 167, loosely pivoted for convenience to the mold blade lever 135. The movement of the slide 160 against the distance piece 167 causes the latter to engage a lever 169, adapted to rock on a pivot 170 on the frame of the machine. The opposite end of the lever 169 carries a pin 171 working in a slot 172 in the arm 173 of a bell crank lever 174 having a bearing 175, on the frame of the machine. The other arm 176 of the bell crank lever 174, carries at its outer end a pin 177, adapted to fit in a socket 178 on the under-side of one end of the unit gage slide, (see Figs. 24 and 25). During each type ejecting operation, the cam 164 urges the cam slide 166 in the direction of the arrow in Fig. 32, and, through the connections just traced, this movement causes the unit gage slide to move back to its initial position. 85

The movement of the unit gage slide from its initial position to a setting position for the casting of a type will not be of uniform distance in every instance but will, according to which particular step on the edge 139 90 of the gage, is to serve as a stop for the mold blade. This will be controlled from the record strip to accord with the unit width of body of character or space quad to be cast. The motive power for urging the unit gage from its zero or initial position to its setting position is not the cam 164, but is a coil spring 179, on the shaft 175, (see Figs. 31 and 34), one end of the spring being attached to the stop lever, and the other end to the frame of the machine. The movement of the gage slide in response to the action of this spring will be determined in each instance by one of a number or bank of stops 181 (see Figs. 30, 31, and 33) 105 electrically controlled from the record strip. The arrangement and operation of these stops constitutes one of the important features of novelty of the present invention. As has been stated, this machine is adapted to cast types of unit widths varying from a minimum of four to a maximum of sixteen units, (inclusive) and to this end, the unit gage slide, (see Fig. 25) is provided with thirteen steps. As the mold slides from a casting to an ejecting position, the mold plunger must not draw away from the type just cast. After the ejection of each type into the galley, however, the mold plunger falls back against some particular step of the unit gage, according to the setting of the latter, and is then slid together with the mold sections 123 and 124 into position for the next casting. If, therefore, the unit gage be stopped and held stationary, when 110 it is engaged and set by one of the stops of the bank 180, then the steps on the gage must be of sufficient length to permit the mold plunger to slide on the same all the way from the type ejecting to the type cast- 115 120 125 130

ing position. If the steps be of sufficient length to permit of this movement, then because there are thirteen steps on the gage plate, the latter will be of excessive length; 5 and furthermore an excessive movement of the same will be required for the casting of type of the larger unit widths. In order to avoid such excessive length and movement of unit gage, we have devised a stop mechanism, such that after the gage has been set by a stop, both stop and gage, instead of being stationary, move with the mold sections 123 and 124, as the latter slide from the type ejecting to the type casting position. 10 The gage thus moving exactly with the mold blade, no sliding movement of the latter on the step of the gage takes place. The steps need, therefore, be no wider than the mold blade itself. The movement of the 15 pin stops with the gage, after the latter has been set, we believe to be new with the present invention.

The stop pins 181 are loosely mounted in the bars 182 and 183 of the pin box. Coil 20 springs 184 (see Figs. 31 and 33), normally hold the pins depressed, but the latter may be lifted by the armature levers 185 of electromagnets 186, so that the upper ends of the pins when lifted, pass through the bar 182 25 of the pin box and into the path of a slide 187, having movement in a way 188 in the top of the pin box. The slide 187 is attached to an arm 189 fast on the shaft 175 (see Figs. 34 and 32). The cam 164 in carrying 30 the unit gage to its zero position, after the casting of a type, carries also the slide 187 to an initial or zero position. The spring 179, which serves to turn the shaft in the opposite direction when permitted so to do 35 by the cam, moves the slide 187 back along the way 188, until it engages one of the pins 181. The position of the slide 187, when it engages the pins, determines the setting of the unit gage for the next type. Each of 40 the magnets 186 is in the circuit of one of the index pins 46, so that the particular pin 181 to be elevated is determined by the record strip. When the unit gage is set, the mold blade falls back against the same, 45 and is ready to be moved by the goose-neck slide to the casting position.

Referring now to Fig. 30, it will be noted, that the pin box is carried by a slide 190, which by means of set screws 191 and spring 50 plunger 192 has an adjustable connection to a lug 193, attached to and depending from the goose-neck slide 154. The pin box is, therefore, practically a part of the goose-neck slide, and must move when the latter moves. During movement of the pin box, the elevated pin is held in its raised position by the engagement of a tip 187' on the slide 187 with a recess 181' in the head of the pin (see Fig. 30). Each pin is 55 provided with a foot 194, so that in event

the pin fails to be held by the slide 187, it may by engagement of the foot 194 with the armature lever, be prevented from falling behind the latter, and on its return movement stripping the levers or itself being 60 broken. To this end, the feet 194 are of such length that they are over their respective armature levers 185, during the entire movement of the pin box. In order that the pins may be held from turning in their sockets in 65 the pin box, and the feet thereby thrown out of alignment, the openings 195 in the lower bar 183 of the pin box are slotted to fit the pin feet 194 (see Figs. 33 and 35).

It is to be observed that the goose-neck 70 slide, with the pin box thereto attached, is moved positively by the cam 149 both forward and backward, whereas, the unit gage slide, with the stop arm 189 is moved positively by the cam 164 to its zero or initial 75 position only, and is moved to its setting position by the spring 179 on the shaft 175. The relative movements of these parts are 80 as follows: After a type or quad has been cast, the cam 149 moves the mold sections 85 to a position determined by the stop 163 on the slide 130, so that a type may be ejected 90 into the galley. This movement of the goose-neck slide 154, carries with it the pin box 180, returning the latter to its normal 95 position over the magnets 186. Simultaneously, the mold parts and unit gage are 100 carried to the ejecting position. The lever 136 then moves the mold blade to eject the type, and the unit gage is carried to zero 105 position. To cast the next succeeding type, the proper stop pin 181 is now actuated from the record strip by the movement of one of the armature levers 185, and lifted into the 110 path of the slide 187. The movement of the cam shaft 1 now causes the cam 164 to release the lever 169 to the action of the spring 179, whereby the slide 187 is driven forward until it engages a pin 181, thus setting the 115 unit gage by causing the particular step thereon, corresponding to the pin 181 actuated to be presented in front of the mold blade. The latter, after the ejection of a type into the galley, is drawn back by the spring 128 (see Fig. 24) until it falls on the 120 step of the unit gage presented to it by the movement of the gage slide. The cam 149 then commences to move the goose-neck slide, with the mold sections 123, 124 and the mold blade 125 from the type ejecting position 125 opposite the galley entrance to the type casting position over the pump nipple, carrying with it in this movement the pin box.

As the pin box moves with the elevated 130 stop pin, the slide 187 and the stop arm 189 follow by virtue of the spring 179. The stop arm 189 and the unit gage driving arm 176 are of the same effective length, so that the movement of the gage slide will be just

equal to the movement of the pin box, so that the position of the unit gage with respect to the mold blade 125 may not change as the latter is moved to the casting position.

5 In order that the unit gage may be properly set with respect to the mold blade in the first instance, the pin box is adjustable with respect to the slide 154 by means of the set screw 191 (see Fig. 30), heretofore mentioned.

10 The mold blade lever 135 (see Figs. 2, 5, 6, 32, 36 and 44) is pivoted or fulcrumed at 196 on a slide bar 197. The slide 197 is normally stationary, but has a slight movement at the end of each line to shift the fulcrum 196, for a purpose to be hereafter described. At its forward end, the lever 135 carries a cam roller 198 engaging a cam 199 on the cam shaft. The cam 199 actuates the lever 135 to force the mold blade 125 forward after the latter has been brought by the goose-neck slide to a position opposite the galley entrance from the mold. After the unit gage has been set by the mechanisms described, the cam 199 releases the lever 135 to permit the mold blade to be drawn back by the spring 128 against the stepped edge of the gage.

15 It is to be remembered that while the goose-neck and gage are going through the succession of movements referred to, the matrix block is also moving. When the type has been cast and removed from the matrix, the matrix block is moved by the cam 92 to its initial position. This movement of the matrix block is simultaneous with the movement of the mold to the type ejecting position, and with the movements of the pin box, the slide 187 and the gage slide to their initial or normal positions. The next movement of the matrix block to a setting position under the action of the springs 109 and 112 takes place while the goose-neck and the elements connected thereto move again to a casting position.

20 It is sometimes desirable to use the machine for casting successively a number of slugs or type of the same size or character, without the aid of a record strip or tape. At such times it is convenient to give the mold plunger the proper setting and to lock it in such position, removing the mold plunger lever 135. If the plunger is to be locked, the gage must not be operated, as otherwise the steps of the gage would be drawn against the plunger. To permit of disconnection of the gage, the distance piece 167, attached to the plunger lever is provided. In lifting the mold blade lever 135 from its pivot, the distance piece is also removed, so that when the former is removed, there will be no connection between the slide 166 and the lever 169. When under such circumstances, the machine is operated, the movement of the

slide 166 is not transmitted to the lever 169, 65 and, consequently, no effort is exerted by the latter on the gage.

Disengagement of type from matrix.—It has been observed that in the present machine, the matrix block has no vertical movement upward from the mold, but that on the contrary, the mold block has a downward movement away from the matrix block after the casting of each character or quad, to permit the type to be moved to the ejecting position opposite the galley entrance. In order that the mold block may have this downward movement, it is mounted upon and attached to a sliding support 200 (see Figs. 23 and 38) by means of screws which pass through holes 201 in the mold block (see Fig. 25) and holes 202 in the sliding support (see Fig. 38). Near the base of the sliding support 200 is a roller 203 (see Figs. 23 and 39). The roller 203 is adapted to engage and rest upon a cam or beveled surface 204 (see Figs. 23, 30 and 39) carried on the end of one arm 205 of a bell crank lever pivoted at 206 on the frame of the machine. The other arm 207 of the bell crank lever (see Figs. 1, 38 and 40) carries a roller 208 engaging the cam surface 209 (see Figs. 1, 5 and 6). The position of the bell crank lever with respect to the slide 200 on the one hand, and the cam 209 on the other hand, may be adjusted by means of set screws 210 (see Fig. 40).

25 After the mold parts 123, 124 and 125 have been returned to the casting position by the goose-neck slide 154, the cam 209 rocks the arm 205 so that the cam 204 on the same, by reason of its engagement with the roller 203 raises the slide 200, thereby causing the mold parts to be lifted for engagement with the matrix block, which latter has by this time been properly set over the mold cavity, and is ready to be centered and pressed down upon the mold for the casting of a type. After the type has been cast, the cam 209 releases the lever 207 to the action of a spring 211 (see Fig. 40) which promptly rocks the bell crank lever and the cam 204 carried thereby in such a direction as to allow the sliding support 200 to descend. To insure the prompt downward movement of the support 200, when released by the cam 204, a plate spring 212, on the frame of the machine (see Fig. 38) engages at one end a shoulder 213 on a cross bar 214, attached to and forming part of the support 200. After the downward movement of the mold from the matrix block has been effected, the goose-neck slide 154 starts with the mold parts to the type ejecting position.

30 *Pump nipple support and connections.*—The plate 129, forming the base of the mold block is cut away to form a passage

215 (see Figs. 23, 25 and 41) for the admission of the pump nipple 216 and its yoke 217. Supported on and extending transversely across the base plate 129 and against the wall 126 of the mold block is a nipple plate 218 having a passage 219 through the same. When the mold block is in casting position, the passage 219 registers with the mold cavity. In Fig. 41, the mold cavity 220 is shown in alignment with the passage 219, the front wall of the cavity being formed by a thrust plate 221, resting on the nipple plate against the wall 126. The pump nipple 216 is shown in casting position in the nipple plate. To the nipple 216 is attached the pipe 222 for conducting the molten metal from the pump.

Since after each casting operation, the entire mold block must be depressed from the matrix block, it is evident that the pump nipple must also be depressed. The movement of the pump nipple away from the matrix block may be conveniently provided for by making the nipple support an attachment of the sliding mold block support 200. The nipple must, however, have an additional movement relative to the mold block, so that after the goose-neck starts with the mold sections 123, 124 and 125 toward the ejecting position, the nipple may be withdrawn from the nipple plate.

The nipple will not be withdrawn from the nipple plate until after the mold parts have moved the mold cavity with the type away from the nipple hole in the nipple plate. Otherwise, any uncongealed metal remaining in the type would, upon removal of the nipple, flow out through the hole in the nipple plate, and dropping down into the nipple in a more or less cooled condition, plug up the latter and render it inoperative. As soon as the mold cavity is moved onto the flat continuous surface of the nipple plate, escape of the metal is impossible, and the nipple may then be dropped.

Referring to Figs. 23, 30, 38 and 41, the nipple yoke is shown as a metal band 224, encircling the nipple and forming an extension of two metal bars 225 and 226. The bars 225 and 226, together with a bar 227 located centrally of the two are each supported in a groove in the upper face of a member 228, from which member and from each other, the bars 225, 226 and 227 are at all points insulated by pieces of insulation 230. The member 228 is attached to a platform composed of two shelves 231, carried by an upright slide 232, adapted to have vertical movement in ways 233 on the sliding mold block support 200. Springs 234 attached at their upper ends to the platform members 231, and at their lower ends to a cross bar 214 on the slide 200, tend to hold the pump nipple down away from the nipple

plate 218 in the mold block. At the bottom of the vertical slide 232 is a bevel or cam surface 235 (see Figs. 30, 38 and 39) adapted to engage a corresponding bevel 236 on the end of the arm 237 of a bell crank lever. The lever 237 lies over the lever 205, and like the latter is pivoted at 206 on the frame, (see Fig. 38). The other arm 238 of this bell crank lever carries at its outer end a roller 239 (see Fig. 40), engaging a cam 240 on the cam shaft 1 (see Figs. 1, 5 and 6). 75

After the cam 209 releases the mold support 200 to the action of the plate spring 212, so that the mold is drawn away from the matrix plate, and after the goose-neck slide 154 starts toward the type ejecting position with the type, the cam 239 releases the lever 238 to the action of a coil spring 241, (see Fig. 40), and this in turn causes the bevel 236 on the lever arm 237 to release the pump nipple slide 232 to the action of the coil springs 234, whereby the pump nipple is withdrawn from the nipple plate. After the mold parts have been returned to the casting position by the goose-neck slide 154, and after the matrix block is in a position above the mold and the mold block lifted against the latter by the cam 209, the cam 239 through the connections aforesaid lifts the pump nipple into the nipple cavity in the nipple plate preparatory to the casting 95 of the next type.

Matrix centering.—Before the ejection of the molten metal at each casting operation, it is necessary that the various elements forming parts of the mold be set with great exactness. The stops for accurately determining the casting and ejecting positions of the mold block have been described. The stop pins for stopping the matrix block with any particular matrix over the mold has also 105 been described. It has been found advisable, however, to provide means in addition to the stop pins for determining with great exactness, the position of each matrix over the mold cavity. Any inaccuracy in this 11 respect results in the character being misplaced on the face of the type and the composition to be disfigured. To assure the desired certainty in the positioning of the matrices over the mold, the following means is 11 employed. Referring to Figs. 21, 23, 30, 42 and 43, the matrix block 82 is shown as mounted upon and carried by a plate 242, the latter plate being the plate actually engaged by the stop pin slide 87, as shown 12 in Fig. 21. In the upper face of the plate 242 are a number of pockets or holes 243, having beveled or flared side walls adapted to admit a correspondingly shaped centering pin or plunger 244, which is mounted to have a vertical movement in a bearing 245 (see Fig. 23), in turn carried in a yoke or cross bar 246. The cross bar 246 is mounted

on the frame of the machine, and extends over the matrix block carriage as shown in Figs. 6 and 21, for example. For every matrix on the face of the matrix block, there is a hole 243 in the back of the pin plate. The holes 243 are in each instance directly opposite the matrices on the matrix block, and are so positioned with respect thereto, that when the pin 244 is forced into any hole 243, the matrix corresponding to that hole is truly positioned over the mold.

The bearing 245 of the pin plunger is held in position in a socket 247 in the cross piece 246 by set screws 248, between which and a flange 249 on the socket, a flange 250 on the bearing is retained. A spring 251 engaging a shoulder 252 on the bearing 245, and a collar 253 on the pin plunger, serves to keep the plunger normally elevated and away from the matrix block. The upper end 254 of the plunger is adapted to fit within a socket 255 in the end of an arm 256. The arm 256 is mounted on or forms part of a post 257 (see Figs. 30, 44, 45 and 46), pivoted in the frame of the machine. By swinging the arm, the socket 255 in the end thereof may be made to engage the end 254 of the pin plunger, as when the machine is in normal operation, or when desired to be disengaged therefrom may be withdrawn from over the matrix block, so that the carriage frame 81 of the latter may be lifted.

In addition to having a pivotal movement in its bearing on the frame, the post 257 is adapted to have a vertical or sliding movement in its bearing. A heavy coil compression spring 258 (see Figs. 30 and 44) bearing at 259 on the frame of the machine, and bearing against the collar 260 on the post 257, serves to hold the latter normally elevated. The post 257 is engaged between the collar 260 and a second collar 261 by the fork or yoke 262 on a lever 263, pivoted at 264 to the frame of the machine. The lever 263 carries at its outer end a roller 265, which engages a cam 266 on the cam shaft.

After the matrix block has been moved to present any desired matrix to the mold cavity, and after the mold parts have been returned from the type ejecting position to the casting position, so that the parts are in the position shown in Fig. 42, the cam 209 forces the mold block up against the matrix block, and simultaneously, the cam 266, by means of the lever 263, depresses the post 257 and the pin plunger 244, so that the parts come to the position shown in Fig. 43.

Squirt preventer.—Although it is designed that when the parts are in the position shown in Fig. 43, they shall fit so closely that no molten metal may escape, or squirt out, between the matrix block and the mold, yet, occasionally this does happen. Where there is such a squirt, the type cast is an im-

perfect one, and if allowed to enter the gallery mars the composition. It is, therefore, desirable that in the event of a squirt, the machine is automatically stopped in order that the defective type may be removed, and a perfect type cast in its stead.

To effect an automatic stoppage of the machine, the following device is employed. The machine is provided with an automatic electrically controlled cut-out, which will not be described now, but which may be operated under any one of a number of contingencies. In one of the circuits controlling this cut-out, there is a circuit making and breaking device comprising a bell crank lever 267 (see Figs. 30, 45 and 47) mounted on a bracket 268 on the frame of the machine near the post 257. One of the wires 269 of the cut-out circuit is attached to the pivot of the lever 267 and the other wire 270 to a binding post 271, in electrical connection with an adjustable contact 272, opposite the end of the lower arm of the lever. When the upper arm 273 of the lever is depressed, the circuit is established through the lower arm of the lever, and the cut-out operated. A spring 274 tends to keep the arm 273 elevated and the circuit normally open. The normal position of the lever may be adjusted by means of a stop 275. The arm 273 of the lever, when the plunger arm 256 is in engagement with the centering pin 244, protrudes into a position just below the lower end of a pin 276 carried by the plunger pin post 257.

Pivoted at 276' in a slot in the plunger arm 256 is a lever 277 having a bearing at one end on the plunger pin socket 255, and at the other end on the top of the pin 276. A spring 278 normally holds the pins 276 in an elevated position, so that the lever 277 assumes the position shown in Fig. 46. The normal downward movement of the plunger arm 256, with the plunger pin to center the matrix, does not cause the lever 277 to be rocked, sufficiently to depress the pin 276 to contact with lever 267. When, however, there is a squirt between the matrix block and the mold, this film of intervening metal prevents the centering pin from taking its full downward stroke, and produces such relative movement between the centering pin and the arm 256, that the lever 277 is rocked and the pin 276 depressed into contact with the arm 273 of the lever 269, of the circuit making lever 267, establishing the circuit to the cut-out, and stopping the machine. The pocket or slot for the lever 277 is covered by a flat spring 279 held in place by a screw 280. This spring 279 serves to form a yielding contact between the plunger pin 244 and the matrix block 242. The lower end 281 of the pin 276 is insulated as shown in Fig. 46, in order

that the cut-out device may not be short circuited through the frame of the machine when the pin 276 strikes the lever 273.

Pump and metal connection to the mold.—

5 The metal pot and pump is inclosed in a casing 282 (see Figs. 1, 3 and 4) carried on a bracket 283 over the burners 284 and gas connection 284', at the end of the machine. The pot 285 is shown in Fig. 48 with the 10 casing removed. The pump which is within the pot, comprises a piston 286 attached by a connecting rod 287 to a rocking lever 288, in turn is actuated by a cam on the cam shaft 1, in conjunction with a coil spring 15 289 as presently to be described. The pump cylinder or barrel 290 is supplied with metal from the pot through the inlet 291 controlled by the inlet valve 292, and delivers through an outlet valve 293 to an outlet passage 294, connected at 295 with the pipe 222, which conducts metal to the pump nipple at the mold (see Fig. 41).

When the piston 286 is depressed, the 20 molten metal in front of the same is forced through the valve 293 and thence through the passage 294 and the pipe 222 to the mold. The pressure on the metal in the cylinder causes the valve 292 to close automatically. As the piston reaches the limit of its downward stroke, and passes beyond the inlet opening 291, the metal flows through the inlet passage to the valve 292. When the piston starts to return to its upper position, the valve 293 closes and the valve 292 opens, the 30 opening of the latter valve again admitting the metal to the cylinder in front of the piston.

After the injection of the metal into the mold, and after the type body has been 40 formed, it is usual in this art to withdraw from the type body a certain amount of uncongealed metal. This is conveniently done in the present machine just before the mold sections are moved to the ejecting position. 45 To effect this withdrawal of molten metal, there is in the head of the cylinder a small passage 296 from the metal pipe to the pump chamber. Through this passage a small amount of metal is sucked as the piston 50 moves up on its return stroke. This suction withdraws the uncongealed metal from the type body. The metal actually drawn into the cylinder through the passage 296 is, however, slightly greater than the amount to 55 be withdrawn from the type body, so that the proper withdrawal of the latter is assured.

Referring to Figs. 3, 6, 48 and 49, the pump rod 297 is shown attached to the lower 60 end of an arm or lever 298, fast to one end of the rock shaft 299, to the other end of which is attached the arm 288, to which the connecting rod 287 is connected. The forward end of the pump rod 297 (see Figs. 50 and 51, Sheet 26) is attached to and support-

ed by an arm 300 pivoted to the frame of the machine near the cam shaft 1. At the point of its attachment to the arm 300, the pump rod carries a roller 301, adapted to engage a cam 302, on the cam shaft, the cam 70 302 being circular except for a depression at one point of its periphery. The coil spring 289 (see Figs. 48 and 49) one end of which is attached to the arm 298 and the other end to the frame, forces the pump rod toward 75 the cam 302, and holds the roller 301 against the latter.

As the cam rotates, the pump rod is forced forward against the action of the spring 289, and the pump piston is elevated through 80 the connections mentioned. As soon as the pump rod has reached the end of its forward stroke, and the piston reached the limit of its upward stroke, the parts are held in this position against the action of 85 the coil spring 289 by the circular position of the periphery of the cam. While the parts are so held a spring latch 303 (see Fig. 49), snaps up in front of the arm 298, and if allowed to remain there would prevent the 90 arm 298 from rocking in response to the spring 289, when freed to the action of the latter by the presentation of the cam depression to the roller on the arm. Before the depression in the cam is turned into line 95 with the pump rod, the latch 303 is normally moved out of the path of the arm 298 by means of a link 304 (see Fig. 49), which is attached to the armature of a magnet 305, suitably controlled from the record strip. 100 The roller 301 is then free to follow into the depression of the cam surface thereby depressing the pump plunger and causing another type to cast. The aforesaid safety latch is provided to hold in check the pump 105 rod during the revolution of the machine when no type is cast. During the normal operation of the machine, when type are to be cast, the pump magnet 305 is energized every time any row or individual stop magnet is operated. When, however, as in canceling a line, no type are to be cast, the 110 circuits of the pump magnet 305 are all broken, as will be hereinafter pointed out, so that the latch 303 will at such times remain in front of the arm 298, preventing the movement of the latter through the cam 302, and continue to rotate with the cam shaft.

The pump body is held in place in the pot 115 by means of a pair of rods 306 (see Figs. 52 and 53) attached thereto, and seated in cavities in the clamp 307, to be held by the latter. This clamp is adapted to be swung on a loose pivot at 308, and to be removed 1 or to be locked by a hand nut 309, engaging a threaded link 310, pivoted to a bracket 310' attached to the upper interior portion of the pot about opposite the pivot 308. When the clamp is removed, the pump may 1

be lifted bodily out of the pot. Easy access to all parts of the pump mechanism is thereby assured.

Pump safety device.—When the matrix block and carriage frame 80 are lifted on the pivot 81 to permit of access to the parts under the same, the pump should be rendered inoperative. Otherwise, the operation of the machine at this time will cause the molten metal to be squirted through the open mold cavity and over the machine. To put the pump automatically out of commission when the matrix block is lifted, there is provided a latch or hook 311 (see Figs. 45, 50 and 51) pivoted to the machine frame and adapted to engage a lug 312 on the end of the pump rod. When this latch is in engagement with the pump rod, the latter is held forward against the action of the spring 289, and is prevented from following the cam 302. The arm 298 although released by the magnet 305 can, therefore, not be moved.

A spring 313 (see Figs. 45 and 50) unless restrained throws the latch into engagement with the pump rod. A link or lever 314, pivoted at 315 to the frame connects at one end to the latch 311, and at the other end 316 bears against the side of the matrix carriage frame 80, when the latter is down and in its normal position. When the carriage frame 80 is down, the link 316 is held by the same in such a position that the latch 311 connected thereto is held up and out of engagement with the pump rod. As soon, however, as the carriage frame 80 is lifted and the link 316 released to the spring 313, the latch 311 is forced into engagement with the pump rod to hold the latter and cut out the pump.

Heating and attemperating metal in passage from pump to mold.—In the present machine, the metal in its flow from the pump to the mold is maintained heated and at a uniform and predetermined temperature by means of an electric current, after the manner set forth in application Serial Number 293,649 for United States Letters Patent filed by Kirke West, December 28, 1905, but involving certain improvements over the Goodson method. In the Goodson method, it will be recalled, the metal in the pipe from the pump to the mold is prevented from becoming congealed, and is maintained at a more or less constant temperature by means of an electric current, flowing through the pipe itself.

The great advantage of this electrical heating is that the pump and pot may be located at any desired distance from the mold and other mechanism, and the metal still be delivered hot at the mold. In other monotype machines, the close proximity of the pot to the mold, rendered necessary in order that the metal may not congeal in pas-

sage is a great inconvenience and disadvantage. Furthermore, where electrical heating is not employed, elaborate and expensive pump constructions are required, so that the metal may be delivered to the mold quickly and with force. The Goodson method, while in a large measure clear of the difficulties involved where no electrical heating is employed is, nevertheless, in some respects deficient. With the Goodson method, for instance, if the metal in the pipe be at the right temperature, it is likely to congeal at the nipple and vice versa. This difference of temperature between nipple and pipe method may be ascribed to two causes. In the first place, the nipple is almost necessarily of greater diameter than the rest of the pipe and offers a larger conductor and less heating resistance to the current than is offered by the pipe. The drop of the resistance at the nipple involves a corresponding drop of temperature. In the second place, the nipple is in immediate proximity to the jacketed and water-cooled mold sections, and is likely to be itself cooled by the latter.

In the present machine, we avoid or counteract the cooling effect at the nipple. This we do by the employment of a second electrical circuit, whereby a greater current is made to pass through the nipple than passes through the metal pipe to which it is attached. We also provide means for regulating this auxiliary supply of heating current, so as to effect any desired adjustment of temperature at the nipple.

Our heating circuits are as follows: For heating purposes we prefer to employ a low voltage alternating current. The current may be had from any suitable source and then brought to the desired voltage by a transformer. From the transformer the current passes by way of a conductor 317 (see Figs. 1, 4 and 38) to the folded spring metal strip 318, thence along the metal bar 225 to the band 224 by which the nipple is embraced (see Fig. 41), thence following the band 224 around the nipple, returning by way of the metal bar 226 into the metal plate 319, back along the bar 227 into the metal pipe 222, and along the same to the metal pot. From the metal pot, this circuit is continued by a suitable conductor 323 back to the transformer. To prevent grounding of the heating current through the machine, the pump lever 288 (see Fig. 48) contains a piece of insulation 324, and the entire pot is insulated from the machine as shown at 324' in Figs. 3 and 4.

The current does not pass into the nipple in its passage through the band 224 around the same. The band 224 is insulated from the nipple by a film or layer of oxidation on the latter, which in view of the low voltage of the current has been found to be 130

entirely sufficient for the purpose. The central plate 227, however, is in direct electrical connection with the pipe (see Fig. 41), and supplies to the latter the current necessary for maintaining the metal hot in the pipe between the pump and the nipple. The band 224 around the nipple, by reason of the current passing through the same, acts as a heating band for the nipple.

- 10 The nipple band, in addition to being in the circuit of the metal pipe, is also in a circuit in parallel therewith. This last circuit is identical with the circuit just traced as far as the plate 319. From the plate 319, the 15 second circuit leads through a depending curved metal extension 320 of the plate 319 to a conductor 321 attached thereto, and thence to a rheostat 322 (see Fig. 4) attached to the inside of the frame near the metal pot. 20 From the rheostat the circuit is continued back by a suitable conductor to the transformer.

Only a portion of the current which passes from the transformer through the heating band 224, passes, therefore, through the pipe 25 222. The excess of current in the band 224 over that in the pipe may be regulated at will by the rheostat. This excess may be considerable, or it may be cut down to practically nothing, according to circumstances.

Water cooling of mold.—It is of course necessary that there be means for keeping the mold cold, so that the molten metal when injected into the same may be promptly congealed. Otherwise, the type or slugs cannot be set up quickly, or, if set up, may adhere in the galley line. In this machine the mold sections 123 and 124 are water cooled. Within section 123 (see Fig. 30) are communicating water chambers, or passages, 326 and 327; and in the section 124 corresponding communicating chambers or passages 328 and 329. Tapped into the block 124, so as to be in communication with the 40 passage 329 is a water supply pipe 330. Connecting the water chamber 328 of the block 124, and the chamber 327 of the block 123, is a pipe 331. A pipe 332 tapped into the chamber 326 of the block 123 connects 45 the latter with a chamber in the thrust plate 221. Into the latter is tapped an outlet or off-take for the water.

Galley.—As is common in the art, the galley of the present machine is of the kind ordinarily used by printers in hand setting. The galley is attachable to and removable from the machine. When full or at any desired time, it may be taken from the machine with the type set up therein, and another galley of the same kind may then be substituted for the one removed. Such a galley 333, (see Fig. 54) is shown on the main platform of the machine with its open or inner end against the shoulder 334 formed 60 by a plate 335. The plate 335 extends en-

tirely across the front of the inserted galley, and its upper surface is flush with and forms a continuation of the surface of the latter, so that the two together comprise the galley of the machine. The left hand side piece 336 of the galley 333 rests against stops 337, so as to have its inner surface flush with, and a continuation of a vertical plate 338, attached to one end of the plate 335. Thus positioned, the edge 339 of the galley is secured by 75 clamps 340 to the machine.

Since the width of column of composition set up is variable, it is, of course, necessary that the galley 333 be provided with adjustable type furniture, and that the galley extension formed by the plate 335 be likewise provided with adjustable furniture or its equivalent. Adapted to be secured within the galley 333 is a piece of furniture 341 having pivotally attached to its forward end 80 an arm or locking member 342, which projects over the surface 335 and has in its underside a groove or key-way 343. On the plate 335 is a piece of furniture or block 344, mounted on the end of a rod 345, adapted to 85 have a telescopic adjustment in a sleeve 346. The sleeve 346 likewise has a telescopic adjustment within a sleeve 347, secured to the frame of the machine at 348. Set screws 349 permit the sleeves 346 and 347, and the rod 90 345, to be locked in any desired relative position; and the position of the block 344 on the surface 335 to be thereby adjusted. The block 344 has integral therewith a key or lug 350 adapted to be fitted within the 95 groove or key-way 343 in the arm or member 342 pivoted to the furniture 341, so that when the member 342 is turned down into a horizontal position, the key 350 enters the key-way 343 and locks the block 344 to the 100 furniture 341. When the member 342 is thus locked to the block 344, the end face 351 of the block 344 is flush with and forms an extension of the inside face of the furniture 341.

To adjust the galley for any desired column width of composition, the edge 351 of the block 344 is set by means of the telescopic adjustment mentioned in such a position that the distance between the plate 115 338 and block 344 is equal to desired length of type line. The correct setting of the block 344 is facilitated by means of a graduated plate or gage 353, extending across the head of the galley. When the edge 351 of the block has been brought to the right point on the gage, it is locked in position by means of the set screws 349. The furniture 341 is then inserted in the galley with its end 354 abutting the block 344, and with 120 its edge 355 flush with the edge 351 of the block. The member 342 is then swung down and the furniture locked to the block by means of the key 343 on the latter. The opposite end of the furniture 341 is then 13

clamped to the back of the galley 333 by a clamp screw 356, which passes down through the furniture and into a strip or tongue 357, under and in contact with the galley, so that by turning the screw the galley may be tightly engaged between the furniture and the tongue 357.

Line mechanism.—The individual types as cast and ejected from the mold are set up or assembled in a channel 357 (see Figs. 36 and 54) at the head of the galley, until a line is completed, whereupon the line of type is shifted as a whole into the galley proper. This channel or line 357 is formed on the one hand by a block 358, and on the other hand by a rule 359, and has an entrance through the plate 338 registering with the passage 127 in the mold plate 126. The position of the block 358 is adjustable to make the width of the channel 357 accord with the size of the type or slugs to be set up therein. The shifting of the set-up line into the galley is effected at the end of every line by a movement of the block 358. At this time, the rule 359 must be removed from in front of the type to permit the same to be so shifted. The mechanism for actuating the line shifting block 358, and rule 359, will hereinafter be described in connection with certain other end-of-line mechanisms.

It has been explained that after each type is cast, the mold sections 123 and 124 with the mold blade 125 are moved by the goose-neck slide, until the mold blade is opposite the opening 127 in the mold plate 126, and that the mold blade is then moved to force the type from the mold through the opening 127 to the galley. In order that the type may be forced into the galley channel 357 a sufficient distance to be clear of the moving mold sections, the stroke of the mold blade is such that the blade in delivering a type to the galley, itself enters the line slightly. In Fig. 55 (Sheet 29) the mold blade is shown in its forward position 362, after having just delivered a type 363 to the line.

A yielding type support 364 (see Figs. 23, 36, 55, 56, 61 and 81) holds the type erect and from falling forward as they are forced into and along the line. This support slides on a rod 365 which lies in a pocket or slot 366 in the front of the shifting block 358 (see Fig. 81) across the head of the galley parallel to the line, and which is supported at the mold end of the line by a bracket 365' (Fig. 57) in turn attached to the plate 338. To a tail piece 364' on the type support 364, is attached one end of the cord 367 (see Fig. 56), the other end of which is attached to a spring drum 368 (see Figs. 57 and 36). The tension of the spring drum on the cord tends to throw the type support 364 toward the mold. The support, however, carries a leaf spring 575 adapted, when

the shifting block is in its normal position, as during the setting up of a line, to engage a flange 576 on the shifting block (see Fig. 81) whereby the type support is held against the action of the spring drum 368. The leaf spring 575 does not, however, interfere with the movement of the type support by the type as the latter are forced into the line by the mold blade. As the type are inserted in the line, one after another, the support 364, always engaging the first type, (see Fig. 61) is forced step by step toward the right hand side of the galley.

In order that the type last inserted into the line by the mold blade may not, by sticking to the blade, be drawn back with it toward the mold, and also to keep the type from falling back when the mold blade withdraws, there is provided a type clamp 369 (see Figs. 55, 57, 58, 59 and 50). This clamp moves back and forth perpendicularly to the line in a guideway in the extension 338' of the plate 338 (see Fig. 59), between the mold block and the line shifting block 358. It is actuated from the cam shaft 1, and its movement is so timed that after the mold blade has forced a type into the line, the clamp moves toward the line and engages the type last inserted (see Fig. 55). The clamp is then withdrawn from the type in time to permit the latter to be thrust along the line when the next succeeding type is delivered by the mold plunger.

To the rear of the clamp is attached a link 370 (see Figs. 50, 59 and 44), in turn attached to the upper end of a lever 371, fulcrumed at 372. At its outer end, the lever 371 connects to a link 373, which carries a roller 374, engaging a cam 374' on the cam shaft. A spring 375 attached to the lever 371, and to an adjusting screw 376 on a bracket 377 on the frame, causes the roller 374 to follow the cam 374', and the clamp to move toward the line when permitted by the cam. By adjusting the tension of the spring 375, the pressure of the clamp 369 on the type may be regulated.

In order that the type may not stick to the clamp 369, and thereby be drawn out of line when the clamp moves back, there is attached to the mold plate 126 at the line entrance 127 (see Figs. 25, 36 and 60), a finger 378, which projects outward across the path of the clamp, just back of the type. So that the finger 378 may not in protruding across the path of the clamp interfere with the movement of the latter to the type, the clamp is recessed as shown at 379 in Figs. 58, 59 and 60. The recess 379 permits the clamp to straddle the finger 378, and to engage the type over and under the same. When the clamp withdraws from the line, the finger 378 prevents the type from following. The manner of attaching the finger 378 to the mold plate 126 is shown in Figs. 130

25 and 60. The finger constitutes one arm of a three armed member secured by a screw 380 in recesses or countersinks in the mold plate 126. By reason of these recesses, the 5 finger attachment does not interfere with the movement of either type clamp or the mold blade. The recess 379 in the type clamp is of sufficient width to permit the finger 378 to rise with the mold block when 10 the latter is lifted against the matrix.

10 To assure proper clearance between the mold blade and the type clamp, the edge of the latter is nicked or cut away on the lines 381 and 382 (see Figs. 55 and 58).

15 The edge 381 is sufficiently to the side of the path of the mold blade to prevent any contact of the two while the clamp engages the type, and the edge 382 moves in a path beyond the extreme position reached by the

20 mold blade, during the ordinary movements of the latter. The clamp may, therefore, engage the type and still be at all times out of reach on the mold blade.

Type separator.—Whereas, in the casting 25 of all ordinary sizes of type or slugs at ordinary speeds, the type metal cools so quickly that the type will not adhere to each other in the line, yet, in the casting of type or slugs of unusual size at high speed, 30 it may happen, unless provision to the contrary is made, that the type by reason of insufficient cooling will adhere to each other when pressed together in the line. Accordingly, where it is desired to cast large slugs 35 or type at high speed, the following device is employed, it being understood that under ordinary circumstances, this device is not used and may be removed from the machine.

Attached to the left hand end of the 40 shifting block 358 (see Figs. 61, 62 and 63) by means of screws 384 is a plate 385. In the underside of the plate there is a guideway 386 perpendicular to the line channel 357. Mounted to have reciprocatory movement in the way 386 is a slide 387, in the end of which, near, and parallel to the line 357 is a guideway 388. Mounted to have reciprocatory movement in the way 388 is a second slide 389. The slide 389 carries on 45 its left hand end a finger 390 adapted to project into the path of the type in the line 357. A spring 391 attached at one end to the slide 389 and at the other end to the slide 387 tends to throw the finger 390 toward the left. A projection on the slide 389 by coming into contact with the side 50 of the slide 387 stops the former in its movement to the left. On the other end of the slide 387 is a cross arm 392, and, carried on pins 393 between the latter and the plate 55 385 are coil compression springs 394, the action of which is to throw the slide 387, and, consequently, the slide 389 and finger 390, away from the line 357, until this movement is stopped by the engagement of the

shoulder 395 on the slide 387 with the plate 385.

Pivotedly mounted on a bracket 395' is a 60 rocking arm or lever 396, carrying at one end a set screw 397, which when the lever 396 is rocked, engages the cross piece 392 to move the slide 387 with the separator finger 390 into the type line against the action of the spring 394. On the goose-neck 158 (see Figs. 36, 61 and 62) is a lug 398. Into the 65 path of this lug, as the goose-neck moves, projects one end of the lever 396. As the goose neck moves to carry the mold sections with the type last cast from the casting position to the galley entrance, the lug 398 on 70 the goose-neck slide engages the end of the arm 396, and by rocking the same moves the slide 387, so that the separator finger is projected into the type line, as shown in Fig. 61. The separator finger reaches the position shown in Fig. 61, before the mold blade delivers the type, so that when the type is finally delivered by the mold blade, 75 it is first forced against the type separator finger. The mold blade then continuing to 80 advance, forces the type, and with it the separator finger 390 and its slide 388, against the resistance of the springs 391, until the type has been fully delivered to the line. The type clamp 369 now comes forward, as 85 heretofore described, to engage and hold the type while the mold blade returns to a setting position. The type clamp pressing against the type, as shown in Fig. 61 holds 90 the type and the separator finger 390 from moving in response to the action of the spring 391, when the mold blade returns. The goose-neck slide now returns with the mold sections 123, 124 and 125 to the casting 95 position, and in so doing, releases the arm 1 396 and the slide 387 to the action of the springs 394. These springs at once act to withdraw the separator finger 390 from the line clear of the type, which continues to be held by the clamp. The spring 391 is then 100 free to act, and moves the finger 390 past the type held by the clamp, and into the position from which it was forced by the joint actions of the mold blade and goose-neck. The separator is then ready for the next type. The presence of the separating finger between the type already set up in a line and the type just being forced into the same permits the latter to cool, before it is allowed to engage the previously set up type.

End of line mechanism.—At the end of each line, the type set up must be given a final compression in the galley channel. The compressed line of type must be tested as to its length, so that, if by chance the line be over or under-fed, the machine may be automatically stopped to permit the error to be corrected. If no error appears in the line, the rule must then be dropped and the

line shifted into the galley. The steps recited concern, obviously, only the type already set up. Concurrently with these operations however, there must take place another group of operations, which relate, not to the line that has been cast, but to the line next to be cast. The present machine, it is understood, automatically justifies the line during the casting and setting up of the same by casting the space quads of a predetermined size, such that, the line, when fully set up, should always be of a predetermined unit length. Accordingly before the casting of a line, certain mechanisms which may be termed the justification mechanisms, must be set to determine the size of space quads to be cast in that line. Since the mechanisms affecting the line already cast, which may be termed the end-of-line mechanisms, and those relating to the justification of the line to follow, must all operate in the brief interval between lines, the two groups of mechanisms may conveniently coöperate, and to some extent be made identical. This has been done in the present machine, and many of the parts which are immediately to be described, relate as well to the justification mechanisms as to the end-of-line mechanisms. Such parts first will be considered in connection with the end-of-line mechanisms.

After all the type to be contained within a line are cast and fed into the channel at the head of the galley, as heretofore described, the first step is to disconnect from the index head, those mechanisms concerned exclusively with the casting of type, and to connect to the cam shaft and to the index head the end-of-line and justification mechanisms heretofore idle. In the present machine those last named mechanisms are in part operated positively from a cam member 400 on the cam shaft. This cam member rides idly on the shaft during the casting and setting up of type, but at the end of each line is locked to the cam shaft by means of a clutch, in turn electrically operated from the trip pin in the index head, whenever a punch hole in the tape registers therewith. The resulting movement of the cam member 400 is conveniently utilized to operate the switch whereby the exclusively type casting circuits are disconnected from the index head and the justification and end-of-line circuits connected thereto. The punch hole in the tape which closes the circuit of the trip pin to trip the clutch and lock the cam member 400 to the shaft, may be designated as the trip hole. Such a hole is shown at 401 in Fig. 8. Since it is this hole which first sets into operation the justification mechanism, this will be the first hole presented to the index head at the beginning of each line. It will be recalled that this is 65 the hole punched by the operator at the com-

posing machine in the closing of each line. Ordinarily, there is but a single justification, and, therefore, a single trip hole for each line. When, however, a line is to be justified in parts, there must be a trip hole 70 for each justification, as will presently appear.

Referring now to Figs. 5, 6, 64 and 65, the cam member 400 is shown fast to a sleeve 403, in turn loosely mounted on a second sleeve 404 on the end of the cam shaft 1. On the end of the sleeve 403 is a pinion 405, and on the end of the sleeve 404 is a pinion 406. Loosely mounted on a stud 407, on the standard of the machine, near the bearing therein of the shaft 1 (see Figs. 6 and 65) are planetary gears 408 and 409, the gear 408 meshing with the gear 405 on the sleeve 403, and the gear 409 with the gear 406 on the sleeve 404. The planetary gears 408 80 and 409 are so designed with respect to the sun gears 405 and 406, that the sleeve 403, with the cam member 400, will have one revolution for every two revolutions of the sleeve 404. During the casting of type, the 90 sleeve 404 rides loosely on the shaft 1, so that the cam member 400 may not be driven through the gearing described. Fast to the inner end of the sleeve 404 is a collar or second sleeve 410 having splined thereto a 95 clutch member 411. The clutch member 411 may be moved longitudinally on the collar 410 into and out of engagement with a second clutch member 412 held fast to the shaft 1 by a set screw 413. The clutch member 411 is loosely engaged by a yoke 414, forming part of a clutch arm 415, pivoted at 416 to ears 417 on the cam member 400.

A coil compression spring 418 bears against the arm 415 to throw the clutch 105 member 411 into engagement with the clutch member 412, when the cam member 400 is to be locked to the cam shaft. During the casting and setting up of type however, the arm 415 is engaged by an arm or 110 latch 419 and held against the action of the spring 418 so that the clutch members are disengaged, and the cam 400 disconnected from the shaft. The arm or latch 419 is fast to a rock shaft 420 (see Figs. 65 and 66) 115 mounted in a bracket 421. Also fast to the shaft 420 is the armature lever 422 of an electro-magnet 423 in the circuit of the trip pin of the index pins 46. A spring 424 normally holds the arm 419 in such a position that the 120 clutch arm 415 is prevented from rocking, and the clutch members 411 and 412 held apart. When, however, a trip punch hole 401 presents itself at the index head, the magnet 423 is energized and the latch 419 125 rocked in an arc away from the arm 415 to permit the throw of the clutch to lock the cam member 400 to the shaft. As the cam moves, it carries with it in its revolution the clutch arm 415, and quickly takes the latter 130

out of reach of the latch 419. As soon as the magnet 423 is deenergized, the latch 419 falls back again to its normal position. It does not, however, in falling back at once release the cam 400 from the shaft because the clutch arm 415 has been revolved by the cam out of reach of the latch. The latch, however, lies across the path of revolution of the clutch arm so that as the cam completes its first revolution the clutch arm is wiped across the face of the latch and thereby rocked to disengage the clutch members and stop the cam. In this position the clutch rests until another trip hole presents itself at the index head.

The cam member 400 carries several cam surfaces. A peripheral cam surface 425 on the cam member engages a roller 426 on the end of a cam lever 427, pivoted at 428 (see Figs. 64 and 67). One of the functions of this cam lever is to operate a switch or circuit changer 429. This is the switch heretofore referred to for disconnecting from the index head those circuits relating peculiarly to the casting of type, and for connecting to the index head those circuits relating specially to the end-of-line and justification mechanisms, and vice versa. The first mentioned of these groups of circuits will hereinafter be termed the working circuits, and the other group the setting circuits. Since the two groups of circuits are not concurrently used, the same pins 46 at the index head may conveniently be employed to control both groups, and unnecessary duplication of pins and circuit connections thereby avoided.

The switch 429 carries a set of thirty contacts 430 (see Fig. 67 and side elevation in Fig. 3). On a switch-board 431, co-acting with the switch are mounted two rows 432 and 433 of thirty contacts each, one above the other. The switch contacts 430 engage the switch-board contacts 432, when the switch is elevated, and the switch-board contacts 433, when the switch is lowered. The switch contacts 430 are severally connected to the mercury wells 434 in the base block 52 of the index head (see Fig. 12). The wires forming these connections are grouped in cables 436 (see Fig. 67). The lower row of switch-board contacts 433 represent terminals in the working circuits, and the upper row of switch-board contacts 432, terminals in the setting circuits. The wires are led from the switch-board terminals in a cable 436 (see Fig. 67). From this, it will appear that during the casting and setting up of a line, the switch 429 rests on the contacts 433, and that when the switch is shifted at the end of every line, it rests on the contacts 432. The switch may, therefore, be considered as held normally depressed by the cam 425 on the cam member 400, acting through the bell-crank lever 427, one arm 437

of which engages a slide 438 by which the switch is carried. A spring 439 engaging a third arm 440 of the lever 427 rocks the same and raises the switch as soon as permitted so to do by the cam 425. This, as has been seen, occurs when the trip magnet 423 is energized to throw the clutch and start the cam member.

Final positioning of type in line.—One effect then of the operation of the clutch 411—412 in response to the presentation of a trip hole in the tape is to throw the switch 429 to the setting circuit contacts. Another result of the throw of the clutch 411—412, and consequent movement of the cam member 400 is to actuate a lever 440 (see Fig. 6). This lever is pivoted at 441 to the frame of the machine and carries at its end a roller 442, engaging the cam 425 on the cam member 400. A coil spring 443 on the pivot post 441 of the lever causes the same to follow the cam surface 425 and to rock in response thereto. This lever at an intermediate point 444 of the same is adapted to be connected to and to move the slide 197 on which the mold blade lever 135 is fulcrumed at 196. When the slide 197 is moved by the lever 440 in response to the cam 425, the fulcrum of the mold blade lever 135 is correspondingly moved. This movement of the slide 197 is designed to take place only at the end of the line. The object of shifting the mold blade lever fulcrum at this time is to cause the mold blade plunger 125 to have a stroke of exceptional length in delivering the last type to the line, so that all the type in a line may be given a final positioning preliminary to the shifting of the line to the galley.

It has been seen that the type as they are set up in the line are engaged and held by a type clamp; that the type clamp has certain movements to and from the line, so as to permit the type to be fed into the line and then to engage the same before the mold blade withdraws; and that the clamp is so cut or shaped as to be out of reach of the mold blade during all ordinary movements of the latter. The clearance provided between mold blade and type clamp, while sufficient during the normal movements of the blade is entirely insufficient when the blade makes its abnormal stroke at the end of the line. If at this time the clamp be allowed to have its usual movement to the line, the blade and the clamp will strike each other. Therefore, since the clamp has no function to perform when the line is being finally positioned by the mold blade, its usual stroke to the line is eliminated. Pivoted to the machine frame at 445 (see Figs. 36 and 50) is a latch 446 in the form of a bell crank lever, one arm 447 of which lies in the path of the link 370 (see Fig. 50) by which the clamp is moved. The other arm 448 of the lever lies in the path of an

adjusting screw 449 (see Fig. 36), carried on a lug 450, attached to the mold blade fulcrum shifting slide 197. When the slide 197 is in its normal position, the bell crank lever 446 serves merely as a stop for the link 370. When, however, the slide 197 is shifted at the end of the line by the cam 425, the set screw 449 is moved into such a position with respect to the arm 448, that the lever 446 is not free to rock so that when the type clamp in its movement toward the line engages the arm 447, the movement of the type clamp is stopped by the engagement of the arm 448 with the set screw on the shifting slide, thus preventing the clamp from reaching the line at the time the mold blade is positioning the same.

It has just been pointed out that the fulcrum shifting slide 197 is operated from the cam member 400 by means of the cam lever 440. If, therefore, the lever 440 be permanently attached to the slide 197, the latter will move on every movement of the cam member 400. It is apparent that the slide 197 should move but once for each line, because the only purpose of moving the slide at all is to test and prepare for the galley a line that has been fully set up. On the other hand, the cam lever 440 to which the slide 197 is connected must move every time justification is called for since it is through this cam that the justification mechanism is actuated. In the more usual kind of composition, the lines are justified but once and for their entire length. When, therefore, the machine is handling composition of this class, the cam member 400 need be actuated but once for each line to set the justification mechanism. Since in such case the cam member has but one movement during the line, the slide 197 may well be permanently locked thereto. The machine is not uncommonly employed, however, to handle composition, such for instance, as tablative work, where several portions or lengths of a line are to be justified independently. Where such is the case, the justification mechanism must be set at the beginning of each of the several lengths to be justified, and the cam member 400, must, therefore, be turned not only at the end of the line, but at intermediate points thereof. Since, under no circumstances, however, must the slide be operated more than once for a line, it is apparent that in multiple justification work, provision must be made whereby the cam member 400 may move independently of the slide 197 except at the end of the line, when both should, of course, move together.

In order that the cam member 400 may actuate the slide 197 at the end of the line and at other times be free thereof, the following device is employed. Referring to Figs. 6, 68 and 69, it will be seen that in the

lever 440 over the slide 197 is a pocket 453 into which projects the lug 454 on the slide 197. The lug 454 is not, however, of the full width of the pocket 453. There is a clearance 455 between it and the wall of the pocket, whereby the lever 440 may rock with the cam 400 during multiple justification, without engaging the lug 454 to move the slide. This clearance may be varied by adjusting screws 456. If this clearance is eliminated, the slide 197 must, of course, move whenever the lever moves. Except when the machine is doing multiple justification, clearance between the lever and slide is not necessary, and may be eliminated. When multiple justification is being effected by the machine, however, the clearance 455 must always exist except at the end of each line. At the end of the line, however, the clearance must always be eliminated, so that the slide will move with the lever. For this purpose, there is in a pocket 457 in the slide immediately below the pocket 453, a distance piece 458, adapted to be elevated to enter the pocket 453 and take up the clearance 455. When the distance piece 458 is in place in the pocket 453, the slide 197 and lever 440 are effectively locked. The distance piece is held normally depressed and out of the pocket by a spring 459. It is adapted to be raised by means of a lever 460. The lever 460 carries the armature of an electromagnet 462, wherefore, the latter when energized locks the slide to the lever 440. The magnet 462 is energized at the end of line only, and by means of a circuit closing device presently to be described. To eliminate the clearance 455, the distance piece may be locked in its elevated position by means of a set screw 463, in which case the slide and lever 440 are locked and the machine set as for single justification.

We now come to the last function of the cam member 400, which is to operate a slide 465 (see Figs. 49, 70 and 71) by means of which a number of objects are effected. The slide 465 carries on one end a roller 466 (see Fig. 49) which engages the cam surface 467 on the cam member. When the clutch is tripped to lock the cam member 400 to the cam shaft, the rotation of the cam draws the slide forward. The slide is returned by a coil spring 468, acting through an arm 469 (see Fig. 49), which engages the slide behind a plate 470 attached thereto. This slide among its other functions sets the justification mechanism, and may, therefore, be conveniently designated as the justification slide. It is this slide, however, which operates those mechanisms effecting the final transfer of the line to the galley, which we have hereinbefore referred to as the end-of-line mechanism, and it is in the light of its action on the end-of-line mechanisms that the slide will first be considered. The end-

of-line mechanisms, such for instance, as the means for dropping the rule, moving the line shifting block, etc., are not, however, connected immediately to the justification slide, but to the same through the medium of a second slide 471, which may conveniently be termed the end-of-line slide. The purpose of two slides instead of one is to permit the justification mechanism to be operated independently of the line shifting mechanisms. The need for two slides arises in the adaptability of the machine to multiple justification. If the slides 465 and 471 were at all times integral, so as to be in effect a single slide, it is apparent that every setting of the justifier would result in the operation of all the end-of-line mechanisms. The situation here is precisely analogous to that discussed in connection with the full crum shifting means. Where the line requires but one justification, the two slides may be permanently locked. Where, however, multiple justification is required, the end-of-line slide 471 must be free of the justification slide 465, except on the movement of the latter at the end of the line, when, of course, the end-of-line slide must be operated with the justification slide.

The means by which the slides are locked and unlocked to meet the requirements of multiple justification will be seen upon reference to Figs. 72 to 77 inclusive. Mounted in the end-of-line slide 471 to have an up and down movement in a pocket 473 therein is a clutch member 472. This member carries on its upper face a tooth 474, which when elevated is adapted to enter a pocket 475 in the under face of the justification slide 465, thereby locking the two slides, so that on a forward movement of the justification slide, the end-of-line slide will likewise move forward. A curved surface or cut 472' in the slide 471, by engagement with the bottom of the member 472, makes certain the complete entry of the tooth 474 into the pocket 475 when the member 472 is however slightly engaged by the slide 465. The beveled edge 474 of the tooth 472 by engagement with a corresponding beveled wall of the pocket 475, causes the clutch to be depressed and the end-of-line slide to be released from the justification slide upon backward movement of the latter. A light spring member 477 by centering in a nick in the clutch member 472, insures the complete withdrawal of the latter from the path of movement of the slide 465.

The clutch 472 protrudes below the lower face of the end-of-line slide and into an elongated slot 478 in the platform of the machine. The slot 478 is of sufficient length to permit the required movement of the clutch with the slide. In a passage through the platform below the clutch is loosely

mounted a pin 479, engaged by a coil spring 480, which tends to throw the pin upward against a beveled face 481 on the base of the clutch, and thereby to raise the latter so that the tooth 474 thereof may enter the pocket 475 in the justification slide. The pin 479 is, however, normally held depressed against the action of the spring 480 by a shoulder 482 on the head of a second pin 483, which is loosely mounted in a bracket 484, attached to the underside of the platform. A spring 485, bearing against the head of the pin 483, normally holds the shoulder 492 under the head of the pin 479 to prevent the spring 480 from throwing the pin 479 up against the clutch. The pin 483 is cut away as shown in Figs. 74 and 77, so that a beveled shoulder 486 is formed thereon. The beveled shoulder 486 is adapted to engage a corresponding bevel in a pin 487 mounted in the bracket 484 to have a movement perpendicular to and in a recess 488 in the pin 483. The pin 487 is normally depressed by a spring 489, so that the shoulder 486 on the pin 483 fits within a conversely formed notch in the pin 487. The armature lever 490 of an electromagnet 491 (see Fig. 7) co-acts with the pin 487 to lift the same against the resistance of the spring 489.

When the electromagnet 491 is energized, the pin 487 is elevated, and by reason of the beveled engaging surfaces of the pins 487 and 483, the latter pin is shifted until the shoulder 482 is removed from in front of the head of the pin 479. The pin 479 then springing up in response to the spring 480 engages the lower surface 481 of the clutch member and exerts a pressure on the latter to lift the same into the pocket 475 in the justification setting slide, so soon as the pocket 475, by virtue of the forward movement of the justification slide shall register with the tooth 474 on the clutch. Therefore, on further movement of the justification slide, the two slides move forward together. As the end-of-line slide moves forward with the justification setting slide, the beveled surface 481 of the clutch is drawn over the end of the pin 479, depressing the latter to its original position, and the pins 487 and 483 having by this time been again released to the action of their springs 485 and 480, the retaining shoulder 482 on the pin 483 locks the pin 479 in its depressed position.

When the machine is to effect but one justification for each line, the clutch 472 is so set that the end-of-line slide is moved by the justification slide on every movement of the latter. To effect such a setting of the clutch, it is simply necessary to push back the pin 483, so that the stop shoulder 482 is removed from the path of the setting pin 479, and then to lock the pin 483 against the action of its spring 485. This locking

is accomplished by means of a set screw 492 (see Fig. 76). The pin 479 is now free to force the clutch tooth 474 into the pocket 475 of the justification slide whenever the 5 pocket and tooth register, which will occur every time the justification slide moves forward.

The electromagnet 491 is not energized to lock the end-of-line slide to the justification 10 setting slide upon the first movement of the latter at the end of the line. It will be recalled that the cam 402 is thrown into a gear with the cam shaft 1 by the clutch 410'—411.

15 *The control of the end-of-line slide lock from the record strip.*—For the purpose of avoiding multiplication of parts, a single index pin 46 is made to control both the circuit of the trip magnet 423 and that of the 20 slide lock magnet 491. The trip magnet is in one of the circuits on the working side, that is to say, in one of the circuits leading to the switchboard terminals 433. If the 25 pin which controls the trip magnet circuit is likewise to control the circuit of the slide lock magnet, the circuit of the latter must be on the setting side, as it is necessary that the two magnets be separately operable. Accordingly the magnet 491 is connected to 30 one of the setting terminals 432 of the switchboard. This magnet can therefore be energized only after the switch 429 has been thrown, or in other words, after the 35 circuit of the trip magnet has been closed by a trip hole 401. The cam member 400 makes but one revolution for two revolutions of the cam shaft, whereas, the tape is fed once every time the cam shaft turns. After the partial rotation of the cam member 400 has lifted the switch to the setting 40 terminals 433, and before the completion of its rotation again depresses the switch, there registers with the index pin, a hole 493 (see Fig. 8) by means of which the circuit of 45 the slide lock magnet 491 is closed. The partial rotation of the cam member 400 has, however, by this time drawn the pocket 475 (see Fig. 74) well forward of the clutch tooth 474, so that although the magnet 491 50 has released the setting pin 479 of the clutch, no operation of the end-of-line slide can take place on this rotation of the cam member. The cam member 400 now completes its revolution, returning the switch to 55 the working circuits and the justification slide to the position shown in Fig. 74. The parts are then in the position in which they first were found by the trip hole 401, except that the pin 479, which has been released is now 60 bearing against the clutch member 472. To move the end-of-line slide the trip magnet 423 must therefore again be operated, and for this purpose there is in the tape a second trip hole 494 following the hole 493. No 65 sooner, therefore, does the cam member 400

complete its first revolution than it is called upon to make another. In making this second revolution, all the parts connected to the cam are actuated as before, but when the justification slide comes forward on this 70 occasion, it picks up and carries with it the end-of-line slide by reason of the released setting pin 479.

It is obvious that when, as in multiple justification, a trip hole 401 occurs intermediate the ends of a line for the purpose of setting the justifier for the justification of some part only of the line, then the trip hole 401 is unaccompanied by the holes 493 and 494. Also where the machine is effecting but one justification for the whole line, the holes 493 and 494 are absent. In case of single justification, it will be remembered that the lock pin 479 is always set, and that, therefore, the lock magnet 491 has no function.

Control of the distance piece setting magnet by the end-of-line slide.—It will be recalled that when multiple justification is being effected, the fulcrum shift slide 197 is 90 free of its actuating lever 440, except at the end of the line, when by reason of a distance piece 458, the slide is locked to the lever. The means for operating the distance piece has been shown to be a magnet 95 462. Since there is no occasion to operate the magnet 462, except when the end-of-line slide is operated, the circuit of the magnet may well be closed by the movement of the slide. This is the first operation performed 100 by the end-of-line slide as it moves with the justification slide. For this purpose, there is in the circuit of the magnet a circuit maker or breaker 495 (see Figs. 49, 70 and 71) pivotally mounted at 496 on the frame of 105 the machine, and having an arm 497, projecting into the path of the movement of a lug 498 on a plate 499 on the end-of-line slide 471 (see Fig. 72). A spring 500 attached to the machine frame and to the 110 plate 499 holds the end-of-line slide, except when the latter is carried forward by the justification slide, in a position determined by the engagement of the stop 501 on the slide with a stop 502 on the machine frame. 115 When in this position, the lug 498 bears against the arm 497 of the circuit maker and breaker, and holds apart the contacts 503 and 504 thereof. The circuit of the distance piece magnet 462, which may be traced 120 through the wire 505, binding post 506, pivot 496, contact 503, contact 504, binding post 507 and wire 508, is then broken. As soon, however, as the end-of-line slide moves forward with the justification slide, and the 125 lug 498 moves away from the arm 497, the circuit maker and breaker is released to the action of a light spring 509 (see Fig. 49), whereupon the contacts 503 and 504 engage and the circuit of the distance piece 130

magnet 462 is closed to lift the distance piece. An instant later, the arm 440 shifts the fulcrum of the mold blade lever, and the mold blade finally positions the type assembled in the line.

Automatic cut-out.—The next function of the end-of-line slide is to operate automatically a cut-out to stop the machine in event the line, when positioned by the mold blade 10 is found to be under-fed or of insufficient length. The cut-out is also effected automatically without the aid of the end-of-line slide in event of a squirt or of an over-fed line. The automatic cut-out and the various means for operating the same will now 15 be considered.

It has been seen that the cam shaft 1 is driven by a motor 2 (see Fig. 4). This motor and the connections 510 to the lighting 20 circuit from which it receives its power are indicated diagrammatically in Figs. 7 and 78. In the line 510 is a circuit maker and breaker consisting of contact strips 511 and a metallic plug 512. The plug 512 is carried on the end of a shaft 513, adapted to be reciprocated longitudinally in its bearings. A coil spring 514 on the shaft tends to move the shaft in a direction to withdraw the plug from the terminals 511 to break the 30 circuit of the motor. The shaft is held against the action of the spring by a latch 515, one arm of which engages a collar 516 on the shaft. The other arm 517 of the latch constitutes the armature of an electromagnet 518. When the magnet is energized 35 the latch 515 is disengaged from the collar 516 and the shaft released to the action of the spring 514. The circuit 513—514 of the electromagnet includes a suitable source of 40 electrical energy and also includes a peculiar circuit maker and breaker and circuit changing device 529, shown at the left.

The circuit of the magnet 518 is normally open so that the motor circuit 510 may be 45 maintained closed. The magnet 518 is, however, adapted to be energized to break the motor circuit and stop the motor upon any one of these contingencies mentioned, viz. when a squirt occurs at the mold, when at 50 any time the line being set up in the galley channel may be over-fed, and when after the line has been set up, it be found that the line is underfed.

Automatic cut-out in event of squirt.— 55 The operation of the squirt preventer has been heretofore discussed in connection with Figs. 45, 46 and 47. It only remains to trace the circuit of the squirt preventer to the cut-out magnet. Referring to Figs. 47, 60 7 and 78, the wire 269, which is attached at one end to the pivot post of the circuit breaker 267, is at the other end (see Figs. 7 and 78) connected at 519 to the positive supply wire. The wire 270 from the contact 65 272 passes direct to the cut-out magnet (see

Fig. 78). From the cut-out magnet, the squirt preventer circuit is continued by the wire 520 back to the supply lines. Every time, therefore, that the squirt preventer is actuated to close the contact 272, the cut-out 70 magnet is energized and the motor circuit broken to stop the machine.

Automatic cut-out in event of over-feed.— 75 The cut-out magnet 518, besides being in the circuit 269—270 of the squirt preventer is in a second circuit indicated at 522—523, (see Figs. 7 and 78). The line 522 may be traced from the point 519 of the supply wire (see Fig. 78) to a binding post 524 carried by a circuit breaker 525, pivoted at 526 on the 80 machine (see Figs. 78 and 79). The line 523 may be traced from a stationary contact 527 at the circuit breaker, through the cut-out magnet, and by way of the wire 520, back to the supply wires. The contact 527 85 is opposed to and adapted to be engaged by a contact 528 on the arm 529 of the circuit breaker whenever the arm 529 is rocked. When these contacts thus engage, the circuit 90 of the cut-out magnet is closed, and the circuit of the motor broken to stop the machine.

The circuit changer 529 has an arm 530, the end of which is insulated and fits within a yoke 531 on the end of an arm 532 freely pivoted at 533 to the machine. Also freely 95 pivoted at 533 is an arm or lever 534 having yielding connection with the arm 532 by means of a compression spring 535. When the arm 534 is moved toward the arm 532, this motion is presently transmitted by the 100 spring 535 to the latter arm, and so to the arm 530 of the circuit breaker, raising the arm 529 thereof.

The upper end of the arm or lever 534 bears against the end of the rod or slide 105 365. It will be recalled upon reference to Figs. 56, 57 and 58, that the other end of this bar 365 is supported in the bracket 365' at the line entrance; and that it is upon this bar that the type support 364 has its movement along the line with the type. The bar 365 also carries a stop 536, which may be made fast thereto at any desired point by means of a set screw 537. The stop 536 lies in the path of the type support 364 as 110 the latter moves along the bar. The bar has a slight longitudinal movement in its bearing in the bracket 365', but is normally held at the end of its bearing toward the plate 338 (see Fig. 57) by means of a spring 115 538 (see Fig. 78) acting through the medium of the lever 534. When, however, the stop 536 is engaged by the moving type support 364, the bar 365 is moved in its bearing against the action of the spring 538, so that 120 the levers 534 and 532, and the circuit breaker 525, are rocked. Whether or not the circuit breaker will be rocked sufficiently 125 to make the contacts 527 and 528 will depend upon the distance the stop 536 is moved 130

by the type support 364, or in other words upon the amount of type fed into the line above and beyond the amount just necessary to force the support into contact with the 5 stop. In practice, the stop 536 is so positioned on the bar 365 that when a line of type of the predetermined correct length is finally positioned by the mold blade after the fulcrum of the lever of the latter has been 10 shifted, the type support will be forced against the stop 536, and the latter carried therewith a distance sufficient to lift the circuit breaker arm 529 slightly, but not sufficient to make the contacts 527 and 528 15 to stop the machine. If, however, for any reason, more than the predetermined amount of type is fed into the line, so that the line is in fact over-fed and of incorrect length, then the type support 364, and with it the 20 stop 536, are given an abnormal movement, the result being that the arm 525 of the circuit breaker is moved a distance sufficient to make the contacts 527 and 528, to stop the machine. This abnormal movement of 25 the stop may occur before in fact the line is closed, or the mold blade lever fulcrum shifted. Whenever it occurs, the machine is stopped.

It will be understood that all parts of the 30 automatic cut-out mechanism are properly insulated, so that none of the circuits may be grounded through the machine.

Automatic cut-out in event of under-feed.—

The line 523 of the cut-out magnet, in addition to having a connection to the contact 35 527, has also a connection to the pivot post 540 of a second circuit breaker 541 (see Figs. 78, 79 and 80). This second circuit breaker is in effect a bell crank lever, but the two 40 arms 542 and 543 thereof, instead of being rigidly connected, are as shown in Figs. 79 and 80, and for reasons to be presently noted, yieldingly connected by a spring 544. On the end of the arm 542 is a contact 545, 45 opposed to and adapted to engage a contact 546. The contact 546 is in electrical connection with a contact 547, and the latter contact is opposed to and adapted to be engaged by a contact 548 on the underside of 50 the arm 529 of the first circuit breaker 525.

When, therefore, contact 545 is in engagement with the contact 546, and contact 547 with contact 548, then the circuit of the 55 cut-out magnet 518 is closed as follows— from supply line through line 522, binding post 524, circuit breaker arm 529, contacts 548 and 547, metal plate 549, contacts 546 and 545, arm 542 of circuit breaker 541, pivot 540, wire 540', line 523 through cut-out 60 magnet 518, returning to supply lines by line 520.

The normal position of the circuit breaker 525, during the casting and setting up of a line, and before the type support 364 engages the stop 536, is such that the contact 65 548 rests upon the contact 547. If,

therefore, the line is under-fed, so that the type support does not engage the stop 536 to rock the circuit changer arm 529, even when the mold blade makes its long stroke at the end of a line, then the circuit of the cut-out magnet 518 is closed, so far as the contacts 547 and 548 are concerned. The circuit is still open at the contacts 545 and 546 however, and remains open at this point until the end-of-line slide moves with the 70 justification slide, whereupon the circuit is closed and the machine stopped.

In order that the movement of the end-of-line slide may effect the closing of the contacts 545 and 546, the arm 543 of the circuit closer 541 projects into the path of a pawl or latch 549 carried on, but insulated from the end-of-line slide (see Figs. 49, 70, 71, 72, 75 and 78). As the slide moves forward, the pawl 549' strikes the arm 543, 80 rocking the latter, and with it, by virtue of the spring 544, the arm 542, thus closing the contacts 545 and 546. The spring 544 then permits the arm 543 to have such further movement as may be necessary to allow the 85 pawl 549' to pass by. A spring 550 (see Fig. 80) opens the contacts 545 and 546, and returns the circuit closer 541 to normal position after the passage of the pawl. The pawl is yieldingly pivoted to the slide, so 90 that on engaging the arm 543, when the slide returns, it may by rocking, pass over the arm.

It has been stated that the stop 536 on the bar 365 is so set that when the line is of the 100 correct length, the circuit changer arm is rocked very slightly. This slight movement of the arm 529 suffices to lift the contact 548 from the contact 547. When in such case, the end-of-line slide subsequently closes 105 the contacts 545 and 546, the circuit of the cut-out therefore remains open, and there is no stoppage of the machine. It is thus that only in the event of an under-fed line does the movement of the end-of-line slide 110 effect the cut-out.

The automatic cut-out device is restored to its normal position with the plug 512 between the strips 511 by means of a button 513' on the rod 513, which extends to the 115 front of the machine (see Figs. 3 and 78).

Shift of line to galley.—Provided the line in the galley channel is of correct length, so that the machine is not stopped when the pawl 549 on the end-of-line slide strikes the 120 arm 543 of the cut-out circuit closer, the end-of-line slide continues forward and sets in motion the mechanisms for dropping the rule 359 and for actuating the lint shifting block 358.

Referring now to Figs. 59, 81, 82, 83 and 84, it will be seen that the rule 359 is carried in bearings on the ends of arms 551 and 551' fast to a shaft 552 in a bracket 553, depending from the machine platform. A coil 130

spring 554 on the shaft 552 holds the rule normally elevated. Integral with one of the arms 551 is a finger 555 (see Figs. 59 and 83). The finger 555 projects into the 5 path of a slide 556, adapted to have up and down movement in a guide way 557 in the bracket. The slide 556 when moved upward engages the finger 555 to rock the shaft 552 and to depress the rule. The spring 554 acting through the finger 555 holds the slide 10 normally depressed. Pivoted to and depending from the slide 556 is a pawl or finger 558 beveled at 559 on its lower face. The beveled portion 559 of the finger 558 projects into the path of a corresponding beveled surface 560, on the end-of-line slide 471 (see Figs. 83, 49, 70, 71, 72 and 75).

When the end-of-line slide moves forward with the justification setting slide, the surface 560 engages the surface 559 on the block 556, raising the latter and depressing the rule. The finger 558 is pivoted to the block 556, and has a spring connection therewith, so that it may be turned out of the 20 path of the end-of-line slide on the return stroke of the latter. To permit the rule to be depressed manually at any time, there is in engagement with the arm 551' on which the rule is mounted, a second arm 561 (see 25 Figs. 59, 81, and 82), pivoted at 562. Supported by the arm 561 and projecting through the platform is a pin 563. The pin 563 carries on its upper end a button or handle 564. By pressing the button 564, the 30 lever 561 may be depressed to the position shown in Fig. 82, carrying with it the arm 551' and the rule. As soon as the pin is released, the spring 554 returns the parts to their normal position.

40 The line shifting block 358 (see Figs. 59, 81 and 82) is securely attached to a slide 565. The line shifting block is held in its normal position to the front of the line by a coil spring 566, attached on one end to 45 the slide 565 and at the other end to a cross piece 567 on the bracket 553. An adjustable stop 568 determines the position assumed by the line shifting block under the action of the spring. The normal position 50 of the shifting block may be adjusted for any desired width of type line by means of this stop. Pivoted to the frame at 569, below the shifting block is a lever 570 having an arm 571, adapted, when the lever 55 570 is rocked, to push the line shifting block across the line against the action of the spring 566. The lower arm 572 of the lever 570 lies in the path of a lever 573 (see Figs. 49, 81, 82, 70 and 71), so that when the 60 lever 573 is rocked forward, the lever 570 is rocked to move the line-shifting block. The lever 573 is bent at 574 (see Fig. 49) to cross the path of a lug 575 on the forward end of the end-of-line slide 471. When, 65 therefore, the end-of-line slide in its for-

ward movement with the justification slide, reaches the arm 573, the line shifting block starts with the line toward the galley. This movement is so timed as to have allowed the rule to be depressed out of the path of the line of type. The lever 573 is loosely pivoted to the frame, so that the spring 566 (see Fig. 82) acting through the slide in the lever 570 may return the arm 573 when the end-of-line slide returns to its normal position. 70

The movement of the line shifting block, with the line of type, releases the type support 364 (see Fig. 56) to the action of the spring drum 368 (see Fig. 57), and the support is then returned to its initial position at the line entrance. It will be remembered that the type support 364 is held against the action of the spring drum 368, by reason of the frictional engagement of the spring 575 on the type support with the flange 576 in the shifting block, (see Fig. 81) when the latter is in its normal position and the line is being set up. Upon forward movement of the line shifting block, however, 80 the flange 576, as shown in Fig. 82, is removed from the leaf spring 575, and the type support 364 is thereupon free to obey the drum spring 368. 85

Safety device to protect galley mechanism 95 from injury by over-fed line, line supports, etc.—Referring now to Figs. 36 and 54, it will be noted that in the block 344 is a slide 577. A spring 578 urges the slide in the direction of the rule. A spring pawl 579, 100 jamming against the surface of the slide holds the latter against movement by the spring 578, in whatever position in which the slide may be set. The slide is normally set (see Fig. 36) so that its end is substantially flush with the edge of the passage through the platform for the rule. Carried by the slide is a leaf spring 580. On the free end of the leaf spring is a pin 581, the end of which is rounded and protrudes slightly 110 beyond the edge 351 of the block 344 into the galley. When the line shifting block shifts a line of type of correct length into the galley, the pin 581 is forced by the type back into the slide 577, but exerts a slight pressure on the end of the line of type thus introduced. This pressure is sufficient to hold the line erect and in position until the next line is introduced. 115

The purpose of the spring slide 577 is to 120 provide a yielding abutment on the block 344, so that, if by any chance, an over-fed line of type is forced into the galley by the line-shifting block, no injury may be done to the parts. In event of such an over-fed 125 line is fed to the galley, then as soon as the over-fed type strikes the slide 577, the latter yields against the action of the spring 578. When now the line shifting block, on its return movement, relieves the slide of 130

pressure from the type, it is necessary that the slide be prevented from moving in response to the spring 578. Otherwise, the over-fed type will be thrown back by the 5 slide, and may, possibly fall across the rule passage, in which case the return of the rule may be prevented or parts broken. This return kick of the slide is prevented by the spring pawl 579, which holds the slide in 10 whatever position it may have been thrust by the line shifting block. The machine is then stopped by the operator, and the over-fed type removed and the parts re-set.

As the lines are fed, one after another, 15 down the galley, they are supported by a yielding block of a suitable form. This block may be composed of telescopic sections to adapt it to the width of the galley.

Justification.—In the present machine, the 20 lines are justified automatically to a uniform unit length. The justification is invariably additive, that is to say, whenever justification is necessary, the composition is stopped short of the end of the line, and the 25 number of units necessary to fill out the line added thereto. The composition cannot overrun the line, and the latter be then justified by the subtraction, as is the case of the Goodson machine for example. The justification 30 is distributed along the line by increasing in amounts of one or more units the size of the space quads only; the type bodies are not affected by justification. The justification is not fractional; that is to say, 35 no space quad is varied from the normal by fractions of units.

The necessary justification is distributed to the several spaces in amounts as nearly as possible equal. It is obvious, however, that 40 since the justification is never fractional, the distribution can be absolutely equal only when the number of spaces in the line is a factor of the number representing the total of units of justification to be added to that line. This situation does not ordinarily arise; and so, there must usually be a variation in unit body of the quads. In this machine, however, no quad in any line varies in body from any other quad in that line by 45 more than one unit.

The machine has a justification capacity of sixty-four units; that is to say, a line sixty-four units short may be brought to proper length. Occasionally a combination 55 arises within the sixty-four unit capacity of the machine in which justification is not possible. For instance, there must in every machine be a limit to the size of quad which the machine can cast, or in other words, a 60 maximum to the size of mold cavity. In the present machine this maximum is sixteen units. If the line be, say, forty-eight units short and contain but four spaces, the forty-eight units would be distributed evenly 65 among the spaces, so that each space quad

would ultimately have a body of sixteen units, which is the maximum body the machine can cast. If, however, there be less than four spaces among which to distribute the forty-eight or more units, it is obvious 70 that justification will be impossible, since in such case, each space quad would require a body larger than the mold can cast. Just as the limit to the size of mold cavity in certain rare instances precludes justification, 75 so also under certain unusual conditions, as will presently appear, the limit to the number of available setting circuits may make justification impossible, where the number of spaces is too great.

Where the space quads in a justified line are to be of two sizes, it is convenient to set the justification mechanism, so that all space quads of the same size are cast successively. The mechanism is, therefore, first set to cast 80 one size of space quad, and only after all quads of that size are cast, is it set to cast the quads of the other size. Let us assume, for instance, that a line having nine spaces is to be justified by the addition of twenty 85 units. The normal or unjustified space quad of this machine is of four unit body. By adding two units to seven of the nine quads and three units to the other two quads, the twenty additional units or justification 90 required, is supplied. The first seven quads will then be of four plus two, or six, unit body, and the other two, of four plus three, or seven unit, bodies.

In Figs. 95, 96, 97 and 98 is a chart showing every possible distribution of from one to sixty-four units of justification, among from one to twenty spaces. The number of spaces in the line is indicated in the vertical column at the right and left of the chart, 100 and the total amount of units of justification to be distributed is indicated in horizontal lines, at the head of the chart. In the example cited, where twenty units of justification 105 is to be distributed to nine spaces, the sizes of the space quads to be cast would be found upon reference to the fourth column of Fig. 96, at the head of which the number "20" appears, and to the line in that column opposite the space number "9" at the side 110 of the chart (Fig. 96). The figures thus found are in this instance "7—6—7". The last "7" indicates that the quads last cast are 7 unit quads. The middle figure "6" indicates that the quads first cast are 6 unit 115 quads. The first figure "7" indicates that there are seven quads of the 6 unit size to be cast, before the mold is changed to cast the quads of 7 unit size. We have already found that in the instance cited there were 120 to be seven six unit quads and two seven unit quads, or, as expressed by the table, there were to be seven six unit quads and the others, seven unit quads. When all 125 quads are to be of the same size; that is 130

to say, where the amount representing the total number of units of justification required is evenly divisible by the number of spaces in the line, then, of course, there is 5 no change in the mold setting. In such cases the first of the three figures will be a zero, to indicate no change.

All impossible justifications are indicated in the chart by blanks. The example cited, 10 viz., the attempted distribution of forty-eight units to less than four spaces is shown to be impossible upon reference to Fig. 98.

The justification mechanism, according to its setting, controls the size of space quads 15 to be cast, by determining which of the circuits of the mold stop magnets 186 shall be closed by the space holes in the tape. All space holes register with the same pin 46 at the index head, and, therefore, the 20 stop magnets 186, in order to be operated for the casting of space quads, must be placed or set in the circuit of that pin. It is the function of the justification mechanism to select the circuits of the stop magnets to 25 be so utilized, and to connect the selected magnet to the space pin 46, or, if two stop magnets are required, as when the space quads are of two sizes, not only to select the circuits of those two magnets, but separately 30 to connect first the one and then the other to the space pin 46, so that, for a certain number of spaces, the circuit of the one stop magnet may be closed by the space pin, and thereafter the circuit of the other. In the 35 example cited, where the space quads are to be first of six unit body and then of seven unit body, the justification mechanism will select the circuits of the six and seven unit 40 stop magnets 186, whereupon it will maintain a connection between the six unit stop magnet and the space pin, until seven space quads have been cast, as indicated in the chart, after which it will disconnect that magnet from the space pin and connect the 45 seven unit stop magnet thereto for the casting of the remaining two space quads.

The mold stop magnet terminals are arranged at the justifier in two rows, the odd units in one row and the even units in the 50 other, as indicated in the diagram in Fig. 90, so that when two sizes are required, one terminal must be selected from each row. Two terminals, if selected from the same row would differ by at least two units, which 55 is a greater variation than the space quads are ever permitted to have in this machine. Adapted to be moved, one over each row of contacts, are two sliding contact fingers 611 and 612 (see Fig. 7), each of which is connected to one of the contacts 627 and 628 of a switch or circuit changer by means of 60 which circuit changer, first the one and then the other of the selected stop magnets may be connected to the space pin 46 at the index head.

The switch or circuit changer here employed comprises, in addition to the contacts 627 and 628, a movable contact finger 625 (see Fig. 7), at all times connected to the space index pin 46, but adapted to be 70 shifted from one to the other of the contacts 627 and 628. The circuit closer also involves means, presently to be described, by which the shifting contact may have a step by step movement along the contact 627, 75 then off that contact and onto the contact 628, there being one step or movement of the finger each time a space quad is cast, so that after a given number of quads are cast, the shifting contact may disconnect the 80 space pin from one of the contacts 627, and connect it to the contact 628. The circuit closer finally comprises means by which the initial position of the shifting contact 625, relative to the contacts 627 and 628 85 may be set in each instance to determine the number of steps necessary to the shifting contact to carry it off of the contact 627 and and onto the contact 628, or to determine whether or not the contact 625 shall engage 90 the contact 627, at all. In the example already cited, the justifier will be set, so that the six unit mold stop terminal magnet is selected by the sliding finger 612 and connected to the contact 627 of the circuit 95 changer, while the seven unit terminal is selected and connected to the other circuit changer contact 628. The shifting contact 625 of the circuit changer will be set relative to the first contact strip 627 so that seven 100 movements of the finger will carry it to from the six to the seven unit contact.

In the present machine, the circuit changer may be set in any one of nine setting positions, so that a maximum of nine quads 105 of one size may be cast before the circuits are changed. It will be understood, of course, that after the change, any number of quads of the other size may be cast, as the contact finger 625 may remain stationary on 110 the second contact 628, after it has exhausted its nine movements. If, therefore, there be nine or less than nine of each of the two sizes of space quads to be cast, it is immaterial so far as the capacity of the circuit 115 changer alone is concerned, which of the two sizes be cast first, since the circuit changer may be so set that the contact finger will not reach the changing position, until all of the quads of one of the sizes are 120 cast. Where, however, there are to be cast more than nine quads of one size, but less than nine quads of the other size, the quads of the latter size are cast first, whether they be of the larger or of the smaller unit size. 125 If, for instance, forty-one units of justification are to be distributed among fifteen spaces, eleven of the space quads would be of seven unit body, and the other four of six unit body. It is apparent that any effort 130

to cast the seven unit quads first must fail, because the circuit changer, with its maximum of nine movements before a change, would upon its tenth movement cause the 5 machine to begin casting six unit quads. If, however, the four six unit quads be cast first, it is only necessary to set the changer, so that on the fourth movement, it will reach its circuit changing position (see chart, Fig. 10 97). After that the desired eleven seven unit quads may be cast because the contact finger will remain on the second contact, regardless of the number of spaces in the line. Where, then, more than nine quads of a 15 given size are required, the quads of this size must be the quads cast after the quads of the other size, regardless of the fact, that the quads so cast last may be an odd or even unit size. We have heretofore seen, 20 however, (see Figs. 7 and 90) that the even unit mold stop terminals are arranged in one row 602, and through a sliding finger 612, may have a connection to the first of the center strip 627 of the circuit changer, 25 whereas, the odd unit mold stop terminals are similarly connectible to the second contact strip 628 of the circuit changer. It is, therefore, apparent that where more than nine space quads of even unit size are called 30 for, the connections from the rows of mold stop terminals to the contacts 627 and 628 of the circuit changer must be reversed. To effect this reversal, when the occasion demands, the justifier therefore comprises a 35 second circuit changer 666 (see Fig. 7). The operation of this second circuit changer to determine the order in which the sizes are cast is governed by the row #13 punch in the composing machine. This punch, it will 40 be recalled, is operated in the composing machine whenever a corresponding pin appears in the series of pins presented by the roller 121 of the composing machine to the contacts of the justification key-board of 45 that machine. The function of the row #13 hole, in the justification circuits, when presented at the index head of the casting machine is to close a circuit controlling the second circuit changer 666, thereby moving 50 the latter to reverse the connections to the first circuit changer so that the normal order of casting the odd and even unit quads is reversed. When no row #13 hole is 55 presented, the sizes are cast in the order fixed by the normal connections from the rows of mold stop terminals to the circuit changer.

It occasionally happens, when the number of spaces are greater than nineteen, that 60 more than nine quads of each size are required. It is apparent that when such is the case, the capacity of the circuit changer is overreached, no matter which size be first cast. An attempt to distribute thirty units 65 of justification to twenty spaces is an in-

stance of the last character. Here ten quads should be of seven unit body and ten quads of six unit body. Before either the ten seven-unit quads or the ten six-unit quads could be cast, the contact finger of the circuit changer would pass onto the second contact and change the circuit. Such a justification is impossible (see chart Fig. 96) with the machine constructed as shown in the drawings. 70

Mention has been made of two instances of impossible justification, the first, when the relation of the total amount of justification to the number of spaces is such as to call for space quads of a size greater than 80 the mold capacity of sixteen units; and the second, where the number of quads of each size required is greater than the capacity of the justifier circuit changer. These conditions have been mentioned, not because they 85 present any serious problem in the successful operation of the machine, but merely that the operation of this machine in its relation to the composing machine may be fully understood. As a matter of fact, the 90 instances mentioned are rare, as will be seen upon reference to the chart forming Figs. 95-98 of the drawings. Where such instances do occur, however, they are disclosed to the operator at the composing machine, as soon as he depresses the justification key. He has then merely to fill in at 95 the end of the line, or to cancel and re-write the line so that the amount of justification is changed. 100

Referring now to Fig. 70, there is shown mounted on a bracket 600 at the rear of the machine, and in line with the justification setting slide 465, the two rows 601 and 602 of contact members 603 of the mold stop 105 selecting device. Each contact of the row 601 is connected (see Fig. 7) to one of the odd unit stop magnets 186, and each contact of the row 602 to one of the even unit stop magnets 186, so that when the circuit of 110 any one of the contacts 603 is closed, the mold will be set for the casting of a space lug of a size determined by the particular mold stop magnet energized. Where the space quads are to be of two sizes, the circuits of two of the contacts 603 are successively closed as heretofore explained. It 115 will be understood that the circuits are merely set at the contacts 603 at the beginning of every line, and are really closed 120 only when the space hole presents itself at the index head.

The circuits of the contact 603 are set by the justification slide 465 when the latter is actuated by the cam member 400. For 125 this purpose the slide 465 carries a lug or knob 604 (see Figs. 49, 70 and 71) which engages a recess in a bar 605 forming in effect a part of the slide 465. The bar 605 extends under and well to the rear of the 130

contacts 603, and carries near its rear end an upwardly projecting lug or finger 606 (see Fig. 85). Mounted in ways 607 and 608 above the bar 605 are two slides 609 and 610, each of which carries on its forward end one of two contact fingers 611 and 612. The fingers 611 and 612 are adapted upon movement of the slides to travel over the rows of contacts 601 and 602, respectively. 10 The fingers are pivotally attached to the slides, but are pressed firmly down against the contact plate by means of coil springs 613. Coil springs 614 tend to draw the slides to the rear end of the ways, so that 15 each of the fingers may rest upon the last contact of its respective row, as shown in Fig. 70. The springs 614, furthermore, serve as electrical connections from the fingers to the binding posts 615 and 616. To the bottom of each of the slides 609 and 610 (see Fig. 85) is a depending lug 617. These lugs project into the path of the lug 606 on the bar 605, so that when the bar 605 is thrown forward with the justification 20 slide, the slides 609 and 610 are likewise drawn forward against the resistance of the springs 614.

Mounted in the frame beneath the slides 609 and 610 (see Figs. 71 and 85) are stop pins 618. These are arranged in two rows 30 619 and 620, each row being longitudinally disposed beneath one of the slides. The pins 618 are normally held depressed in the position shown in Fig. 85 by means of coil 35 springs 621. The stop pins are, however, adapted to be raised by means of the armature levers 622 of electro magnets 623, so that when elevated their upper ends lie in the path of stops 624, depending from the lugs 617 on the slides 609 and 610. Each magnet 623 is in the circuit of one of the index pins 46 when the switch 429 is thrown to the setting side by the cam member 400. Which of the magnets 623 is energized in 40 any particular instance depends upon the position of the justification punch holes in the tape and these in turn upon the size of the space quads to be cast.

The operation of the parts is so timed 50 that the selected pins 618 are elevated after the slides 609 and 610 have been drawn forward by the justification slide. As soon as the justification slide releases the slides 609 and 610 to the action of their respective 55 springs 614, the latter slides are drawn back, and, if no pin 618 has been elevated, returned to the position shown in Fig. 70. If, however, any pin 618 in either row has been elevated, the corresponding slide will 60 be stopped by that pin upon engagement therewith of its depending stop 624. When thus stopped at an intermediate position, the contact fingers 611 or 612 will rest upon 65 whichever of the contacts 603, may be in the circuits of the mold stop magnets corre-

sponding to the justification punches in the tape.

The circuit changer (see Figs. 70, 71, 85 and 86) consists of the shifting contact 625 and of the slide 626 carrying the two contact strips 627 and 628. The binding post 615 is normally in connection with the contact 627, and the binding post 616 with the contact 628 through lines 665 and 664 (see Figs. 7 and 70). The shifting contact 625 is permanently connected to the space index pin 46. According, therefore, to which of the contacts 627 and 628 is engaged by the shifting contacts 625, the circuit of one or the other of the fingers 611 and 612, and, therefore, of the mold stop magnets connected thereto, will be closed when the space hole presents itself at the index head.

The slide 626 has at its forward end a hook 628' by means of which it engages a cross piece 629, on the extension 605 of the justification slide. The justification slide, therefore, on its forward movement carries with it the slide 626 and the contacts 627 and 628. Mounted on a spindle 630 (see Fig. 71) is a pinion 631, engaging a rack 632 on the slide 626. The spindle 630 is engaged by a coil spring 633 tending to turn the pinion in such direction as to return the rack and slide to the rear, after the forward movement of the same by the justification slide. Attached to the slide 626 at the point 634 thereof (see Figs. 71 and 85) is a link 635 (see Figs. 87, 85, and 2) connected to a bell crank lever 636. The lever 636 is pivoted at 637 to the frame (see Fig. 2). In the path of an arm 638 of the bell crank lever 636 is a row of ten stop pins 639 (see Figs. 2 and 87). The link 635 being attached to the bar 626, the lever 638 is rocked in the direction of the arrow (see Figs. 2 and 87) when the justification slide draws the bar 627 forward. When the bar 626 is released to the action of the clock spring 633 and starts toward its initial position, it carries with it the arm 635 and rocks the lever 638 in the direction reverse to the arrows (Figs. 2 and 87). If on the return movement the arm 638 be not previously intercepted, the spring 633 moves the slide until the arm 638 strikes the last stop 639', which is a stationary elevated stop, and the slide 626 is in what may be considered its initial position. If, however, any of the movable pins 639 be elevated, the slide 626 is stopped as soon as the arm 638 engages the elevated pin. The movable pins 639 are normally depressed out of the path of the arm 638 by the spring 640, but are adapted to be projected upward into the path of the arm 638 by the armature levers of electromagnets 641, diagrammatically shown in Fig. 7. The magnets 641 are each in the circuit of one of the index pins 46, when the switch 429 is thrown to the setting side by the cam 130

member 402 and are operated by the justification holes in the tape.

The function of the stops 639 is to determine the number of quads of one size to be cast before the shifting contact of the circuit changer operates to break the circuit of the mold stop magnet first operated. The manner in which the stop 639 determines the number of slugs of a size to be first cast is as follows: It will be remembered that the shifting contact 625 of the circuit changer, advances a step with the casting of each space quad, so that the connections to the mold stop magnets may be changed after a predetermined number of quads of a size have been cast. This contact is carried by a slide 642 (see Fig. 86) having a movement in ways on the bracket 600. The slide or bar 642, at its forward end has a hook 643 similar to the hook 628 on the slide 626, and like the latter, is engaged by the cross piece 629 on the extension 605 of the justification slide. A pinion 644 on a spindle 645 engages a rack 646 on the bar 642; and, under the tension of a coil spring 647 tends to return the bar to its initial position after it has been drawn forward by the justification slide. The bar 642 is, however, prevented from at once obeying the spring 647, by reason of a pawl or escapement device 648, which engages a serrated or toothed member 649 on the bar (see Fig. 86). The escapement tooth or pawl 648 is pivoted at 650 to an arm 651 so that it may be rocked downward against the action of a spring 652 out of the way of the toothed member 649 to permit the forward movement of the bar 642 by the justification slide. It cannot, however, rock on its pivot 650 to allow free return of the bar 642 by the spring 647.

The arm 651 upon which the tooth 648 is mounted, forms in effect one arm of a bell crank lever, pivoted at 653 to have a movement such that the tooth 648 may be rocked laterally in and out of the serrated edge 649 to allow a step by step escapement of the latter. The other arm 654 of this bell crank lever is adapted to be engaged by the armature lever 655 of a magnet 656. This magnet is in the circuit of the space pin and is, therefore, energized every time a space quad is cast. Wherefore, as the latter are cast the bar 642 and with it the finger 625 move to the rear under the action of the spring 647.

The bar 642 with its contact finger 625 and the bar 626 with its contacts 627 and 628 are drawn forward simultaneously by the justification slide. The bar 642 is held in its forward or first position against the action of the return spring 647 until the escapement mechanism commences to operate. The slide 626 may return entirely or not, according to which, if any, stop pins 639 has been elevated.

If the first stop 639" be the stop operated,

then the slide 626 is held so far forward that the shifting contact 625 rests on the contact 628 even before the escapement mechanism begins to operate. The result is that when the stop 639" is operated, there is no change 70 from one to the other of the contact strips 627 and 628, and, consequently, that particular mold stop magnet which may be connected to the stop 628 is operated for every space in the line. This is properly the case 75 either where there is no justification at all, so that all space quads have the normal four unit size, or where the number of spaces is a factor of the number representing the total justification, so that all the spaces are of 80 the same size. When, therefore, all the space quads are of one size, it is simply necessary to connect the proper mold stop magnet to the second contact strip 628, and then by operating the first of the stops 639 (#0 Fig. 85 93) to hold the slide 626 so far forward that the contact finger when in its first position rests upon the strip 628. The subsequent escapements of the shifting contact in no wise affect the connection to the selected 90 mold stop, since the finger in escaping merely moves along the strip 628 until its escapements are exhausted, or until all the space quads in the line have been cast.

If, however, it be the last pin 639 (# 9, 95 Fig. 93) at the other end of the row of the bank of stops that finally intercepts the return movement of the slide 626, then the slide 626 falls so far back that the finger 625 in its first position rests on the forward 100 end of the contact member 627, so that nine escapements or step by step movements of the finger 625 will be required to carry the shifting contact 625 off of the contact 627 and onto the contact 628. The slide 626 105 may be arrested in its return movement by any of the intermediate stops 639, and according to which particular stop it is that arrests it, the number of movements required to carry the finger 625 off of the contact 627 110 and onto the contact 628 to change the size of quads will be greater or less. The shifting contact or finger 625 is maintained in electrical connection with a binding post 657, during its various movements by a 115 spring connection 658. From the binding post 657, the circuit leads first to the escapement magnet 656 and then through one of the working circuit contacts 433 of the switch 429 to the space pin 46 at the index 120 head.

It has been stated that the contact strip 627 is normally in connection with the sliding contact 612 of the setting device which engages the terminals of the even unit mold 125 stop magnets, whereas, the contact strip 628 has a normal connection to the sliding contact 611 engaging the terminals of the odd unit stop magnates. It has also been pointed out that under certain conditions these 130

connections must be reversed. One purpose of effecting such reversal is to cast the odd unit quads first, where the even unit quads are greater in number than the escapements 5 allowed the shifting contact. Another purpose of such a reversal is to connect a given even unit stop to the last contact strip 628 in an instance where the shifting contact 625 engages the strip 628 only, so that all 10 the quads in the line may be of the one selected even unit size. In the last instance, the connection to the first strip 627 is not utilized, and it is consequently immaterial that the sliding contact connected therewith 15 may be resting upon the terminal of a stop which is not desired.

The circuit changer for reversing the stop connections in the justifier is shown diagrammatically in Fig. 7, and is shown in 20 structural detail in Figs. 70, 71, 85, 88 and 89. Located near the slide 626 are four stationary contact plates 660, 661, 662 and 663. The plates 661 and 662 are electrically connected to the sliding contact 612, as indicated by the line 664 (see Fig. 7), and the plates 660 and 663 to the contact 611. Between the contacts 660, 661, 662 and 663 and the contacts 627 and 628, there is mounted a slide 666 (see Figs. 85 and 89) carrying 25 contact fingers 667, 668, 669 and 670. A contact finger 668 is in engagement with the contact strip 627 during all movements of the slide 666, and similarly, during all movements of the slide, the contact finger 30 669 is in engagement with the contact strip 628. According to the position of the slide 666, the finger 667 will be in engagement with one or the other of the contacts 660 and 661, and the finger 670 in connection with 35 one or the other of the contacts 662 and 663. The contacts 667 and 668 are in effect a continuation of each other from the contact 627 to either the plate 660 or 661, and, similarly, the contact fingers 669 and 670, a 40 connection from the contact 628 to either the plate 662 or 663.

The slide 666 carries a lug 671 (see Figs. 71, and 85), which projects into the path of a lug 672 carried by the slide 626, so that 45 when the slide 626 is drawn forward by the justification slide, it engages, toward the end of its movement, the slide 666, and gives the latter a slight forward movement. The forward movement of the slide 666 brings 50 the finger 667 onto the contact 660 and the finger 670 onto the contact 662, thus temporarily connecting the slide 611 to the contact 627 and the slide 612 to the contact 628. As soon as the justification slide releases the 55 slide 626, the movement of the latter withdraws the lug 672 from the lug 671.

To the lug 671 and to the frame of the machine is attached a spring 673, which, when permitted, draws the slide 666 to such 60 a position that the finger 667 rests upon the

plate 661, and the finger 670 upon the plate 663. It is to this position that the slide 666 will move as soon as released by the slide 626, unless otherwise restrained. In the under face of the slide 666 (see Fig. 89) is a pocket 674. Mounted in the frame below the slide 666 is a pin 675, normally held depressed by a spring 676. The pin 675 is so positioned that when the slide 666 is drawn forward by the slide 626, the pin registers with the pocket 674, and if lifted, will enter the pocket. The armature lever 677 of an electromagnet 678, when the latter is energized, forces the pin 675 into the pocket 674. The pin 675 when in the pocket holds the 6 slide in its forward position against the action of the spring 673. It is apparent that if the pin 675 be not lifted, the slide 666 will assume such a position that the contact strip 627 is connected to the sliding 7 contact 612 and the contact 628 to the sliding contact 611. If on the other hand, the pin 675 is lifted, these connections are 8 just reversed. The magnet 678 is the row #13 magnet, so-called which is operated 9 from the row #13 pin in the index head for the purposes heretofore discussed.

Justification record, circuit diagram and chart.—A single perforation 680 in the tape (see Fig. 8) is required for the operation 9 of each pair of setting pins 618. That two punch holes are not required to operate two pins is due to the fact that the stop magnets 623 are coupled in pairs, in series, as shown in diagram in Fig. 90. Each magnet is in 1 circuits with the magnet representing the next ascending or descending unit value of space quad. In other words the magnets representing the difference of two units are in parallel circuits, but are each in series with 1 the magnet representing the intermediate number of units. There being two magnets in each circuit, the number of circuits and index pins required is considerably less than would be needed were the magnets all independently operable. The fact that, when so connected, they are not independently operable presents no difficulty to the successful operation of the justifier.

It is at once apparent from the connections shown in Fig. 90, that even in those instances where all the quads of a line are to be of one size, so that but one mold stop is wanted, nevertheless, two mold stop setting pins 618 are operated. Where all quads 1 are to be a size, however, but one of the mold stops so set is in fact used. In such instances, the stop to be used is connected to the circuit changer contact 628, and the other stop to the contact 627, whereupon the 1 circuit changer shifting contact 625 is at once set upon the contact 628, so that the stop connected to the contact 627 is never operated.

Referring to Fig. 90, the circuits of the 1

magnets 623 are indicated as "R-1" to "R-12", inclusive, and the magnets there-in are marked according to the unit value of the mold stop controlled by each. The 5 circuit of row #13 magnet, 678, is marked "R-13". In the first and fourth columns of a table shown in Fig. 91, there are enumerated all the combinations of two stops available, where the space quads are to be of 0 two sizes. The stops appear in each combination in the order in which the space quads are to be cast, when that combination is employed. For instance, the first combination 5 of the first column, "4 & 5", is the combination used where four unit quads are first to be cast, and thereafter, five unit quads. On the other hand the combination "5 & 4" at the head of the fourth column is the combination to be used where five unit and there- 10 after, four unit quads are desired. In the columns marked "Use" are enumerated the circuits, "R-1" to "R-12" of Fig. 90, the numeral for each circuit being set opposite the particular combination of stops in that 15 circuit. At intervals in the column marked "Shift", is the symbol "R-13".

Wherever the symbol "R-13" appears in the table, the combination of stops denoted opposite the same, can be obtained 20 only by the use of the row #13 magnet, 678, to reverse the normal order of operation of the selected mold stop magnets. It will be recalled that when the row #13 magnet, 678, is not operated, the circuit changer 666 normally positions itself so that the sliding contact 612 (see Fig. 7), controlling the stop magnet terminals of row of contacts 602, is connected to the contact strip 627 and the sliding contact 611, controlling the terminals 25 of row of contacts 601, to the strip 628.

To exemplify the signification of the "R-13" symbol, let us consider the combinations "4 & 5" and "5 & 4". On reference to Fig. 90, it will be seen, that the 30 four unit stop is in the row 602, and the five unit stop in the row 601. Since, now, of the two stops of any combination, that stop which appears in row 602 is the one first used when the connections are normal, it 35 follows that the combination "4 & 5" may be had without the use of the row #13 magnet. The symbol "R-13" does not appear opposite the combination "4 & 5" in the table of Fig. 91. In the combination "5 & 4", on the other hand, the first stop wanted 40 (stop 5) is in the row 601, and the row #13 magnet must, therefore, be operated. Consequently, the symbol "R-13" appears opposite "5 & 4". This symbol, it will be 45 noted, appears opposite every combination in which the stops 5, 7, 9, 11, 13 or 15, are the first to be used.

Just as the table of Fig. 91 discloses in each instance, the circuits employed where 50 space quads of two certain sizes are to be

cast, so a second table (Fig. 93) discloses the several circuits employed, where all quads in a line are of the one size. The size of quads are indicated in the first column of Fig. 93, and the circuits in the second column. For all four unit quads, there is no circuit, the "Dead" stop being used. The four unit quad, it will be remembered, is the smallest slug cast by the machine, and is, moreover, the normal space quad, that is to 55 say, the quad which is cast when the line is not justified, or requires no justification. In addition to the four unit stop pin of row 602, which is used when combinations of four and fives are to be cast, there is a stationary 60 four unit stop at end of the row 601. The latter, as stated, is the four unit stop employed where all the quads in the line are of four unit body.

Where all quads are to be of the same 65 size, the shifting contact 625 of the circuit changer must be set at once upon the contact strip 628, so that there may be no change of circuits to the setting magnets 186. In order that the shifting contact 625 may be at once 70 set upon the contact strip 628, it will be recalled, that the slide 626, carrying the contacts 627 and 628, must be held by the first of the justifier lever stops 639". The stops 639 are shown in Fig. 92, the first stop 639" being marked "I-8", and the other stops being marked from "I-1" to "I-9" and "Dead". In the fourth column in Fig. 93, after each of the markings "All 4 u" to "All 16 u" inclusive, there therefore appears the same symbol "I-8", meaning that whenever all quads are to be of a size, the circuit "I-8" of the end stop 639" is used.

In the third column of Fig. 93, the symbol "R-13" appears at intervals, indicating 105 the use of the row #13 magnet circuit to reverse the normal connections of the sliding contacts 611 and 612 to the contacts 627 and 628. Whereas, however, in the table of Fig. 91, the "R-13" appears opposite 110 all combinations in which the odd unit comes first, in Fig. 93, on the contrary, the "R-13" is set opposite those combinations, in which even unit appears. This difference is due to the fact that the purpose of the 115 reversals indicated in Fig. 91, is to invert the normal order of operation of the stops, so that the odd unit stop is first, and the even unit stop last, operated, whereas, on the other hand, the purpose of the reversals 120 indicated in Fig. 93, is to eliminate the odd unit stop and to make the even unit stop the first, and only stop operated. In Fig. 94 is yet another table. This table indicates the 125 justifier lever stop circuits (see Fig. 93) used to time the shift from one to the other size of two desired sizes of quads. If, for example, there are to be four six-unit quads and then a number of seven-unit quads, the shift must take place after the fourth quad is 130

cast. Upon reference to table 94, it will be seen that, to effect the shift at that time, the justifier lever circuit "1-4" is employed. Each of the circuits "1-1" to "1-9" is controlled by a different index pin 46.

It appears then that a justification record may consist of one, two, or three perforations in the record tape, to wit: one perforation 480 (Fig. 8) for the selected justifier 10 setting pins 618, except where the stationary end stops 4 or 16 are used; one perforation 481, for the circuit of the selected justifier lever stop 639, except when the "Dead" stop #9 is used; and one perforation for the 15 "R-13" magnet, whenever the latter is needed. This justification record immediately follows the trip hole, and presents itself at the index pins 46, while the switch 429 is resting upon the setting terminals 20 432 of the switchboard 431. When multiple justification is being effected, the justification record follows the second trip hole. It will be recalled, that the first trip hole in the latter instance is followed by the 25 perforation, representing the end-of-line slide lock magnet. It would be futile to have the justification record follow the first of two trip holes, for the reason, that the movement of the justification slide, in response to the second trip hole, would undo any previous setting.

In Figs. 99, 100, 101 and 102 is a chart showing the circuits required for any justification of from one to sixty-four units, with 35 from one to twenty spaces in the lines. The justification numbers are here again arranged horizontally at the top of the chart, and the space numbers vertically at the sides of the chart. The figures or symbols within 40 the columns are from one to three in number, according to the number of justification circuits required in each instance. In the first of the three spaces assigned to each justification is a number representing one 45 of the justifier lever stop circuits "I-1" to "I-9" (see Fig. 93), the circuit "I-1" being represented by the numeral "1" and the circuit "I-2" by the numeral "2", etc. Where no numeral appears in the first 50 of the three spaces, it signifies that the "Dead" stop (see Fig. 93) is the stop employed. The second of the three spaces is assigned to the numeral "13" representing the circuit of the row #13 magnet. When 55 no numeral appears in the second space, the row #13 magnet is not operated. The third or last space assigned to each justification is reserved for the numerals representing the circuits "R-1" to "R-12" (see Fig. 60 90) of the setting stop pin magnets 623, the circuit "R-1" being represented by the numeral "1"; the circuit "R-2" by the numeral "2", etc. When no numeral appears in the third space, it signifies that one

of the stationary stops 4 or 16 (see Fig. 90) is used.

To demonstrate the utility of the chart; suppose, for example, we wish to know what circuits are to be used when forty units of justification are to be distributed to four spaces. In this case, ten units must be added to the normal four unit body of each quad, making each space quad of fourteen unit body. This distribution is verified upon reference to Fig. 97, where the justification is found to be represented by the numerals 0-14-14, indicating all 14's with no change. Referring now to Fig. 90, we find that the 14 unit stop is in the circuits "R-10" and "R-11" with the 13 and 15 unit stops, respectively. Since in this instance, all quads are to be of 14 unit size, it is immaterial whether the R-10 or R-11 circuit be selected, because in neither event will the 13 or the 15 unit stop be used. We may, 85 therefore, select the circuit "R-10." To cut the 13 unit stop out of operation, it is necessary, however, that the circuit changer member 625 be set in the first instance on the contact 628. This, as has been pointed out, 90 is effected by the use of the justifier lever circuit "I-8." Since, however, the row 602 of even unit stops, is normally connected to the circuit changer contact stop 627, it is apparent that if the 14 unit stop is to be 95 used from the contact 628, then the row 13 magnet must be operated. Thus, we find that the circuits required in this example are "R-10" and "R-13," Fig. 90, and "I-8," Fig. 93. Referring now to the chart 10 (Fig. 101) under the justification numeral 40 and opposite this space number 4, we find the Figs. 8-13-10. These, it will be seen, correspond precisely with the circuits just found.

The circuits are furthermore indicated by the numerals on the chart of Figs. 99-102, precisely as they are indicated on the cylinder 121, of the composing machine by the pins 122. It will be recalled that the pins on the cylinder are arranged in groups of from one to three each. The groups of pins on the cylinder correspond in number and disposition to the groups of numerals on the chart of Figs. 99-102, and each is in that 115 circuit of the composing machine, which corresponds to the circuit of the casting machine represented by the corresponding numeral on the chart.

Line cancel.—It sometimes happens that 120 the operator at the composing machine, for some reason or other, finds it is necessary to cancel a line, which he has partly or wholly recorded on the tape. It has been explained in connection with the composing machine, 125 that to cancel a line, the operator depresses the line-cancel key, and then the trip key, thus putting a line-cancel and a trip hole in

the tape. The line cancel hole on reaching the index head of the casting machine causes the circuit of the pump magnet 305 to be broken and the matrix block to be locked against movement, during the passage through the machine, of that section of the tape carrying the record of the line to be canceled. The line-cancel circuit in the casting machine is in the setting-circuit, so that to operate the line-cancel, the switch 429, must first be thrown to the setting contacts 432 of the switch-board 431. Hence, it is, that the operator at the composing machine punches a trip hole in the tape, after 15 he has punched the line-cancel hole. Since the tape is fed into the casting machine backward, the trip hole throws the switch 429, before the line-cancel hole registers at the index head.

20 The line-cancel circuit of the casting machine is shown diagrammatically in Fig. 103. It may be traced as follows: into the machine at the positive terminal of the switch 690', through the switch and by line 25 691 to a commutator brush 692 on the cam shaft of the machine, thence by line 693 to the bank of index pins 46, through the row #14 index pin, and by line 694 to a switch 695, which is closed upon movement of the 30 justifier setting slide 465, thence by line 696 to the switch 429, through contact 14 of the setting contacts 432 of the switch-board 431, thence by line 697 through the line-cancel magnet 698, through the setting-35 circuit outlet 699, to point 699', and by line 702 to the negative terminal 741, at the switch 690. The return line 752 of the circuit of the pump magnet is shown attached to the working outlet 705 of the magnet 40 tray, and thence continues by way of line 706' through the contacts 700 of the line-cancel switch 701, thence to 699' and through the line 702 to the switch outlet. The line-cancel magnet 698 operates the 45 line-cancel switch 701, so that when the line cancel-circuit is closed, the switch 701 is thrown to break the pump magnet circuit.

The matrix block is locked against movement by means, presently to be described, 50 such means being in turn operated by an electromagnet 706, termed the matrix stop action magnet, whenever the latter is energized. The circuit of the matrix stop action magnet 706, may be traced 55 from the commutator brush 692 through the line 707 to the magnet, from the magnet by line 708 to the contacts 709 of the line-cancel switch, and thence when the switch is thrown, through the line 702 to the 60 negative terminal of the switch 690. When the line cancel magnet throws the switch 701, it, therefore, not only breaks the circuit of the pump magnet, but also closes the circuit of the matrix stop action magnet.

65 Referring now to Figs. 5, 103 and 104,

the armature lever 710 of the matrix stop action magnet, is shown as having at one end a hook 711, by means of which it may engage the end of the lever 94. The lever 94, when so engaged, is held against 70 the spring 92' and is prevented from following the cam 92 on the cam shaft. It will be recalled, upon reference to Fig. 18, Sheet 13, that it is the lever 94 which draws the matrix block to an initial position after 75 each setting. When, therefore, the lever 94 is engaged by the armature lever 710, the matrix block is held in its initial position. A spring 712 holds the lever 710 away from the lever 94, except when the matrix stop 80 action magnet is energized. During the entire period that a canceled line is passing through the machine, the circuit of the matrix stop action magnet is closed through the contacts 709 of the line-cancel switch, 85 and, therefore, during that period, the matrix block is held by the lever 94 against movement.

It is desirable not only to restrain the 90 matrix block from moving, during the cancellation of a line, but also, to restrain it from moving whenever the cam member 400 is operated. The matrix stop action magnet 706 is, for this last purpose, 95 provided with a second return line 713 (see Fig. 103), adapted to be closed by a switch 714. The switch 714 (see Fig. 67, Sheet 33) is operated to close the return line 713, whenever the cam member 400 permits the switch 429 to be lifted to the setting circuits. 100 As soon as the switch 429 is returned, however, the line 713 is again opened, to release the matrix block.

The line-cancel switch also operates to break 105 the circuit 520 (see Fig. 103) of the automatic cut-out magnet 518 (see Fig. 78). Otherwise, at the end of a canceled line, the automatic cut-out would act as in case of an under-fed line to stop the machine. Such 110 stoppage of the machine is prevented by cutting the cut-out magnet until the machine is again ready to resume the casting of type.

The line cancel mechanism switch 701 is 115 normally held on the contacts 700, as shown in Fig. 105, by means of a retaining pawl 731. Connected at one end of the lever arm 440, is a rod 715 (see Fig. 67), the other end of which connects to an arm 716, pivoted to the frame at 717. To the arm 716 is attached a rod 718 (see Figs. 67 and 105), in turn attached to a slide 719. Carried by and pivoted to the slide 719 is a pawl or latch 720 adapted to engage in a series of two teeth 721 and 722, on the arm 724 of the line-cancel switch. A spring 720', normally forces the latch 720 toward the toothed face of the switch arm. A spring 725 tends to throw the switch 724 to the contacts 709, but 120 is normally prevented from so doing by rea- 125

son of the pawls 731 and 720. The switch is adapted to be released from the pawls 731 and 720 by a bell crank lever 726 (see Fig. 106), one arm 727 of which (see Fig. 105) 5 lies between the pawls and the arm 724 of the switch lever, so that when the lever 726 is rocked, the pawls are forced away from the teeth on the switch arm. The other arm of the bell crank lever 726 carries the armature 728 of the line-cancel magnet. When, therefore, the line-cancel magnet is energized, the lever 726 is rocked to release the switch to the action of the coil spring 725, and the switch is thrown to the position 10 shown in Fig. 107.

The line-cancel magnet does not, however, remain energized, for its circuit is but momentarily established at the tape. As soon as the line-cancel magnet is deenergized, a 20 spring 729 (see Fig. 106) at once returns the armature lever 726 to its normal position, permitting the spring 720' to throw the pawl or latch 720 again into engagement with the teeth on the switch arm.

25 It will be remembered that the operation of the line-cancel magnet takes place after the switch 429 has been tripped, and while it rests upon the setting circuits. The return of the switch 429 to the working circuit 30 contacts must move the rod 715, to which the arm 724 of the line-cancel switch has again been attached by the latch 720. The line-cancel switch 701, will, therefore, upon the return of the switch 429, be moved toward the position shown in Fig. 67. It 35 must, however, remain on the contacts 709, and off the contacts 700, until the record of the line to be canceled has passed the index head, wherefore, the first return of the 40 switch 429 to the working circuit contacts must not move the line-cancel switch sufficiently to change the contacts of the latter. In order that the movement of the switch 429 may take place without immediately 45 changing the contacts of the line-cancel switch, the following device is employed.

When the line-cancel switch is released to the action of the spring 725, it swings into a position on the contacts 709, determined by 50 a stop 730. The arm 724 of the switch thereby assumes a position with respect to the pawl 720, such that, when the pawl is released, it engages the first tooth 721 on the switch arm (see Fig. 105). Thus engaged 55 by the pawl, the line-cancel switch is rocked toward the contacts 700, when the switch 429 returns to the working circuit contacts. The movement of the rod 715 is only sufficient, however, to rock the arm 724 a distance 60 equal to one of the teeth thereon, so that when the switch 429 is again on the working circuit contacts 433, the switch 701 is in the position shown in Fig. 108. Upon reference to this last figure, it will be noted, that 65 the line-cancel switch has not been moved

sufficiently to change the contacts shown in Fig. 107. In this position, the line cancel switch rests, during the passage of the canceled record through the index head.

After the canceled record has passed, the 70 trip must be again operated to set the justifier for the line to follow. When the trip is so operated, the pawl 720 is forced over the long face of the second tooth 722 on the line-cancel switch and by virtue of the 75 spring 720' drops behind that tooth. During this movement of the pawl 720, the line-cancel switch is held against the action of its spring 725 by the pawl 731. The pawl 731 is not attached to the slide 719, and does 80 not move therewith. On the contrary, it is carried on a pivot post 732, which passes through a slot 733 in the slide. The slot permits movement of the slide without interference from the post 732. A spring similar to the spring 720' holds the pawl 731 in locking engagement with the tooth 722, to hold the switch, while the pawl 720 passes over the long face of that tooth, and drops behind the same. When now, the switch 429 90 is returned for the second time to the working circuit contacts 433, it again moves the line-cancel switch the distance of one tooth. This second movement of the line-cancel switch carries it from the position shown in 95 Fig. 108, to the position shown in Fig. 67, thereby breaking the contacts 709 of the matrix stop action magnet, and closing the contacts 700 of the pump magnet. The machine is then again ready for casting. This 100 second movement of the switch causes the pawl 731 to pass over and engage the last tooth 723 on the switch arm 724. Subsequent trips have no other effect than to move the line-cancel switch slightly on the 105 contacts 700, without breaking the latter. To the end that such subsequent trips of the pawl 720 may not move the switch arm, the last tooth 723 on such arm (see Figs. 107 and 108) is cut away at the top, so that it is 110 not engaged by the uppermost pawl 720 although engaged by the lower and stationary pawl 731.

Machine circuits.—We may now conveniently trace the machine circuits, shown diagrammatically in Fig. 7. Some of these circuits have necessarily been described more or less in detail in connection with certain of the elements of the machine. Where a detailed description of the circuits is not essential to an understanding of the operation of the parts, the circuits have heretofore, however, been mentioned only in a general way.

It was early stated, that the current for 125 operating the machine may be taken from any suitable supply, such for instance, as the lighting wires of the building, and by means of a rheostat be adapted to the requirements of the machine. To disconnect 130

the machine from the supply, when not in operation, there is the switch 690 (see Fig. 7) on the switchboard 742, heretofore mentioned in connection with the line-cancel. 5 The + and — lines from the switch 690 to the supply lines are marked 740 and 741, respectively. The rheostat is not indicated in Fig. 7. The current entering the machine from the switch 690 is variously subdivided.

10 Part of it passes by way of the line 743 through the armature of the cam shaft motor 2, and thence, by way of line 744 to the negative terminal of the switchboard. Another part of the current passes by way 15 of the line 745 through the field 746 of the motor, and thence, by way of the line 744 to the negative terminal at the switchboard.

Working circuits.—Assuming now the switch 429 (see Fig. 67) to be on the working contacts of the switchboard 431, the circuits through the index head are as follows: From the switch 690, a third division of the circuit passes by way of the line 691 to a commutator 692 on the cam shaft of 25 the machine, and thence, whenever the commutator circuit contacts are closed, by way of the line 693 to the index head. The pins 46 at the index head are shown diagrammatically in two rows, one of which is marked 30 "Row" and the other "IND." According to the number and disposition of the punch holes in the tape, the circuit is extended from the index head by way of one or by two of the pins 46 to correspondingly marked 35 contacts on the switch 429. The circuits are not, in fact, made and broken at the index head by the movement of the pins 46 into and out of the wells 48, but are made and broken at the commutator 692, by the revolution 40 of the cam shaft immediately after the pins 46 have entered or have been withdrawn from the wells of the index head. The purpose is to prevent destructive sparking and that would otherwise take place at 45 the pins, when the circuits were broken.

When the switch 429 is on the working circuit contacts 433, the circuits of the "Row" index pins are continued by lines 747 to a terminal board 770, and thence by 50 way of lines 748 to the several matrix stop "Row" magnets 749. These are the magnets which control the pins 89, to determine the movement of the matrix carriage, so that the proper row of the matrix block may 55 be positioned over the mold. From the "Row" magnets 749, the several circuits return to the terminal board 770, and thence through a lay-out switch 776, presently to be described, and by lines 750 to the mold 60 stop magnets 186. The several working circuits from the mold stop magnets 186 unite in the line 751, and are thereby continued to and through the pump magnet 305, and therefrom by line 752 to the working 65 circuit outlet 705, when the circuits are con-

tinued by the line 706 to line cancel contacts 700 and through line 702 to the negative terminal of the switchboard.

Every matrix stop "Row" magnet 749, it is seen, is connected to a separate working 70 terminal 433, on the switchboard 431. Every "Row" magnet is not, however, connected, on the other hand, to a separate mold stop magnet 186. The matrices on the matrix plate are arranged in rows, according to 75 their unit value. All the matrices in any one row have the same unit value. The mold setting is, therefore, the same for each individual matrix of any row. Since this is so, then the one and the same circuit may conveniently be used to set not only any particular matrix row stop, but also to set the mold stop which accords to the unit value of the matrices in that row. Hence it is that of the working circuits from the row pins 80 46, each includes a certain one of the mold stop magnets. It generally happens, however, that there are on the matrix plate more matrices of the same unit value than can be gathered into a single row. In such cases, 85 there may be two or more rows of matrices of the same unit value. For each of such rows, however, the same mold stop must be operated, and, therefore, a single mold stop magnet 186 may be in several of the circuits 90 from the matrix row stop magnets. Since the pump magnet is operated every time a type of any size is to be cast, it is conveniently operated by being placed in the common return from all the mold stop magnets. 95

From the working circuit contacts of the switchboard 431, the circuits of the "IND" pins 46 are continued by the lines 754 directly to the several "individual" matrix stop magnets 753. These magnets, it will 100 be recalled, determine the movement of the matrix block in a second direction to select any individual matrix of the row selected by the row magnet. From the "individual" magnets, the circuits are continued by a 105 common return 755 through the pump magnet 305, and by the return line 752, line cancel contacts 700, and line 702, to the switchboard 742.

The circuit of the space index pin 46, for 110 the casting of space quads has been traced more or less in detail in connection with the description of the justifier. It leads (see Figs. 7 and 112) from the "IND" index pin 46, marked "SP" to the correspondingly 115 marked contact of the switch 429 and switchboard 431, and thence, by way of line 756 to the magnet 656, which, it will be recalled, operates the escapement of the circuit changer contact 625. From the magnet 656, this 120 circuit is continued by the line 757 and 757' to the sliding contact 625, and through one or the other of the contacts 627 and 628 to one or the other of the sliding contacts 611 and 612. From one or the other of the 125 130

contacts 611 or 612, the space pin circuit is continued through the selected contact 603 and through the selected line 758 to one of the mold stop magnets 186, and thence by 5 way of the common return 751 to the pump magnet 305, and by the return 752, line cancel contacts 700 and line 702 to the negative terminal of the switchboard 742. If now, during the casting of a line, and while the 10 switch is on the working circuits of the terminal of the switchboard 431, a squirt occurs at the mold, the circuit of the automatic cut-out magnet 518 is established, and the machine is stopped. This circuit, as 15 heretofore traced in connection with the description of the cut-out leads from the switchboard 742, by way of line 269 to the squirt preventer circuit closer 267, thence by way of line 270 through the cut-out magnet 518 and by way of line 520 through the line-cancel contact 700, and by way of the common return line 702 to the negative terminal switchboard 742.

In event of an over-feed at any time during 25 the setting of a line, the circuit of the automatic cut-out magnet 518, may also be established through the line 691, commutator 692, lines 693 and 522, circuit changer 539 to the cut-out magnet 518, and thence, by 30 line 520 to the circuit changer contact 700, and by line 702 to the negative terminal of the switchboard 742.

For the operation of the justifier, of the end-of-line mechanisms, or of the line-cancel mechanism, the circuit of the trip magnet 423 must be established to throw the switch 429 to the setting circuit 432. The circuit of the trip magnet may be traced from the switchboard 742, through the line 40 691, commutator 692, line 693, to the index head, thence through the "Row" index pin 46, marked "ST", and by line 759, to a marked contact "ST", on the switch 429. Since the trip is to throw the switch from 45 the working to the setting circuits, the circuit of the trip magnet must necessarily be one of the "working" circuits. It is, therefore, continued from a "working" terminal "ST", on the switchboard 431, by a line 50 759, through the trip magnet 423, thence by way of line 760 to the setting circuit outlet 699, and by the common return 702 to the negative terminal of the switchboard 742.

Assuming that the trip magnet has 55 thrown the switch 429 to the "setting" contacts 432 of the switchboard 431, the circuits may now be traced as follows:

Setting circuits.—The "setting" circuits from the "Row" index pins 46, are used to operate the magnets 623 of the justifier setting pins 618. These circuits may be traced from the switchboard 431 by lines 761 to the several magnets 623. From the magnets 623, these circuits have a common return 65 762, leading direct to the setting cir-

cuit outlet 699, and continuing by way of the common return 702 to the negative terminal of the switchboard 742. It will be recalled, that each of these circuits includes two of the magnets 623 (see Fig. 90). 70

Not all of the pins marked "Row" are required to operate the magnets 623. One of these pins, namely, "Row" pin #14 is reserved for the line-cancel circuit; another of the pins, namely, "Row" pin #13 is reserved for the justifier shift magnet; and yet another, the "Row" pin "ST", is reserved for the end-of-line slide lock magnet 491. Those "Row" pins 46, numbered 1 to 12 inclusive, control the various circuits 80 used "R-1" to "R-12" of the magnets 623. 75

The circuit of the "Row" pin 13 may be traced from the Row #13 terminal on the setting side 432 of the switchboard 431, by 85 way of the line 763 to the Row 13 magnet 678, and thence by way of the common returns 762 and 702 to the negative terminal of the switchboard.

The "IND" index pins 46, numbered from 90 "1" to "9" are used on the setting side for controlling the justifier lever stop magnets 641. The circuits of these magnets may be traced from the "IND" contacts 1-9 on the setting side of the switchboard 431, by lines 95 764, direct to the magnets 641, and thence, by way of the common returns 762 and 702 to the negative terminal of the switchboard 742.

In event of multiple justification, then at 100 the end of each line, the circuit of the end-of-line lock magnet 491 is established by the "Row ST" index pin 46. This circuit may be traced from the "setting" contact "ST" on the switchboard 431, by way of 105 line 765 to the terminal board 770, thence by line 766, to the magnet 491, returning by way of the line 767 to the terminal board 770, and by lines 767, 762 and 702, to the negative terminal of the switchboard 742. 110

The movement of the end-of-line slide with the justification slide, after the operation of the magnet 491, closes the circuit of the magnet 462, which operates the fulcrum shift distance piece. The circuit of the 115 magnet 462 is traced from the switchboard 742 through the lines 691 and 505 to the circuit closer 503, on the end-of-line slide (see Figs. 70 and 71), thence through the magnet 462, a switch 768 and line 769, to the common return 702. Where multiple justification is not to be effected, the fulcrum shift distance piece may be locked, and the switch 768 opened, so that the movement of the end-of-line slide does not operate the 120 magnet 462. 125

The circuits of the line-cancel magnet, and of the matrix stop action magnet have been fully traced in connection with Fig. 103, and will not be further mentioned here. 130

Lay-out, or matrix changing switch.—The matrix plate 82 carries a complete font or lay-out of matrices. The machine must, however, be capable of producing type of various styles of fonts, according to the requirements of the work in hand. A number of matrix plates, fonts, or lay-outs are, therefore, necessary for use in connection with the machine. The adaptation of the machine to different lay-outs has heretofore presented serious problems. It is, of course, a simple matter to substitute one matrix plate for another in the carriage. In monotype machines, however, there exists a certain definite relation between the matrix stops and the mold stops, whereby the mold is in each instance set to cast type bodies of a size adapted to the particular matrix presented thereto by the matrix stops. To avoid multiplication and complexity of parts, the mold and matrix stops thus related, are in machines of this class, operated in each instance through a single connection from one of the index pins. In the present machine, such single connections are the electric circuits from the index head through the matrix row stop magnets, and thence through the mold stop magnets. These connections must be changed every time one matrix plate is substituted for another in this carriage, and it is in this change of connections that the difficulty is found.

The type of one lay-out may differ in "set" from the type of another. Furthermore, the number of type of a given unit of set may differ with the different lay-outs. A given row in the matrix plates or lay-outs may in some instance contain the matrices of type of a certain unit of set, and in another instance, contain matrices of type of another unit. The relation of the matrix row stops to the mold stops is, therefore, almost invariably disturbed by a change of lay-outs. For this reason, it is apparent, that the connections from the row stops to the mold stops must not be fixed or permanent; otherwise, without regard to the change in unit of set of the matrices controlled by any particular row stop, the mold would for that row continue always to cast the one size type bodies.

Since every change of lay-outs involves a change in the mold stop connections, it is not difficult to appreciate the trouble involved by such a change. To change the lay-outs in the Goodson machine, for example, it was necessary, separately, to disconnect and interchange the wires between the row stop and the mold magnets. In other machines, the difficulty has not been less. We have in the present invention, however, a means by which the changing of the connections to the mold stops is as simple as the substitution of one matrix plate for another in the carriage.

Mounted in a terminal board 770, at the side of the machine (see Figs. 7, 110 and 111) are four series or rows of pins 771, two rows of which are marked "inlet" and two rows "outlet." Each of the pins marked "inlet" 70 is attached to the inlet wire or one of the matrix row stop magnets, and each of the pins marked "outlet" is attached to the outlet wire of one of these magnets. The pins are numbered in correspondence to the 75 row stop magnets to which they are respectively attached. In a second terminal board 772, below the pins 771 are sets of mercury wells 772' into each of which wells dips one of the pins 771. The series of wells are 80 marked "inlet" and "outlet" respectively, to correspond to the pins 771. The wells marked "inlet" are each connected to the correspondingly numbered working circuit contact 433 on the switchboard 431. In the 85 board 772 are three more rows of mercury wells 773, 774 and 775, respectively. Each of the wells 773 and 774 is connected to one of the wells marked "outlet," and is numbered the same as the "outlet" well to which 90 it is connected. There is a well 775 for each mold stop magnet 186, and each well 775 is permanently connected to one of the mold stop magnets, except the 16 unit which is permanently connected to the inlet of the 95 pump magnet. The wells 775 are numbered according to the unit value of the mold stop to which they are respectively connected. It is, therefore, apparent that any matrix 100 row stop magnet may be connected to any particular mold stop magnet by simply connecting the "outlet" well of the row stop-magnet to the well 775 of the mold stop magnet. Where several of the rows of matrices on the matrix plate call for the same mold 105 stop magnet, then the matrix row stop-magnets representing the same, are all connected to one desired mold stop terminal 775. For every matrix plate or lay-out, however, the connections between the matrix row stop-magnet "outlet" wells, and the wells 775, 110 are different. These connections cannot, therefore, be permanent in the board 772; they are established in each instance by a distinct and separate switch representing the 115 particular matrix block or lay-out employed. One of such switches is shown in position in Figs. 110 and 111. It consists of a block 776, carrying three lines of pins 777, 778 and 779, adapted to be inserted in the wells 120 773, 774 and 775, respectively. Each of the pins 777, 778 and 779 is numbered the same as the well into which it dips, when the switch is in position. On the block 776 are wires permanently connecting each of the 125 pins 779 to one or more of the pins 777 and 778. These connections differ for each lay-out. Since each of the pins 778 and 779 represents a row of matrices on the matrix plate, connections from these pins to the 130

mold stop pins 779, will in each instance depend upon the unit value of the matrices represented by any particular pin 777 or 778. In Fig. 7, for instance, the matrix row stop-
5 magnet, numbered 13, is connected to the terminal of the eleven unit mold stop magnet; thus indicating that the thirteenth row of the lay-out or matrix plate, corresponding to that particular switch or block 776,
10 contains matrices calling for eleven unit type bodies. Similarly the #10 row matrix stop-magnet is shown connected to the terminal of the eight unit mold stop magnet, indicating that the matrices of row #10 in that
15 lay-out call for eight unit type bodies.

The blocks or switches 776 are, of course, detachable from the machine. In fact, their only means of attachment to the machine is the support afforded by the board 772, and
20 the resistance to displacement afforded by the engagement of the pins by the wells in the board. A switch may therefore be removed from the machine by merely lifting it from the board 772, and another switch
25 as easily substituted. It will therefore be seen that the matter of changing the circuits between the matrix stops and the mold stops is as simple as the substitution of one matrix plate for another in the carriage.

30 What we claim is:

1. In a type casting machine, a type mold, means for moving the mold from a type casting to a type ejecting position, a gage for setting the mold to approximately twelve
35 or more sizes of type body, said gage being unitary and movable as a whole, and means for setting said gage in positions corresponding respectively to the different mold settings desired.
- 40 2. In a type casting machine, a type mold, means for moving the mold from a type casting to a type ejecting position, one of the walls of the mold being also movable independently of the other walls of the mold
45 whereby the mold cavity may be set for different sizes of type body, a connection or attachment to said independently movable mold wall for actuating the latter, a gage serving as a stop for said connection or attachment to set the same, means for moving the gage as a whole into approximately
50 for setting said gage in positions corresponding respectively to the different mold settings desired.
- 55 3. In a type casting machine, a type mold, means for moving the mold from a type casting to a type ejecting position, the mold having a mold blade or wall movable independently of the other walls of the mold
60 for setting the mold to different sizes of type body, an extension or connection to the mold blade for actuating the same, a gage having a stepped edge to be engaged on the several steps thereof by the mold blade ex-

tension or connection and thereby to serve 65 as a stop for the latter, said gage having approximately twelve or more steps of a width substantially the same as the width of the extension or connection engaging therewith.

70 4. In a type casting machine, a type mold, means for moving the mold from a type casting to a type ejecting position, the mold having a mold blade or wall movable independently of the other walls of the mold
75 for setting the mold to different sizes of type body, an extension or connection to the mold blade for actuating the same, a gage having a tapering edge movable across the path of the mold blade extension, and means
80 for setting the gage so that different points of the tapering edge thereof may be engaged by, and serve as a stop for, the mold blade extension, said points of engagement with the mold blade extension being spaced each
85 from the next a distance substantially equal to the width of the mold blade extension.

90 5. In a type casting machine, a type mold, means for moving the mold from a type casting to a type ejecting position, means for setting the mold for different sizes of type body, and means for varying the setting an amount as small as approximately one-sixteenth of the full set width of the type.

95 6. In a type casting machine, a type mold, means for moving the mold from a type casting to a type ejecting position, means for setting the mold for different sizes of type body, and means for varying the setting an amount as small as approximately one-sixteenth of the full set width of the type,
100 said setting means comprising a gage movable as a unit to a number of positions corresponding to the mold settings desired.

105 7. In a type casting machine a mold, means for adjusting the mold for the casting of different sizes of type bodies or slugs, a plurality of matrix layouts interchangeably forming a part of the machine, connections for selecting any matrix in a layout,
110 and for setting the mold to size therefor, and a plurality of switch pieces interchangeable in the machine, each for use with and corresponding to one of said interchangeable layouts, whereby the connections are set to
115 accord to the layout employed.

120 8. In a type casting machine, a type mold, means for moving the mold with the type therein from the casting to an ejecting position, means for ejecting the type therefrom,
125 means for returning the mold from the ejecting to the casting position, one of the mold sections being also adjustable to permit of variation in size of type, an adjustable gage co-acting with said adjustable mold section, means for effecting the setting of the mold section and gage, and means whereby after, and without disturbing such

setting, the gage may be moved with the mold as the latter returns to the casting position.

9. In a type casting machine, a type mold, 5 means for moving the mold with the type therein from the casting to an ejecting position, means for ejecting the type therefrom, means for returning the mold from the ejecting to the casting position, one of 10 the mold sections being also adjustable to permit of variation in size of type, an adjustable gage co-acting with said adjustable mold section, a bank of stops for determining the setting of the gage, and means 15 whereby, without disturbing said setting, the gage may be moved with the mold as the latter moves to the casting position.

10. In a type casting machine, a type mold, means for moving the mold with the 20 type therein from the casting to an ejecting position, means for ejecting the type therefrom, means for returning the mold from the ejecting to the casting position, one of the mold sections being also adjustable to 25 permit of variation in size of type, an adjustable gage co-acting with said adjustable mold section, a bank of stops for determining the setting of the gage, and means whereby, without disturbing said setting, the 30 gage and the bank of stops may be moved with the mold as the latter moves to the casting position.

11. In a type casting machine, a lay-out 35 of matrices arranged in rows, a mold, means for setting the mold to the size of type body required for any of said matrices, and means whereby the type body of a single character in the lay-out may be changed together with the corresponding mold setting without 40 changing the matrix from one row to another in the lay-out.

12. In a type casting machine, a type mold, means for moving the mold from a type casting to a type ejecting position, one 45 of the sections of the mold being adjustable to permit of variation in size of type cast, a gage having a stepped edge adjustable across the path of movement of said adjustable mold section, whereby any one of the 50 steps thereon may be engaged by the mold section to set said section, and means whereby the gage may be moved with the mold without disturbing the setting of the adjustable mold section thereon.

55 13. In a type casting machine, a mold, a lay-out of matrices, means for moving the lay-out to present any matrix therein to the mold, means for setting the mold to the size of type body required for the matrix presented thereto, said last named means being uncontrolled by the particular position of the matrix in the lay-out.

14. In a type casting machine, a type mold, means for moving the mold with the

type therein from the casting to an ejecting position, means for ejecting the type therefrom, means for returning the mold from the ejecting to the casting position, one of the mold sections being also adjustable to permit of variation in size of type, an adjustable gage co-acting with said adjustable mold section, a bank of stops for determining the setting of the gage, and means whereby, without disturbing said setting, the gage and the selected stop may be moved 75 with the mold as the latter moves to the casting position.

15. In a type casting machine, a mold having an adjustable section whereby the mold may be set to cast type of any desired size, 80 means for setting said section in any one of its adjusted positions, a matrix block having type matrices thereon arranged in rows according to the type bodies demanded by the respective matrices, setting means for 85 the matrix block whereby any particular row of matrices thereon may be presented to the mold, connections between said matrix block setting means and said mold setting means, such that the selection of any row of 90 matrices on the matrix block involves the setting of the mold at an aperture according to the type body demanded by the matrices of the row selected, means whereby one 95 matrix block or lay-out may be substituted for another in the machine, and means whereby the aforesaid connections between the matrix row setting and the mold setting means may be simultaneously set to accord to any particular lay-out or matrix block. 100

16. In a type casting machine, a mold having an adjustable section whereby the mold may be set to cast type of any desired size, means for setting said section in any one of its adjusted positions, a matrix block having 105 suitably arranged thereon type matrices of the lay-out, setting means for the matrix block whereby any particular matrix thereon may be presented to the mold, connections between said matrix block setting 110 means and said mold setting means, such that the selection of any matrix on the matrix block involves the setting of the mold at an aperture according to the type body demanded by that matrix selected, means 115 whereby one matrix block or lay-out may be substituted for another in the machine, and means whereby the aforesaid connections between the matrix setting and the mold setting means may be simultaneously set to 120 accord to any particular lay-out or matrix block.

17. In a type casting machine, a mold having an adjustable section whereby the mold may be set to cast type of any desired 125 size, means for setting said section in any one of its adjusted positions, a matrix block having type matrices arranged thereon ac-

- 5 cording to the type bodies demanded by the respective matrices, setting means for the matrix block whereby any particular matrix thereon may be presented to the mold, electrical connections between said matrix block 5
10 setting means and said mold setting means, such that the selection of any matrix on the matrix block involves the setting of the mold at an aperture according to the type body demanded by that matrix selected, means whereby one matrix block or lay-out may be substituted for another in the machine, and a switch or circuit changer whereby the aforesaid electrical connections between the matrix setting and the mold setting means may be simultaneously set to accord to any particular lay-out or matrix block.
- 15 18. In a type casting machine, a mold having an adjustable section whereby the mold may be set to cast type of any desired size, means for setting said section in any one of its adjusted positions, a matrix block having type matrices arranged thereon according to the type bodies demanded by the respective matrices, setting means for the matrix block whereby any particular matrix thereon may be presented to the mold, electrical connections between said matrix block setting means and said mold setting means, such that the selection of any matrix on the matrix block involves the setting of the mold at an aperture according to the type body demanded by that matrix selected, means whereby one matrix block or lay-out may be substituted for another in the machine, a terminal or switch-board in the electrical connections between the row setting and the mold setting means, two sets of contact terminals on the switch-board, to the contacts of one set of which the wires to the mold setting means are severally attached and to the contacts of the other set of which the wires from the matrix setting means are severally attached a number of blocks interchangeable with the matrix plates or lay-outs, each block carrying two sets of contacts adapted when the block is placed in the terminal board to engage respectively the two sets of contacts on the latter, the contacts of one of the sets on the block being severally connected to certain of the contacts of the other set on the block, according to the particular lay-out of matrix being used, so that when any one of said blocks is placed upon the switch-board, the several contacts of one of the sets of the latter are so connected to the several contacts of the other set, that the mold setting means will have the connections to the matrix setting necessary for the particular lay-out corresponding to the block used.
- 20 19. In a type casting machine, a mold having an adjustable section whereby the mold may be set to cast type of any desired size, means for setting said section in any one of its adjusted positions, a matrix block having type matrices thereon arranged in rows according to the type bodies demanded by the respective matrices, setting means for the matrix block, whereby any particular row of matrices thereon may be presented to the mold, electrical connections between said matrix block setting means and said mold setting means, such that the selection of any 55 row of matrices on the matrix block involves the setting of the mold at an aperture according to the type body demanded by the matrices of the row selected, means whereby one matrix block or lay-out may be substituted for another in the machine, and a switch or circuit changer whereby the aforesaid electrical connections between the matrix row setting and the mold setting means may be set to accord to any particular lay-out or matrix block.
- 25 20. In a type casting machine, a mold having an adjustable section whereby the mold may be set to cast type of any desired size, means for setting said section in any one of its adjusted positions, a matrix block having type matrices arranged thereon according to the type bodies demanded by the respective matrices, setting means for the matrix block whereby any particular matrix thereon may be presented to the mold, electrical connections between the matrix block setting means and said mold setting means, such that the selection of any matrix on the matrix block involves the setting of the mold at an aperture according to the type body demanded by that matrix selected, means whereby one matrix block or lay-out may be substituted for another in the machine, a terminal or switch-board in the electrical connections between the row setting and the mold setting means, two sets of contact terminals on the switch-board, to the contacts of one set of which the wires to the mold setting means are severally attached and to the contacts of the other set of which the wires from the matrix setting means are severally attached a number of blocks interchangeable with the matrix plates or lay-outs, each block carrying two sets of contacts adapted when the block is placed in the terminal board to engage respectively the two sets of contacts on the latter, the contacts of one of the sets on the block being severally connected to certain of the contacts of the other set on the block, according to the particular lay-out of matrix being used, so that when any one of said blocks is placed upon the switch-board, the several contacts of one of the sets of the latter are so connected to the several contacts of the other set, that the mold setting means will have the connections to the matrix setting necessary for the particular lay-out corresponding to the block used.
- 30 21. For use in and as part of a type casting machine, and in conjunction with some one matrix plate or lay-out, a block carrying a bank of individual means for engaging, when the block is in position in the machine, a bank of connections to the mold setting means, and also carrying a bank of individual means for engaging in the machine a bank of connections from the matrix setting means, and connections on the block from the individual means of one bank to the individual means of the other bank, whereby when the block is in position in the machine the connections between the mold setting means and the matrix setting means will accord to the requirements of the particular layout of matrix corresponding to that block.
- 35 22. For use in and as part of a type casting machine, a block carrying a bank of contacts for severally engaging, when the block is in position in the machine, the terminals
- 40 45 50 55 60 65 70 75 80 85 90 95 100 105 110 115 120 125 130

of a set of electrical connections to the mold setting means, and carrying also a bank of contacts for severally engaging in the machine the terminals of a set of electrical connections from the matrix setting means, the individual contacts of one of the banks on the blocks being severally connected to the individual contacts of the other bank in such a way that when the block is in position in 10 the machine, the connections between the mold and the matrix setting means, will accord to the requirement of the particular lay-out corresponding to that block.

28. In a type casting machine, a set of 15 stops for controlling the adjustment of the mold, a controller for the machine, and operating connections to said stops governed by said controller, a plurality of said stops being arranged in said connections in parallel 20 with each other and another of said stops being in series with a plurality of the stops so arranged in parallel.

24. In a type casting machine, a set of 25 stops for controlling the adjustment of the mold, a controller for the machine, and electrical operating connections to said stops governed by said controller, a plurality of said stops being arranged in said connections in parallel 30 with each other and another of said stops being in series with a plurality of the stops so arranged in parallel.

25. In a type composing machine, a galley comprising a type supporting plate, means for detachably securing the same to the machine, a second plate flush with and against which said first plate abuts, a block adjustably mounted on said second plate, a member on said first plate for defining the length of line of type set up in the galley and means 40 movable independently of said member and block for locking said member to the block, whereby said member may be secured in any desired position in the galley.

26. In a type composing machine, a galley, 45 a block adjustable transversely thereof, a member in the galley for defining the length of line of type set up in the galley and movable means for locking the same to the block.

27. In a type composing machine, a galley, 50 a block adjustable transversely thereof, a telescopic attachment to said block, and means for locking said attachment against telescopic movement.

28. In a type composing machine, a galley, 55 a block adjustable transversely thereof, a telescopic attachment to said block and means for locking said attachment against telescopic movement, a member in the galley for defining the length of line of type set up 60 therein and means for securing the same to the block.

29. In a type composing machine, a galley, 65 a block adjustable transversely thereof, a member in the galley for defining the length of line of type set up therein and means for

detachably locking the same to the block after the member and block are in position.

30. In a type composing machine, a galley, a block adjustable transversely thereof, a member in the galley for defining the length 70 of line of type set up therein and a key by means of which said member and the block may be locked together or detached from each other.

31. In a type casting machine, a set of 75 stops for controlling the adjustment of the mold, each of said stops representing a multiple of the unit of variation of mold setting for different sizes of type slugs, a controller for the machine, and operating connections to said stops governed by said controller, those of said stops representing a difference, one from the other, of two units of set measurement being disposed in parallel with each other in said connections and 80 in series each with the stop representing the intermediate unit of set variation.

32. In a type casting machine, a set of 85 justifier stops for controlling the adjustment of the mold, for line justification, each of 90 said stops representing a multiple of the unit of variation of mold setting for different sizes of type slugs, a controller for the machine, and operating connections to said stops governed by said controller, those of 95 said stops representing a difference, one from the other, of two units of set measurement being disposed in parallel with each other in said connections and in series each with the stop representing the intermediate 100 unit of set variation.

33. In a type composing machine, a galley, an adjustable member therein defining the column of type, means for shifting set-up lines of type into the galley between one 105 wall thereof and said adjustable member, said member comprising two sections yieldingly connected whereby the member is permitted to yield if an overfed line of type be forced against the same, and means for retaining the yielding section in precisely the position into which it may be forced by the type.

34. In a type composing machine, a galley, an adjustable member therein defining 115 the column of type, means for shifting set-up lines of type into the galley between one wall thereof and said adjustable member, said member comprising two sections yieldingly connected whereby the member is permitted to yield if an overfed line of type be forced against the same, and a spring pawl for retaining the yielding section in precisely the position into which it may be forced by the type. 120

35. In a type composing machine, a galley, a member therein defining the type column, means for shifting set-up lines of type into the galley, a slide in the end of said member at the entrance to the galley, a 130

spring normally holding the slide in its outward position, but permitting the slide to yield if an overfed line of type be forced against the same, and means for holding the slide against the action of the spring in precisely the position into which it has been forced by the type.

36. In a type composing machine, a galley, an adjustable member therein defining 10 the column of type, means for shifting set-up lines of type into the galley between one wall thereof and said adjustable member, said member comprising two sections yieldingingly connected whereby the member is permitted to yield if an overfed line of type be forced against the same, and means adapted 15 to jam against the yielding section and thereby to hold the same in precisely the position into which it may be forced by the 20 type.

37. In a type composing machine, a channel in which the individual type are set up to form the line, a type support movable along said channel to serve as a yielding 25 abutment for the type being forced into the same, a guide bar on which said yielding member travels, means for cutting out or stopping the machine, and means carried by the bar in the path of the type support 30 which, when engaged by the type support, causes the bar to operate the cutout.

38. In a type composing machine, a channel in which the individual type are set up to form a line, means for cutting out or 35 stopping the machine, a device for operating said cutout mechanism, said device being adjustable to set positions along the line of the type channel according to the length of line to be set up, means for holding said cutout 40 operating device stationary in its set position until the line has been set up, and means whereby the type is thereupon caused to move said device to operate the cutout in the event of over or under-feed of the type.

45. 39. In a type composing machine, a channel in which the individual type are set up to form the line, a type support movable along said channel to serve as a yielding abutment for the type being forced into 50 the channel, means for cutting out or stopping the machine, a device for operating said cut-out mechanism, said device being adjustable to set positions in the path of said yielding abutment according to the 55 length of line to be set up, means for holding said cut-out operating device stationary in its set position until the line has been set up, and means whereby the yielding abutment is thereupon caused to move said device to operate the cut-out in the event of over or under-feed of the type.

40. In a type composing machine, a channel in which the individual type are set up to form the line, a type support movable 65 along said channel to serve as a yielding

abutment for the type being forced into the same, a guide for the type support, means for cutting out or stopping the machine, the type support guide being movable to control said cut-out, and means adjustably 70 attachable to the type support guide in the path of the type support, so that when engaged by the latter, the guide will be moved to operate the cut-out.

41. In a type composing machine, an 75 automatic cut-out device, a galley mechanism for shifting a set-up line of type to the galley, connections between said line shifting mechanism and the cut-out device whereby the movement of the former may 80 operate the latter, mechanism for setting up the individual type in a line, and means controlled by said line setting mechanism for breaking the connection between the cut-out device and the line shifting mechanism 85 when the line of type is of sufficient length.

42. In a type composing machine, an automatic cut-out device, a galley mechanism for shifting a set-up line of type to the galley, connections between said line shifting 90 mechanism and the cut-out device whereby the movement of the former may operate the latter, mechanism for setting up the individual type in a line, and means controlled by said line setting mechanism through the 95 set-up type for breaking the connection between the cut-out device and the line shifting mechanism when the line of type is of sufficient length.

43. In a type composing machine, an 100 automatic cut-out device, a galley mechanism for shifting a set-up line of type to the galley, connections between said line shifting mechanism and the cut-out device whereby the movement of the former may 105 operate the latter, and means operated by the set up type to break the connection between the cut-out device and the line shifting mechanism when the line of type is of sufficient length.

44. In a type composing machine, an electrically controlled automatic cut-out device, a galley, mechanism for shifting a set-up line of type to the galley, means in the circuit of the cut-out for controlling the operation of the latter, said means being operable by the line shifting mechanism, so that the movement of the latter may effect the cut-out, mechanism for setting up the individual type in a line, and other means in the controlling circuit of the cut-out device operable by the line setting mechanism through the type, whereby when the line of type set up is of sufficient length, the control of the cut-out from the line shifting mechanism 125 is rendered ineffectual.

45. In a type composing machine, an electrically controlled automatic cut-out device, a galley, mechanism for shifting a set-up line of type to the galley, means in the cir- 130

cuit of the cut-out for controlling the operation of the latter, said means being operable by the line shifting mechanism, so that the movement of the latter may effect the cut-out, mechanism for setting up the individual type in a line, and other means in the controlling circuit of the cut-out operable by the set-up type to render ineffective the control of the cut-out from the line shifting mechanism when the line of type set up is of sufficient length.

46. In a type composing machine, a cut-out device for stopping the machine, an electromagnet for operating said cut-out device, two contacts connected in parallel to one of the terminals of the electromagnet, a movable finger connected to the other terminal of the electromagnet and adapted to engage either one or neither of the two contacts aforesaid, the movable finger resting normally however on one of the contacts, a second maker and breaker normally maintaining open the circuit of that contact normally engaged by the movable finger, means connected on the one hand to the movable contact finger, and on the other hand adapted to be engaged and moved, first by an overfed line of type a distance sufficient to move the finger from the contact on which it normally rests, to the other contact thereby closing the circuit of the latter through the electromagnet, second, by a line of proper length a distance sufficient to move the contact finger to a position between the contacts, so that the branch circuits from both are and remain broken, and third by an underfed line a distance insufficient to move the finger from the contact on which it normally rests, a galley means for shifting the set-up line to the galley and means connected to the line shifting mechanism and to the second circuit maker aforesaid whereby the movement of the line shifting mechanism moves the second circuit maker and closes the circuit therethrough to the electromagnet, provided the line be underfed, so that the movable finger still rests on the contact normally engaged thereby.

47. In a type casting and composing machine, a mold in which the type are cast, a channel in which the type are set up, means for delivering the type from the mold to the channel, and means for temporarily holding the type last delivered from the other type in the channel whereby the type so held may cool before contact with other type.

48. In a type casting and composing machine, a mold in which the type are cast, a channel in which the type are set up, means for delivering the type from the mold to the channel, and a separator for temporarily holding the type last ejected from the mold from the other type in the channel whereby the type so held may cool before contact with other type, and means for successively

withdrawing the separator from in front of a type and for bringing it to the rear of that type, in front of the type to follow.

49. In a type casting and composing machine, a mold in which the type are cast, a channel in which the type are set up, means for delivering the type from the mold to the channel, and a separator for temporarily holding the type last delivered from the other type in the channel whereby the type so held may cool before contact with other type, means whereby the separator may move with the type as the latter are fed forward, and means for withdrawing the separator from in front of a type after each feed and for bringing it to the rear of the type, in front of the type to follow.

50. In a type casting and composing machine, a mold in which the type are cast, a channel in which the type are set up, means for delivering the type from the mold to the channel, and a separator for temporarily holding the type last delivered from the other type in the channel whereby the type so held may cool before contact with other type, means for forcing the separator into the path of the type in the channel, means whereby the separator is free to move with the type as the latter are fed along the line, means for withdrawing the separator from the line, and means for returning the separator to the point of the line from which it was fed with the type.

51. In a type casting and composing machine, a mold in which the type are cast, a channel in which the type are set up, means for delivering the type from the mold to the channel, and a separator for temporarily holding the type last delivered from the other type in the channel whereby the type so held may cool before contact with other type, a slide on which the separator is mounted whereby it may be free to move with the type as the latter are fed along the line, a second slide carrying the first slide, and means for moving the second slide to withdraw the separator from the type in the line, a spring for returning the first slide to the position from which it was forced by the feed of the type, and another spring attached to the second slide for again projecting the separator into the line.

52. In a type casting and composing machine, a mold in which the type are cast, a channel in which the type are set up, means for delivering the type from the mold to the channel, and a separator for temporarily holding the type last delivered from the other type in the channel whereby the type so held may cool before contact with other type, means for forcing the separator into the path of the type in the channel, means whereby the separator is free to move with the type as the latter are fed along the line, means operated from the type delivering

mechanism for withdrawing the separator from the line and means for returning the separator to the point of the line from which it was fed with the type.

- 5 53. In a type casting and composing machine, a mold in which the type are cast, a channel in which the type are set up, means for delivering the type from the mold to the channel, and a separator for temporarily holding the type last delivered from the other type in the channel whereby the type so held may cool before contact with other type, means operated from the type delivering mechanism for withdrawing the separator from the type, and means for again advancing the separator to interpose the same in front of the next type.
- 10 54. In a type casting and composing machine, a mold in which the type are cast, a channel in which the type are set up, means for delivering the type from the mold to the channel, and a separator for temporarily holding the type last delivered from the other type in the channel whereby the type so held may cool before contact with other type, means connecting the separator to the type delivering mechanism whereby the latter is alternately withdrawn from and projected into the type line to be interposed in front of the successively delivered type.
- 15 55. In a type casting and composing machine, a mold, a type channel or line, a plunger for feeding the type into the line, a type clamp, means for moving the clamp into engagement with the last delivered type to support the same, and as the plunger retreats to prevent possible displacement of the type due to adhesion of the latter to the plunger.
- 20 56. In a type casting and composing machine, a mold, a type channel or line, a plunger for feeding the type into the line, a type clamp, means for moving the clamp into engagement with the last delivered type to support the same, and as the plunger retreats to prevent possible displacement of the type due to adhesion of the latter to the plunger, and means for withdrawing the clamp from the type in time to permit of
- 25 57. In a type casting and composing machine, a mold, a type channel or line, a plunger for feeding the type into the line, a type clamp in the form of a slide having movement to and from the type perpendicular thereto, means for moving the clamp into engagement with the last delivered type to support the same, and as the plunger retreats to prevent possible displacement of the type due to adhesion of the latter to the plunger.
- 30 58. In a type casting machine, a set of stops for controlling the adjustment of the mold, each of said stops representing a multiple of the unit of variation of mold set-

ting for different sizes of type slugs, a controller for the machine, and electrical operating connections to said stops governed by said controller, those of said stops representing a difference, one from the other, of two units of set measurement being disposed in parallel with each other in said connections and in series each with the stop representing the intermediate unit of set variation.

59. In a type casting machine, a set of justifier stops for controlling the adjustment of the mold, for line justification, each of said stops representing a multiple of the unit of variation of mold setting for different sizes of type slugs, a controller for the machine, and electrical operating connections to said stops governed by said controller, those of said stops representing a difference, one from the other, of two units of set measurement being disposed in parallel with each other in said connections and in series each with the stop representing the intermediate unit of set variation.

60. In a type casting machine, a set of justifier stops for controlling the adjustment of the mold, for line justification, each of said stops representing a multiple of the unit of variation of mold setting for different sizes of type slugs, a controller for the machine, and electrical operating connections to said stops governed by said controller, those of said stops representing a difference, one from the other, of two units of set measurement being disposed in parallel with each other in said connections and in series each with the stop representing the intermediate unit of set variation, whereby the intermediate stop may be operated with either the stop representing the next lower or next higher unit of set variation, and means whereby either of the two stops in series so selected may be caused to control the mold setting means in advance of the other selected stop.

61. In a type casting machine, a mold, means for setting the same for the casting of type slugs of different sizes, a justifier mechanism comprising stops to determine the setting of the mold, a controller for the machine, connections to the justifier stops governed by the controller, a plurality of said stops being in parallel in said connections and each stop in series with another of said stops, connections from the justifier to the mold setting means, said connections being controlled by said stops, and means whereby first one and then the other of the two stops in series in one of said controller connections may through its connection to the mold setting means set the latter.

62. In a type casting machine, a mold, means for setting the same for the casting of type slugs of different sizes, a justifier mechanism comprising stops to determine the set-

ting of the mold, a controller for the machine, connections to the justifier stops governed by the controller, a plurality of said stops being in parallel in said connections 5 and each stop in series with another of said stops, connections from the justifier to the mold setting means, said connections being controlled by said stops, and means whereby first one and then the other of the two stops 10 in series in one of said controller connections may through its connection to the mold setting means set the latter, and means operated from the controller whereby either of said two selected stops may operate in advance of the other to set the mold.

63. In a type casting machine, a mold, means for setting the same for the casting of type slugs of different sizes, a justifier mechanism comprising stops to determine 20 the setting of the mold, a controller for the machine, electrical connections to the justifier stops governed by the controller, a plurality of said stops being in parallel in said connections and each stop in series with another of said stops, connections from the justifier to the mold setting means, said connections being controlled by said stops, and means whereby first one and then the other of the two stops in series in one of said controller connections may through its connection to the mold setting means set the latter, and means operated from the controller whereby either of said two selected stops may operate in advance of the other 30 to set the mold.

64. In a type casting machine, a mold, means for setting the mold, a justifier mechanism comprising several selecting means each connected to the mold setting means to 40 control one setting of the latter, a controller for the machine, and operating connections for the selecting means each governed by the said controller and each serving when operated to set a plurality of said selecting means in the justifier mechanism.

65. In a type casting machine, a mold, means for setting the mold, a justifier mechanism comprising several selecting means each connected to the mold setting means to 50 control one setting of the latter, a controller for the machine, and operating connections for the selecting means each governed by the said controller and each serving when operated to set a plurality of said selecting means in the justifier mechanism, and means whereby any one of the several selecting means set by any one controller connection may operate to set the mold alone and in advance of the other selecting means so set.

66. In a type casting machine, a mold, means for setting the mold, a justifier mechanism comprising several selecting means each connected to the mold setting means to control one setting of the latter, 60 a controller for the machine, and electrical

operating connections for the selecting means each governed by the said controller and each serving when operated to set a plurality of said selecting means in the justifier mechanism, and means whereby any one of the several selecting means set by any one controller connection may operate to set the mold alone and in advance of the other selecting means so set.

67. In a type casting and composing machine, a mold, means for setting the mold at any desired aperture for the casting of different sizes of slugs, justification mechanisms controlling the mold setting means to determine the setting of the mold for the casting of the space quads, the justification mechanisms comprising means adapted to be set to select two sizes of space quads for the line, and means controlling the connections to the selector whereby of the two sizes so selected the quads first cast may be of the one size or of the other size regardless of the setting of the selector.

68. In a type casting and composing machine, a mold, means for setting the mold at any desired aperture for the casting of twelve or more different sizes of slugs, justification mechanisms controlling the mold setting means to determine the setting of the mold for the casting of the space quads, the justification mechanisms comprising means whereby the space quads of a line may be of two sizes differing by a unit of variation between two successive sizes of the mold setting.

69. In a type casting and composing machine, a mold, means for setting the mold at any desired aperture for the casting of different sizes of slugs, justification mechanisms controlling the mold setting means to 105 determine the setting of the mold for the casting of the space quads, the justification mechanisms comprising means adapted to be set to select two sizes of space quads for the line and means controlling the connections to the selector whereby of the two sizes selected the quads first cast may be of the one size or of the other size, according to the number of spaces in the lines regardless of the setting of the selector.

70. In a type casting and composing machine, a mold, means for setting the mold at any desired aperture for the casting of twelve or more different sizes of slugs, justification mechanisms controlling the mold setting 120 means to determine the setting of the mold for the casting of the space quads, the justification mechanisms comprising means whereby the space quads of a line may be of two sizes differing by the unit of variation of two successive sizes of mold setting, regardless of the number of spaces in the line.

71. In a type casting and composing machine, a mold, means for setting the mold 130

- at any desired aperture for the casting of different sizes of slugs, justification mechanisms controlling the mold setting means to determine the setting of the mold for the casting of the space quads, the justification mechanisms comprising means adapted to be set to select space quads of two sizes for the line, and means controlling the connections to the selector whereby of the two sizes selected a limited number of quads of either the one or the other size may first be cast regardless of the setting of the selector, and thereafter an indefinite number of quads of the other size.
- 15 72. In a type casting and composing machine, a mold, means for setting the mold at any desired aperture for the casting of different sizes of slugs, justification mechanisms controlling the mold setting means to determine the setting of the mold for the casting of the space quads, the justification mechanisms comprising means for selecting space quads of two sizes for the line, and means whereby of the two sizes so selected, quads of the one size to the number of nine or thereabout, may first be cast and thereafter an indefinite number of quads of the other size.
- 20 73. In a type casting and composing machine, a mold, means for setting the mold at any desired aperture for the casting of different sizes of slugs, justification mechanisms controlling the mold setting means to determine the setting of the mold for the casting of the space quads, the justification mechanisms comprising means for selecting space quads of two sizes for the line, and means whereby of the two sizes so selected a limited number of quads of the one size may first be cast, and thereafter an indefinite number of quads of the other size, and means controlling the connections to the selector for determining in accordance with the total amount of justification required for the line and number of spaces to which the same is to be distributed, which of the two sizes so selected shall first be cast.
- 25 74. In a type casting and composing machine, a mold, means for setting the mold at any desired aperture for the casting of different sizes of lugs, justification mechanisms controlling the mold setting means to determine the setting of the mold for the casting of the space quads, the justification mechanisms comprising means for selecting space quads of two sizes for the line differing by the unit of variation of two successive sizes of the mold setting and means whereby of the two sizes so selected a limited number of quads of the one size may first be cast, and thereafter an indefinite number of quads of the other size, and means controlling the connections to the selector for determining in accordance with the total

amount of justification required for the line and number of spaces to which the same is to be distributed, which of the two sizes so selected shall first be cast.

75. In a type casting and composing machine, a mold, a bank of stops for setting the mold at any desired aperture for the casting of different sizes of slugs, justification mechanisms and connections thereto from each of the mold stops, a control device carrying space controlling means, a connection to the justification mechanism controlled by said space controlling means, the justification mechanism comprising means whereby two of the connections therefrom to the mold stops may be set or selected, and means whereby the connection thereto controlled by the space controlling means may be connected to first one and then the other of the selected connections to the mold stops, and means for connecting said space control device in the first instance to either of said selected mold stop selecting means.

76. In a type casting and composing machine, a mold, a bank of stops for setting the mold at any desired aperture for the casting of different sizes of slugs, justification mechanisms and electrical connections thereto from each of the mold stops, a control device carrying space controlling means, an electrical connection to the justification mechanism controlled by said space control device, the justification mechanism comprising means whereby two of the connections therefrom to the mold stops may be set or selected, and means whereby the connection thereto controlled by the space control device may be placed in circuit with first one and then the other of the selected connections to the mold stops, and means for electrically connecting said space control device in the first instance to either of said selected mold stop connections without disturbing or determining the setting of said mold stop selecting means.

77. In a type casting and composing machine, a mold, a bank of stops for setting the mold at any desired aperture for the casting of different sizes of slugs, justification mechanisms and electrical connections thereto from each of the mold stops, a control device carrying space controlling means, an electrical connection to the justification mechanism controlled by said space control device, the justification mechanism comprising means whereby two of the connections therefrom to the mold stops may be set or selected, and a circuit changer whereby the connection thereto controlled by the space control device may be placed in circuit with first one and then the other controlling said circuits whereby without regard to the position of the said selecting means, the connections controlled by the space control de-

vice may be placed in the first instance in circuit with either one or the other of the selected mold stops.

78. In a type casting and composing machine, a mold, a bank of stops for setting the mold at any desired aperture for the casting of different sizes of slugs, justification mechanisms and electrical connections thereto from each of the mold stops, a control device carrying space controlling means, an electrical connection to the justification mechanism controlled by said space control device, the justification mechanism comprising means whereby two of the connections therefrom to the mold stops may be set or selected, and a circuit changer whereby the connection thereto controlled by the space control device may be placed in circuit with the first one and then the other of the selected connections to the mold stops, and a second circuit changer for changing the connections of the selected mold stops to the first circuit changer, whereby either one or the other of the selected mold stops may first be in circuit with connections controlled by the space control device.

79. In a type casting and composing machine, a mold, a bank of electrically controlled stops for setting the mold at any desired aperture for the casting of different sizes of slugs, justification mechanisms for determining the size of the space quads comprising a circuit changer or switch having three contacts, means for selecting and connecting the controlling circuits of two of the mold stops to two of the circuit changer contacts respectively, a control device carrying space controlling means, a contact member in the circuit changer movable from one to the other of the just named two contacts, a connection controlled by the space control device and attached to the movable contact of the circuit changer, means for shifting the movable contact from one to the other of the first named contacts, and a second circuit changer for reversing the connections of the two selected stops to the first named two contacts.

80. In a type casting and composing machine, a mold, a bank of electrically controlled stops for setting the mold at any desired aperture for the casting of different sizes of slugs, justification mechanisms for determining the size of the space quads comprising a circuit changer or switch having three contacts, means for selecting and connecting the controlling circuits of two of the mold stops to two of the circuit changer contacts respectively, a control device carrying space controlling means, a contact member in the circuit changer movable from one to the other of the just named two contacts, a connection controlled by the space control device and attached to the movable contact of the circuit changer,

means for shifting the movable contact from one to the other of the first named contacts and a second circuit changer for reversing the connections of the two selected stops to the first named two contacts, and a connection controlled by the space control device for operating the second named circuit changer when desired.

81. In a type casting and composing machine, a mold, a bank of electrically controlled stops for setting the mold at any desired aperture for the casting of different sizes of slugs, justification mechanisms for determining the size of the space quads comprising a circuit changer or switch having three contacts, means for selecting and connecting the controlling circuits of two of the mold stops to two of the circuit changer contacts respectively, a control device carrying space controlling means, a contact member in the circuit changer movable from one to the other of the just named two contacts, a connection controlled by the space control device and attached to the movable contact of the circuit changer, means for shifting the movable contact from one to the other of the first named contacts, and a second circuit changer for reversing the connections of the two selected stops to the first named two contacts, said second named circuit changer having a normal setting whereby the connections from the space control device to the mold stops operate in a definite order, and means for operating the second circuit changer to reverse their order.

82. In a type casting machine, a mold, means for moving the mold from a type casting to a type setting position and vice versa, and means for setting the mold to the next required size of type body while the mold is at the type ejecting position.

83. In a type casting and composing machine, a record strip, a mold, a bank of stops for setting the mold at any desired aperture for the casting of different sizes of slugs, justification mechanism for determining the size of the space slugs, connections to said mechanism from the several mold stops, connections to said mechanism from the record strip, each adapted to select or set two at a time of said mold stop connections, space registrations in the record strip, a connection from the record strip to said mechanism controlled by said space registrations, means in the justifier mechanism for connecting said space controlled connection to first one and then the other of the selected mold stop connections, and means for reversing the order in which said selected mold stop connections are connected to said space controlled connection.

84. In a type casting and composing machine, a record strip, a mold, a bank of stops for setting the mold at any desired aperture for the casting of different sizes of slugs,

justification mechanism for determining the size of the space slugs, connections to said mechanism from the several mold stops, connections to said mechanism from the record strip, each adapted to select or set two at a time of said mold stop connections, the mold settings determined by the two stops of each pair so selected differing by a unit of the full set measurement of the type, space registrations in the record strip, a connection from the record strip to said mechanism controlled by said space registrations, means in the justifier mechanism for connecting said space controlled connection to first one and then the other of the selected mold stop connections.

85. In a type casting and composing machine, a mold, a matrix block carrying a lay-out of matrices, means for moving the block to present any of said matrices to the mold, and means for automatically locking the matrix block against movement when the operation of the machine is not designed to cast type.

86. In a type casting and composing machine, means controlling the operation of the machine to determine the type matter to be cast, a mold, means for supplying molten metal to the mold, a matrix block carrying a lay-out of matrices, means for moving the block to present any of said matrices to the mold, means for cutting out the molten metal supply during the passage through the machine of a portion of the type matter controlling means or record desired to be canceled, and means for locking the matrix block against movement during the passage of such canceled record.

87. In a type casting and composing machine, means controlling the operation of the machine to determine the type matter to be cast, a mold, means for supplying molten metal to the mold, a matrix block carrying a lay-out of matrices, means for moving the block to present any of said matrices to the mold, means for cutting out the molten metal supply during the passage through the machine of a portion of the type matter controlling means or record desired to be canceled, and means controlled by a registration in the record strip for locking the matrix block against movement during the passage of such canceled record.

88. In a type casting and composing machine, means controlling the operation of the machine to determine the type matter to be cast, a mold, means for supplying molten metal to the mold, a matrix block carrying a lay-out of matrices, means for moving the block to present any of said matrices to the mold, means for cutting out the molten metal supply during the passage through the machine of a portion of the type matter controlling means or record desired to be canceled, and an electromagnet controlled

by a registration in the record strip for locking the matrix block against movement during the passage of such canceled record.

89. In a type casting and composing machine, means controlling the operation of the machine to determine the type matter to be cast, a mold, means for supplying molten metal to the mold, a matrix block carrying a lay-out of matrices, means for moving the block to present any of said matrices to the mold, means for cutting out the molten metal supply during the passage through the machine of a portion of the type matter controlling means or record desired to be canceled, and means controlled by said type matter controlling means for locking the matrix block against movement during the passage of such canceled record, and means controlled by said type matter controlling means or record for releasing the matrix block after the passage of such canceled record.

90. In a type casting and composing machine, a mold, a matrix block carrying a lay-out of matrices, means for moving the block to present any of said matrices to the mold, justification mechanism, and means for locking the block against movement during the setting of the justification mechanism.

91. In a type casting and composing machine, means controlling the operation of the machine to determine the type matter to be cast, a mold, means for supplying molten metal to the mold, a matrix block carrying a lay-out of matrices, means for moving the block to present any of said matrices to the mold, means for cutting out the molten metal supply during the passage through the machine of a portion of the type matter controlling means or record desired to be canceled, and means controlled by said type matter controlling means or record for locking the matrix block against movement during the passage of such canceled record, and means controlled by a registration in the record strip for releasing the matrix block and the molten metal supply mechanism, after the passage of such canceled record.

92. In a type casting machine, a controller governing the operation of the machine to determine the character of type cast and to determine the justification of the same, justification mechanism and an operating connection therefor governed by said controller, a galley, mechanism for shifting completed lines of type to the galley, means governed from said controller for positively locking the line shifting mechanism to the justification mechanism whereby the two may operate together at the end of the line and at other times be independent.

93. In a type casting machine, a controller governing the operation of the machine to determine the character of type cast and to

determine the justification of the same, justification mechanism and an operating connection therefor governed by said controller, a galley, a movable locking device governed by 5 said controller and adapted whenever operated to lock together the justification and line shifting mechanisms.

94. In a type casting machine, a controller governing the operation of the machine to 10 determine the character of type cast and to determine the justification of the same, justification mechanism and an operating connection therefor governed by said controller, a galley, an adjustable key engaging 15 one of said mechanisms but normally out of engagement with the other, and means governed by said controller for causing said key to positively engage the other of said mechanisms whereby the two members are 20 caused to move together.

95. In a type casting machine, a controller governing the operation of the machine to 25 determine the character of type cast and to determine the justification of the same, justification mechanism and an operating connection therefor governed by said controller, a galley, an adjustable key engaging one of 30 said mechanisms but normally out of engagement with the other, and means governed by said controller for causing said key to positively engage the other of said mechanisms whereby the two members are caused to reciprocate together.

96. In a type casting machine, an adjustable mold, a movable gage to control the adjustment of the mold, means for moving the gage to set the same, and means for moving the gage as set into a position to coöperate with the adjustable section of the mold to 40 set the latter for the casting operation.

97. In a type casting machine, a mold having an adjustable mold blade, a gage movable across the path of the mold blade to set the latter to various adjustments, means for 45 setting the gage to the required mold adjustment and for then moving the gage to a position to coöperate with the mold blade for setting the latter for the casting operation.

98. In a type casting machine, an adjustable mold mounted to move between a casting and ejecting position in combination with means adapted to control the adjustment of the mold, such means being suitably mounted to travel with the mold in its movement without disturbing such adjustment. 55

99. In a type casting machine, an adjustable mold mounted to move between a casting and ejecting position in combination with means adapted to control the adjustment of the mold such means being suitably mounted to travel with the mold in its movement without disturbing such adjustment, and means to control such adjustment controlling means.

100. In a type casting machine, a mold

having a mold blade adjustable to different sizes of type body, a gage for controlling the setting of the mold blade, stops to control the setting of the gage, means for projecting the proper stop in the path of the gage, 70 means for moving the gage to said stop whereby the gage is set, and means for moving the gage and stop which sets the same together to a position where the gage coöperates with the mold to set the latter 75 for the casting operation.

101. In a type casting machine, a mold having a mold blade adjustable to different sizes of type body, a gage for controlling the setting of the mold blade, stops to control 80 the setting of the gage, means for projecting the proper stop in the path of the gage, means for moving the gage to said stop whereby the gage is set, and means for moving the gage when set and the several stops 85 together a distance to bring the gage into a position where it coöperates with the mold to set the latter for the casting operation.

102. In a type casting and composing machine, a mold in which the type are cast, a 90 channel in which the type are set up against each other in succession, means for delivering the type from the mold to the channel, and means temporarily interposed for holding the type last ejected from the mold from 95 the type previously cast to allow the type last cast to cool before contact with other type.

103. In a type casting and composing machine, a mold in which the type are cast, a 100 positively interposed means for holding the type last cast from the type previously cast to allow the type last cast to cool before contact with other type, a channel in which the type are set up against each other in succession, and means for placing the type last cast against the type previously cast when the same is cooled.

104. In a type casting machine, a mold, means for adjusting the mold for the casting of different sizes of type bodies or slugs, a plurality of matrix layouts interchangeably forming a part of the machine, electrical connections for selecting any matrix in a layout, and for setting the mold to size 110 therefor, and a plurality of electrical switch pieces interchangeable in the machine, each for use with one of said interchangeable layouts, whereby the electrical connections are 115 set to accord to the layout employed.

105. In a type composing machine, a galley, a member adjustable laterally of the galley to form one of the retaining walls for the column of type, means for setting said member according to the width of the galley 125 of type, resilient means whereby said member is permitted to yield lengthwise of the galley when under pressure from the end of an overfed line of type so that such a line may enter the galley, and means for tem- 130

temporarily restraining the return action of said resilient means when said member has so yielded.

106. In a type casting machine, a mold 5 adjustable in size to be set for the casting of type bodies or slugs of various sizes, a layout of matrices of various type characters adapted individually to be brought into coöperation with the mold for the casting of type, 10 means controlling jointly the adjustment of the mold and the selection of the several matrices therefor, so that any matrix according to its position in the layout may be brought into coöperation with the mold and 15 the mold adjusted therefor, and a resetting device to permit the layout to be changed with respect to the position of certain only of the matrices without change of mold adjustment therefor.
- 20 107. In a type casting machine, a mold adjustable in size to be set for the casting of type bodies or slugs of various sizes, a layout of matrices of various type characters adapted individually to be brought into 25 coöperation with the mold for the casting of type, means controlling jointly the adjustment of the mold and the selection of the several matrices therefor, so that any matrix according to its position in the layout, 30 may be brought into coöperation with the mold and the mold adjusted therefor, and a resetting device to permit the layout to be changed with respect to the position at certain only of the matrices and change of 35 mold adjustment to accord to the new matrix substituted.

108. In a type casting machine, a mold 40 adjustable in size to be set for the casting of type bodies or slugs of various sizes, a layout of matrices of various type characters adapted individually to be brought into coöperation with the mold for the casting of type, means controlling jointly the adjustment of the mold and the selection of the 45 several matrices therefor, so that any matrix according to its position in the layout, may be brought into coöperation with the mold and the mold adjusted therefor, a resetting device to permit of change of mold adjustment 50 for a matrix without changing position of such matrix in the layout.

109. In a type casting machine, an adjustable mold, a group of selective devices for 55 determining the several adjustments of the mold, a layout of matrices, each capable of coöperation with the mold, selecting means for determining in each instance the matrix to be presented to the mold, connections between the several matrix selecting means and the several mold adjustment selecting means, so that the proper size of body or slug may be cast for each type, and means for simultaneously changing a plurality of 60 said connections.

110. In a type casting machine, an ad-

justable mold, a group of selective devices for determining the several adjustments of the mold, a layout of matrices, each capable of coöperation with the mold, selecting means for determining in each instance the 70 matrix to be presented to the mold, connections between the several matrix selecting means and the several mold adjustment selecting means so that the proper size of body or slug may be cast for each type, and 75 a switch for changing one or more of said connections.

111. In a type casting machine, an adjustable mold, a group of selective devices for determining the several adjustments of the mold, operating connections to said devices, a layout of matrices each capable of coöperation with the mold, selecting means for determining in each instance the matrix to be presented to the mold, operating connections to said selecting means, two sets of operating terminals, one set for the connections to the mold adjustment selectors, and the other set for the connections to the matrix selectors, and a number of interchangeable devices each having two sets of terminals, one set to coöperate with and connect to the aforesaid mold adjustment connections and the other set to coöperate with and connect to the aforesaid matrix selector connections, and connections in said interchangeable devices from the terminals of one set to the terminals of the other set thereof, said connections being different in each of said interchangeable devices, whereby, upon the substitution of one of said devices for another the connections from the matrix selectors to the mold adjustment selectors are 100 changed.

112. In a type casting machine, a mold, means for adjusting the mold for the casting of different sizes of type bodies or slugs, a plurality of matrix layouts interchangeably forming a part of the machine, connections for selecting any matrix in a layout, and for setting the mold to size therefor, and means whereby a plurality of said connections may be simultaneously changed to accord to any new layout.

113. In a type casting machine, a mold, means for adjusting the mold for the casting of different sizes of type bodies or slugs, a plurality of matrix layouts interchangeably forming a part of the machine, connections for selecting any matrix in a layout, and for setting the mold to size therefor, and a switch whereby a plurality of said connections may be simultaneously changed to accord to any new layout.

114. In a type casting machine, a mold means for adjusting the mold for the casting of different sizes of type bodies or slugs, a plurality of matrix layouts interchangeably forming a part of the machine, connec-

tions for selecting any matrix in a layout, and for setting the mold to size therefor, and means intermediate the terminals of said connections whereby a plurality of said connections may be simultaneously changed to accord to any new layout.

115. In a type casting machine, a mold, means for adjusting the mold for the casting of different sizes of type bodies or slugs, a matrix layout, connections for selecting any matrix in the layout, and for setting the mold to size therefor, and means for simultaneously changing a plurality of said connections, leaving others of said connections undisturbed, whereby the position of one or more matrices in the layout may be changed, or the prescribed mold settings, for one or more of the matrices, changed.

116. In a type casting machine, a mold, means for adjusting the mold for the casting of different sizes of type bodies or slugs, a matrix layout, connections for selecting any matrix in the layout, and for setting the mold to size therefor, and means intermediate the terminals of said connections for simultaneously changing a plurality of said connections, leaving others of said connections undisturbed, whereby the position of one or more matrices in the layout may be changed, or the prescribed mold settings, for one or more of the matrices, changed.

117. In a type casting machine, a mold, means for adjusting the mold for the casting of different sizes of type bodies or slugs, a plurality of matrix layouts interchangeably

forming a part of the machine, connections for selecting any matrix in a layout, and for setting the mold to size therefor, and means whereby all of said connections may be simultaneously set to accord to any new layout.

118. In a type casting machine, a mold, means for adjusting the mold for the casting of different sizes of type bodies or slugs, a plurality of matrix layouts interchangeably forming a part of the machine, connections for selecting any matrix in a layout, and for setting the mold to size therefor, and a switch whereby all of said connections may be simultaneously set to accord to any new layout.

119. In a type casting machine, a mold, means for adjusting the mold for the casting of different sizes of type bodies or slugs, a plurality of matrix layouts interchangeably forming a part of the machine, connections for selecting any matrix in a layout, and for setting the mold to size therefor, and means intermediate the terminals of said connections whereby all of said connections may be simultaneously set to accord to any new layout.

Signed by us at New York city, county and State of New York, this 20 day of February, 1908.

WILLIAM NICHOLAS.
WILLIAM ACKERMAN.
